SO MULTIPLE   M/Z MULTIPLE

FIG. 7A(1).

LEADS 14-154

<img alt="Hand-drawn schematic diagram of a complex electrical circuit, likely for a particle detector. The diagram is organized into several sections: 1. Top section: 'SO MULTIPLE' and 'M/2 MULTIPLE' with leads IV-16V from FIG. 5E(1). 2. Middle section: 'SM1' and 'SM2' with associated switches 'Om1' and 'Om2'. 3. Bottom section: 'S1' and 'S2' with associated switches 'Tf1' and 'Tf2'. 4. Bottom left: 'Smb1' and 'Smb2' with associated switches 'Sm1' and 'Sm2'. 5. Bottom right: A terminal block with connections labeled 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, UNITED STATES PATENT OFFICE

2,344,885

ELECTRICAL CALCULATING EQUIPMENT

Ladislas Kozma and Jakob Kruithof, Antwerp,
Belgium, assignors to International Standard
Electric Corporation, New York, N. Y.

Application November 9, 1939, Serial No. 303,594
In Great Britain October 21, 1938

14 Claims. (Cl. 235—61)

This invention relates to calculating equipment and has for its object a construction of calculating equipment and problem setting equipment such that the equipment can be easily handled by any person without special training.

According to the main feature of the invention a calculating unit comprises means for recording any one of a plurality of different calculation signals in relation to a pair of numbers, and means for modifying the operation of the unitary calculating equipment under control of said calculation signal recording means whereby the same calculating equipment will perform a plurality of different calculations.

The calculating equipment may be arranged to 15 perform addition, subtraction and multiplication.

The invention will be clearly understood from the following description of an embodiment shown in the accompanying drawings in which:

Fig. 1 is a key figure showing how Figs. 4A(1)—8D(2) should be assembled in groups to form representation of the circuits of an apparatus embodying the present invention;

Figs. 2(1) and 2(2) when assembled taken together form the schematic circuits of an operator substation equipment;

Figs. 3(1) and 3(2) when assembled taken together form the schematic circuits of an access apparatus for associating a plurality of substation equipments with one calculating equipment;

Fig. 23 is a chart segregating the principal equipment into functional classes or subassemblies according to the functions performed and shown in the location of each such functional subassembly upon the drawings formed by Figs. 2(1)—8D(2);

45 Fig. 24 is a flow chart for summation showing the principal operational relationship of the several functional subassemblies involved in a summation computation;

Fig. 25 is a similar flow chart for multiplication.

In order to follow the complex circuits of the present invention each group of circuit drawings bearing the same initial number should be assembled together to form one unitary circuit component. For example, Figs. 4A(1), 4A(2), 4B(1), 4B(2), 4C(1), 4C(2), 4C(3), 4D(1), 4D(2), 4E(1), 4E(2), 4F(1) and 4F(2) should be assembled together as shown in the key Fig. 1. To facilitate accurate assembly of these Figures 4A(1)-4F(2) each sheet is provided with alignment arrows near each margin thereof. For easy reading of the circuits the edges of each sheet should be trimmed off along the points of the alignment arrows and then the trimmed sheets should be placed together as shown in key Fig. 1 and adjusted until the alignment arrows of one sheet just meet those of each adjacent sheet. Such assembly of these figures bearing the same initial number 4 will hereafter be referred to as drawing group 4. Similarly, Figs. 5A(1)-5H(2), Figs. 6A(1)-6F(2), Figs. 7A(1)-7D(2), Figs. 8A(1)-8D(2), Figs. 2(1)-2(2), and Figs. 3(1)-3(2) should also be assembled as shown in Fig. 1 to form assemblies or drawing groups hereafter referred to as "drawing group 5," "drawing group 6," "drawing group 7," "drawing group 8," "drawing group 2" and "drawing group 3" respectively. These drawing groups 2-8 together illustrate the circuits of the first embodiment of our invention.

The connections between one drawing group and another drawing group are indicated by reference characters so that the several drawing groups such as drawing groups 4, 5, 6, 7 and 8 need not be assembled together. Nevertheless, it will be convenient to dispose drawing groups 5, 6, and 7 above one another in the order mentioned and to dispose drawing group 4 approximately to the left of drawing group 5 and while disposing drawing group 8 approximately to the left of drawing group 7 as represented in Fig. 23. When so placed connections between drawing groups will approximately align in addition to being identified by reference characters.

In some cases where a substantial number of related wires extend from one drawing group to another drawing group (or even between different switches within one drawing group), the separate wires are brought together in a bracket and thereafter are all represented by one single extra heavy line which signifies a cable of several wires. At the destination of the cable the cable is again separated into its individual wires in a bracket, the separate wires being distinguished from one another by numbers at both ends of the cable.

To facilitate study of the operation of the present invention time charts are provided in addition to the circuit drawings, these time charts serving to indicate graphically the operations which are verbally described in the detailed description of operation included in the specification. In these time charts the different pieces of apparatus are represented by reference characters, the characters relating to relays being enclosed in parenthesis to distinguish them from other characters representing switches, keys etc. The energization and deenergization instants of any relay are indicated by short vertical strokes whereas the interval during which the relay is actually in operative position is represented by a medium heavy horizontal line commencing at the instant when the relay first arrives at operative

position (i. e., shortly after the vertical dash representing energization) and continuing until the instant when the relay moves to nonoperative position (i. e., shortly after the short vertical dash representing deenergization). In the case of step-by-step switches and sequence switches short vertical dashes are still used to represent the energizations and deenergizations of the operating magnets but the motion of the switches is represented in the case of step-by-step switches by a staggering or offsetting of the medium heavy line representing the switches, numerals being provided at each offset point to designate the position into which the switches is thereby stepped. In the case of sequence switches an extra heavy horizontal line opposite the operating magnet represents the interval during which the switch is maintained in rotation by the operating magnet. It will be noted that such extra heavy line begins and terminates shortly after the short vertical dashes representing energization and deenergization of the operating magnet. In addition to the reference character representing the operating magnet, sequence switches have reference characters representing the individual brushes to control cams thereof and extra heavy horizontal lines opposite these latter reference characters indicate the intervals during which the corresponding brushes make connection with their cams. For keys likewise, extra heavy horizontal lines are used to represent intervals during which the key contacts are closed. In general, the operate and release times of relays and step-by-step switches are each represented by one arbitrary unit of time, the time units being indicated by the time scale across the tops of the figures. In the case of certain magnets CM1-CM4PM the operating times are arbitrarily assumed to be four time units since it is well known that such magnets are substantially slower than telephone type relays and step-by-step switches. No attempt to accurately represent small variations in operating times between different relays has been made.

GENERAL ARRANGEMENT OF CALCULATION SYSTEM AND TYPES OF SERVICE RENDERED THEREBY

The calculation system shown comprises an electrically controlled calculating equipment (shown in drawing groups 4-8) which is adapted to be remotely operated over a reasonably small number of wires from any one of a plurality of operator's subsets, of which only one is shown in drawing group 2. This calculating equipment may be located at any convenient central point not necessarily adjacent the points where calculation service is desired. At each point where such service is desired there may be located an operator's subset. An access circuit shown in drawing group 3 (which may be located adjacent the calculating equipment) serves to associate any desired one of the subsets with the calculating equipment over 15 wires in response to closure of a start key at the desired subset. Thereupon a number of transmitting keys provided in the subset become effective to enable the operator to transmit a problem to the calculating equipment, while a printing mechanism also provided in the subset becomes effective to print back at the subset the problem as actually received by the calculating equipment, and subsequently to print the answer computed by the calculating equipment.

The electrically controllable calculating equipment shown in drawing groups 4-8 is capable of performing addition, subtraction, and multiplication. In the case of addition and subtraction, successive additions and/or subtractions may be made repeatedly in any order. Thus, for example, the following problem may be submitted.

$$314.16 + 78.54 - 760.15 + 27 =$$

In response to the submission of such a problem the calculating equipment will print the problem as it receives it and then after the equals sign it will automatically determine and print the answer. In the case of multiplication only a single pair of numbers are intended to be multiplied together. Thus, the machine will solve $760.15 \times 26.05 = 19801.9075$ but is not intended to solve in one operation such problems as $760.15 \times 26.05 \times 3.14 = 62177.98955$.

The electrical calculating equipment of drawing groups 4-8 comprises the following principal parts:

A receiving portion, principally shown in drawing group 4, for receiving, counting and storing incoming digits and signs as well as for controlling the sending back of such digits and signs to the printer of the subset.

A computing portion principally shown in drawing groups 5, 6, 7. This portion can be further subdivided into a readout and sequence control portion shown principally in drawing group 5, a distributor portion shown principally in drawing group 6, and an accumulator portion shown principally in drawing group 7.

A solution sending portion principally shown in drawing group 8, for checking the solution produced by the computing portion and then sending such solution out to the subset for printing.

According to one feature of the invention the actual computing portion of the calculating equipment is provided in duplicate and the solutions obtained thereby are checked against each other by the circuits of drawing group 8 before being sent to the subset for printing. Thus all the circuits shown in drawing groups 5-7 should be understood to be duplicated. Also any parts of the circuits of drawing groups 4 or 8 which are actually used for computation will also be seen to be provided in duplicate.

TYPES OF APPARATUS USED IN CALCULATOR EQUIPMENT

The equipment is principally made up of three different kinds of apparatus, namely, relays, sequence switches, and step-by-step rotary switches. The relays are of the ordinary telephone type and are for the most part quick to operate and quick to release. Each relay in the first embodiment of the invention is designated by one, two or three letters, alone or by one or two letters followed by a number, only the first letter being capitalized and the succeeding letters (if any) being small as for example, Q, Mf, Att, Al, C37, C100, Ar2, St18. Thus one can recognize relay designations by the fact that they always have one and only one capital letter.

The sequence switches and step-by-step rotary switches each comprise a number of contact switching members and a single operating magnet. The operating magnets of both these types of switches are designated by reference characters consisting either of three capital letters or of two capital letters and a number, as for ex-

ample, sequence switch magnet RLM or R2M, or step-by-step switch magnet TTM, or SM2. The magnet of any step-by-step rotary switch is shown as an elongated rectangle somewhat like a relay but having associated therewith a small representation of a stepping pawl and ratchet wheel. The magnets of the sequence switches, on the other hand, are represented by rectangles which are almost square in form and which have no stepping pawls or wheels adjacent thereto.

The step-by-step rotary switches are of the well known type wherein a plurality of brushes are swept over a corresponding plurality of contact arcs by a ratchet wheel movement which is arranged to be tensioned on energization of the associated magnet but advanced upon release of such magnet. For convenience the brushes and arcs of these switches are represented in conventional fashion as being somewhat separated from the operating magnet. The brushes and arcs of any particular step-by-step switch are designated by four small letters, or by three small letters and a number. In the former case the first three of the four letters correspond to the three letters which designate the operating magnet. In the latter case the first two letters and the number correspond to the magnet's designation. Thus, for example, bdma, bdmb and bdmc, Fig. 8D(1), are the three brushes and arcs of the rotary step-by-step switch whose magnet BDM is shown in Fig. 8B(1), while sma7, smb7, smc7, and smf7 are the four brush-and-arc sets of the rotary switch whose magnet is SM7.

There are two sizes of step-by-step rotary switches employed in the equipment of the present invention. The smaller size has eleven contacts in each arc and for convenience these contacts may be considered to be numbered as follows: 0, 1, 2, 3, 4, 5, 6, 7, 8, 9, X. The larger size step-by-step switch has twenty-two contacts in each arc which may be considered to be numbered 0, 1, 2, 3 . . . 20, 21. All these step-by-step switches are arranged in known manner with a sufficient number of wiper arms on each brush so that when a step causes one arm of a brush to leave the last contact of the arc this same step brings the succeeding arm of the brush into engagement with the first contact of the arc. For schematic purposes, therefore, it may be considered that each of the brushes shown associated with a contact arc in the drawings has only a single wiping arm as shown, but that such single arm is arranged to jump instantly from the last to the first contact when the switch makes its eleventh (or twenty-second) step.

The sequence switches are of the type generally used in the telephone industry, this general type of switch being clearly described in United States Patent 1,127,808 to Reynolds et al., February 9, 1915. As is clearly described in the above mentioned patent, each sequence switch, (such as sequence switch RA, Figs. 5B(2) and 5C(2) comprises a shaft adapted to be engaged with a constantly rotating power drive member (not shown) by coupling means controlled by its magnet (RAM, Fig. 5C(1)). On such shaft are arranged a plurality of laminated discs ordinarily referred to as "control cams." Each such laminated disc includes an insulating disc sandwiched between two thin bronze annuli. The two thin annuli are electrically connected together by rivets but are insulated from the shaft of the sequence switch which drives them. Four brushes are provided which wipe respectively on

the inner and outer circumferences of the two annuli. These annuli are, furthermore, cut away according to the codes indicated on the drawings so that the four brushes may contact only at certain points in the rotation of the combined laminated disc. At other times when the brushes are not making contact with their respective bronze annuli, these brushes wipe directly against the insulating disc.

Since the two bronze annuli of any "control cam" are connected only to one another, the only circuits which can be established by the aid of such a "control cam" are circuits from one to another of the four brushes which are associated with such "cam." In order to enable still more complex circuits to be established, provision is made for interconnecting the bronze annuli of any two adjacent "control cams" by means of a conducting brushing insulated from the shaft but bearing against non-cut-away portions of two 20 mutually opposed bronze annuli.

The conventional symbol used in the circuit drawings to represent a control cam of a sequence switch is a narrow black bar with a dot at one end somewhat resembling the symbol for a relay armature, but of somewhat greater length and having four triangles or arrowheads (representing the four brushes) disposed on the two sides thereof. When two or more adjacent cam symbols are shown interconnected by lines, this indicates that conducting bushings are provided as above described for interconnecting the annuli of the corresponding control cams. Thus the cams RAB and RAC of the RA sequence switch, Fig. 5B(2), being connected together, permit connections to be established between different ones of the eight brushes associated with two cams RAB and RAC.

The four brushes which wipe on any given control cam of a sequence switch are individually referred to by using the designation of the cam together with an indication as to the position of the brush as shown in the circuit drawings. Such indication as to position may in some cases be given by words, e. g. "the upper left-hand brush of cam RAB." In other words, the indication as to position may be given by the symbols

+, +, +, +,

which should be understood to mean "upper left," "upper right," "lower left" and "lower right" respectively.

The times at which each brush makes contact with the conducting portion of its associated control cam are indicated in the drawings by coded legends adjacent to each brush. In interpreting these coded legends one complete revolution of the sequence switch should be considered to be divided into eighteen parts so that the rotation from "position 1" to "position 2" or from "position 2" to "position 3," etc. represents 20°. The numbers used in the legends associated with each brush are based upon such division of a complete rotation into eighteen separate positions, 20° apart. The designation "2" opposite any brush of a sequence switch indicates that such brush makes contact with the conducting portion of its control cam in "position 2" and for a few degrees preceding and following such position. Ordinarily such extension of the conducting interval is taken to be plus and minus 5°, so that a brush marked "2"

would actually make contact from position 1 1/2 to position 2 1/2.

When a series of separate numbers separated by dots are applied to a brush this indicates that such brush makes contact at and near each of the positions so indicated. Thus, the legend 2,4,6,8,10,12,14,16 applied to the right hand upper brush of control cam RDC indicates that such brush connects with the conducting part of the cam from position 1 1/2 to position 2 1/2 then is open from position 2 1/2 to position 3 3/4, then again connects from position 3 3/4 to position 4 1/4, then is again open from position 4 1/4 to position 5 1/4, etc. When a pair of numbers (integral or fractional) are separated by a diagonal stroke, this indicates that the corresponding brush makes connection shortly before the first number and remains connected to its cam until shortly after the last number of the pair. Thus, for example, the legend 1/18 applied to the upper left brush of control cam RDC indicates that such brush makes connection in position 18 1/2 (i. e. 5° before position 1) and continues to remain connected until position 18 1/2. It will thus be seen that this upper left brush and control cam RDC is connected at all times excepting during the short interval from position 18 1/2 to position 18 3/4.

In many cases a brush is intended to be connected to its control cam during two or three different periods, each of substantial length. This may be indicated by applying two or three notations adjacent the same brush. Thus the upper left brush of RAC in Fig. 5B(2) bears the legend 1 1/2/6 1/4 . 7 3/4/12 1/4 . 13 3/4/18 1/2 to indicate that this brush makes connection with the conducting portion of cams RAC and RAB during a first period extending from position 1 1/2 to position 6 1/4, then again during a second period extending from position 7 1/2 to position 12 1/2, and finally during a third period extending from position 13 1/2 to position 18 1/2.

In addition to the regular control cams above described each sequence switch is conventionally provided with a special control cam distinguished by the final letter A and used for controlling the stopping of the sequence switch. Such "A" cam conventionally bears only one brush (in addition to some continually wiping brushes, not shown, which are internally connected to the operating magnet). The one brush which is thus provided for external wiring is conventionally designated by numbers which represent not the positions during which the brush makes a connection but rather the positions during which the brush is open. Thus, if the brush shown associated with the "A" cam of a sequence switch bears the designation 1.7.13, as in the case of cam RBA of sequence switch RBM, Fig. 5B(1), this indicates that the brush is connected at all times excepting at or near positions 1, 7 and 13. The exact points at which such brush ceases to make connection are chosen sufficiently far ahead of positions 1, 7 and 13, respectively, so that with due allowance for the stopping time of the sequence switch this switch will come to rest exactly in position 1, or 7, or 13.

In addition to the regular control cams and "A" cams, which are conventionally associated with all sequence switches in the telephone and telegraph and remote control arts, the sequence switches used in the present invention are additionally provided with impulse generating cams which are in the nature of true cams rather

thin laminated discs and which are provided each with a single brush and a single return wiper. These impulse generating cams (hereafter called "pulsers") are represented in the drawings by toothed members associated with conventionalized wipers; see for example, pulsers AM, RAN . . . RAS, RAT of sequence switch A, Fig. 5B(2). These pulsers are not ordinarily provided in sequence switches but are added to the sequence switches of the present invention in order to permit the frequent breaking of comparatively large inductive currents without substantial cam erosion.

In addition to the relays and the step-by-step and sequence type switches certain other kinds of apparatus are used in the present invention. These include indicating lamps, such as lamp L in the lower left corner of Fig. 5D(2); a keyboard shown diagrammatically by contact closing keys, such as key K0, key K3 or key K8 20 (drawing group 2 (which close one contact, two contacts or three contacts respectively); and finally, printing apparatus schematically represented by the four character selecting magnets CM1, CM2, CM3, CM4, together with the printing magnet PM. The exact details of the printing apparatus which is thus schematically represented by the five magnets CM1/CM4, PM is not an essential part of the present invention. In fact the present invention may be practiced with any sort of printing equipment which selects characters in response to energization of different combinations of four wires and prints the character so selected in response to energization of a fifth wire (one such printer being known in U. S. Patent 1,665,594). Preferably, however, contacts should also be provided, as indicated in Figs. 2(1) and 2(2).

LOCATION OF APPARATUS AND CLASSIFICATION BY FUNCTION

In order to facilitate finding any one of the relays or switches in the extensive circuit drawings of Figs. 2(1)-8D(2), the location of all the apparatus by functional groups is shown on a small scale in Fig. 23. In this figure the seven "drawing groups" 2-8 are represented approximately to true scale, and each such drawing group is shown as subdivided into a number of smaller areas numbered GI-B35. In subdividing the seven drawing groups into 35 areas, moreover, the boundaries of the areas have been carefully chosen so as to separate the apparatus into groups each of which has more or less functional unity. Therefore the 35 areas represented in Fig. 23 besides serving to facilitate the finding of a given relay also serve to classify the apparatus according to the function performed thereby and thus facilitate a comprehension of the invention.

The following two tabular indexes list the relays and switches included in each of the 35 areas or functional groups, the first one being arranged in order of groups and the second index being arranged alphabetically by the designations of the relays, keys, and switches. In order to render these indexes and Fig. 23 still more useful it will be found advantageous (after the circuit drawings have been trimmed and assembled into groups) to mark directly on such assembled circuit drawings in transparent colored ink the boundaries shown in Fig. 23 using the aid of the following table to check the position of each boundary as it is drawn. Then the sec-

ond of the following tables may be used as a guide to quickly locate any relay or switch.

GENERAL DESCRIPTION OF RECEIVING AND STORING CIRCUITS

The circuits for receiving and storing digits and signs and for counting the digits and signs so received, as well as for sending corresponding signals back to the operator's control set for printing the problem, are principally shown in drawing group 4. However, several of the relays used for storing the signs (A₄₁, M₄₁, M₄₂) are for convenience shown in drawing group 5 or 8, while two of the digit counting chains (I_a, I_b, I_c, D_{r1}, C_{r1}, D_{r2} . . . C_{r4}, and V_a, V_b, V_c, B_{r1}, V_{r1}, B_{r2} . . . V_{r4}), are shown in drawing group 6, and all three digit counting switches (BDM, PDM, VDM) are shown in drawing group 8.

The individual receiving relays B₁, B₂, B₃, together with the common "sign receiving" relay S_r serve for the reception of operation signs, such as +, -, ×, as well as for the reception of other signs, such as "decimal point" (.), and "equals" (=). For de-coding the signs, relays S₁, S₂, S₃ and S₄, are provided which are operated in different combinations from relays B₁, B₂, B₃; and the contacts of these relays S₁, S₂, S₃ and S₄ are wired to select one of six relays A_d, S_u, M_u, P_o and E_g, which respectively represent the five signs, plus (+), minus (-), times (×), decimal point (.) and equals (=). The relay D_o is arranged to operate in series with A_d, S_u or M_u, so that this relay D_o responds to every operation sign but not to other types of signs.

The individual receiving relays A₁, A₂, A₃, A₄ and O_s, together with the common "digit receiving" relay D_r serve for the reception of incoming digits. Since the digits are stored in the same coded form as received, no digit de-coding relays are necessary.

Relays C₁, C₂ . . . C₅₈, are used for storing the digits of the first number, while relays C₅₁, C₅₂ . . . C₁₀₈ are used for storing the digits of the second number. The set of four relays C₁, C₂, C₃, C₄, which may be collectively referred to as NAI, serve to store the first digit of the first number; relays C₅-C₈, collectively designated NA2, serve to store the second digit of the first number; relays C₉-C₁₂, collectively designated NA3, serve to store the third digit of the first number, etc. The relays C₃₃-C₄₇ form a combined input and output distributor for distributing the received digits to the successive groups NAI, NA2, and also for rendering these groups NAI, NA2, etc., successively effective to control the signals sent back to the operator's sub-set. In similar fashion relays C₅₁-C₆₂ form eight storage groups NB1, NB2 . . . NB8 for the digits of the second number, while relays C₈₃-C₉₈

form a combined input and output distributor similar to that formed by relays C₃₃-C₄₈.

Because of the similarity of successive ones of the storage sets NAI-8 and NB1-8 and of the associated distributor relays, some of these storage sets and their associated distributor relays have been omitted from the circuit drawings. Thus only the first three and last of the A storage sets are shown in drawing group 4 (i. e. NAI, NA2, NA3 and NA8). Of the B storage sets only the first and last are shown in drawing group 4.

For actuating the distributor C₃₃/C₄₈ or the distributor C₈₃/C₉₈, the digits of each number must be counted as they are received. This is done by a counting chain composed of eight relays D₁, F₁, D₂ . . . F₄, preceded by three relays F_t, S_t, T_t.

In order to direct the successively received numbers to the NAI-NA8, then to the NB1-NB8, then again to the NAI-NA8 storage groups, the operation signs must also be counted, since such operation signs mark the transition from one number to the next. For so counting the operation signs, the three relays F_o, S_o, T_o, are provided. These are actuated for counting purposes by D_o, which is arranged to be energized in series with those relays corresponding to operation signs, as previously described. Relay pairs E_c, B_a, and then A_c, A_e are alternately operated by said F_o relay to render the storage sets NAI-8 and NB1-8 alternately effective in accordance with whether an odd or even number of operation signs have been counted since the start of the computation.

For controlling the sending back to the operator's sub-set of signals corresponding to the digits and signs received, relays A_d, S_u, M_u, C_a, P_o and E_g, are wired to energize appropriate ones of the transmitter relays O_g, T_w, F_p, F_q, Fig. 8A(1), for controlling the selection of characters representing signs; whereas the contacts of the storage sets NAI-NA8, or NB1-NB8, when extended through appropriate distributor relays and digit preparing relay D_p, are adapted to control the same four transmitter relays O_g, T_w, F_p and F_q, for the selection of digits. The actual operation of the printing magnet is controlled by relay P_s for printing signs and by relay P_d for printing digits, except that in the case of the digit 0, the actuation of the print magnet is sometimes controlled by O_h instead of by D_p.

GENERAL DESCRIPTION OF READOUT OR DIGIT TRANSFER CIRCUITS

For transferring digital values from the storage sets NAI, NA8 or from storage sets NB1, NB8

to the solution accumulator shown in drawing group 7, a number of sequence switches, shown scattered through drawing group 5, are provided for use as readout mechanisms. More specifically sequence switch RA is provided for additively or subtractively transferring a number stored in storage sets NA1-NA8, while sequence switch RB is provided for additively or subtractively transferring a number stored in storage sets NB1-NB8. The set of eight readout relays Ar1-Ar8 (of which only the first two and the last one are shown) are provided for use in cooperation with either sequence switch RA or sequence switch RB, each of these eight relays being controlled as hereafter explained from a corresponding one of the eight control cams RAE-RAL (or RBE-RBL) in dependence upon the contact combination which is closed in the corresponding one of the eight storage sets NA1-NA8 (or NB1-NB8). Each control cam such as 15 RAE which controls the operation of a relay such as Ar1 has associated with it a pulser such as RAV cut so as to generate the maximum possible number of pulses which may be needed for one digit. The intended principle of operation is that desired ones of these pulses shall be rendered effective by the actuation of the corresponding Ar relay, which supplies ground to its pulser. The exact intervals out of each cycle during 20 which the Ar relays are operated will determine the number of pulses transmitted, these exact intervals being controlled by the values of the stored digits, and more fully explained hereafter.

Normally if the front contact of Ar1 is 25 grounded by relays Ad1, Ad2, the pulses which are rendered effective will correspond to the true number stored in NA1. If, however, the back contact of relay Ar1 is grounded by relays Su1, Su2, then, as explained hereafter, the pulses which are rendered effective will correspond to the nine's complement of the digit stored in set NA1.

Sequence switch RB is identical with switch RA and is wired similarly. For effecting multiplication more rapidly the sequence switches R2, R4 and R5 are provided, which act as readouts of certain multiplicand-multiples rather than simple readouts of the multiplicand itself. The pulsers and control cams of sequence switch R2, for example, are arranged to yield pulses corresponding to twice the value of the digits stored in NA1-8 (i. e. twice the multiplicand). The intended principle is that the pulser of any given order (e. g., R2V) shall be rendered effective and ineffective through control cams of the same order and of the next lower order (e. g., R2F and R2G) in dependence upon the contact combinations of the storage sets of the same order and next lower order (e. g. NA1 and NA2) at such intervals as to deliver over the readout wire of said given order (e. g. 401) pulses corresponding to the units value of twice the digit stored in the same order storage set NA1 plus the ten's value of twice the digit stored in the next lower order storage set NA2. For example, if the digit stored in NA1 were 8 and that stored in NA2 were 4 or less, six pulses (corresponding to the units component of twice 8) should be delivered to 401. If, however, the number stored in NA2 were 5 or greater, seven pulses rather than six should be delivered to readout wire 401.

It should be noted that no readout relay, (such as Ar1 used with switches RA and RB described above) is interposed between control cams R2F, 70

R2G and pulser R2V. Such a relay is not necessary since the R2 sequence switch is only intended to be used for additively transferring the double value of the stored number and never for subtractively transferring such double value.

Both the addition and subtraction sequence switches, such as RB or RA and the multiplication sequence switches, such as R2, R4 and R5 have their impulsive and control cams arranged 10 to readout the desired digital value in a sort of code rather than in pure pulse form. For digits 1, 2, 3 or 4, corresponding numbers of "unit" pulses are sent out in ordinary uncoded form. For the digit 5, however, a single "V" pulse rather than 5 "unit" pulses is sent out over the appropriate readout wire, such as 401, 402 . . . 408, this single "V" pulse being distinguished by the fact that it is transmitted at an earlier point in the readout cycle than the ordinary "unit" pulses. For digits 6, 7, 8 and 9, a "V" pulse followed by 15 1, 2, 3 or 4 "unit" pulses are sent out.

As will be hereafter explained the accumulating structure includes two accumulators, one being a unit accumulator and the other a V pulse accumulator, and also include means for rendering only the V pulse accumulator effective during the first part of a readout cycle and subsequently for making only the unit accumulator effective during the remainder of the readout cycle under control of timing signals transmitted over leads LF and LM, respectively.

Thus the digital values readout from any one of the readout switches are distributed between two accumulators. Later, at the end of a computation the accumulators on these two accumulators are combined as explained hereafter.

The general plan according to which the pulsers and control cams of sequence switches RA and RB are laid out can best be seen in Fig. 14C which should be studied with Figs. 5B(2), 5C(1) and 20 5C(2). As clearly shown in Figure 14C, each of the pulsers RAV, RAW, RAX, RAY, RAZ, RABB, RACC and RADD, delivers first a single impulse (serving as a V pulse) and then after a pause four more impulses (serving as unit pulses). Of the five possible impulses generated by a pulser, such as RAV, only certain ones are rendered effective by the associated relay, such as Ar1. The movement of Ar1 which determines which of the pulses shall be effective is controlled through a control cam, such as RAE, from a storage set, such as 30 NA1.

If the particular code "1, 2, 4, 5" is used for 35 storing digits in the storage sets NA1-NA8, as is the case in the embodiment chosen for illustration, then the conversion into the partially coded form, consisting of unit pulses and V pulses, is particularly simple.

The storage sets NA1-NA8 are illustrated as 40 sets of relays complete with all their contacts in classification area G8 of drawing group 4 (only the first three and the last of these sets being shown). For convenience the readout contacts of these sets are again illustrated at the top of classification area G14 of drawing group 5. This makes it possible to analyze the operation of readout RA from drawing group 5 and the time chart of Fig. 14C without constantly referring to drawing group 4.

As best shown in Fig. 5C(1) the first three contacts of any storage set, such as NA2, control the position of the corresponding readout relay, such as Ar2, during the part of the readout cycle in which the four unit pulses are generated by the corresponding impulsive cams, such as RAW, (i. e., during the rotation of sequence switch RA

from position $1\frac{1}{4}$ to position $5\frac{1}{4}$). The first of these contacts *na21* is wired to extend a ground through the upper left brush of control cam *RAF*, thence through the cam and its lower left brush to relay *Ar2* thus actuating this relay for an interval which includes the first of the four unit pulses. In similar manner contact *na22* is wired to extend a ground through the upper right brush of control cam *RAF* thus actuating relay *Ar2* for an interval which includes the second and third of the four unit pulses. Likewise, contact *na24* is wired to extend a ground through the lower right brush of control cam *RAF*, thus actuating relay *Ar2* for an interval which includes the fourth of the unit pulses. It should be noted that the code used for storing digits is such that contact *na21* will never be closed with either contact *na22* or contact *na22*. Therefore, it is permissible for the control interval of the lower right brush of *RAF* to overlap the control intervals of the upper left and right brushes of this cam, as shown in Fig. 14C.

Contact *na25* controls the operation of the *Ar2* relay through the appropriate contact of the pair of relays *Fa1*, *Fa2* instead of through a control cam of the *RA* sequence switch. This pair of relays *Fa1*, *Fa2*, is arranged to be energized briefly during the interval, while *RA* is rotating from position 1 to position $1\frac{1}{4}$ and thus the *na25* contact is effective at the time when the first or *V* pulse is generated by the cam *RAW*.

In the foregoing description eight pulsers and eight control cams are referred to, the eight pulsers being *RAV*, *RAW*, *RAX*, *RAY*, *RAZ*, *RAB*, *RAC*, *RAD* and the eight corresponding control cams being *RAE*, *RAF*, *RAG*, *RAH*, *RAI*, *RAJ*, *RAK*, *RAL*. Although all of these pulsers and control cams are represented in Fig. 4C only the first two and the last one of each set are shown in the circuits of drawing group 5. The readout switch *RA* (or *RB*) will therefore be seen to require only one pulser and only one control cam per denominational order. Certain supplemental cams, such as *RAB*, *RAC* and *RAD* are provided on the *RA* readout device, the general function of these cams being to control the timing of various miscellaneous switching operations in the course of a readout cycle, as will appear more clearly hereafter.

Readout *RB* is in every way similar to readout *RA*.

The relationships of the cams of the multiple sequence switches *R2*, *R4* and *R5* are similar in principle but are slightly more complex in view of the fact that these sequence switches constitute multiple readouts. In the case of each of these sequence switches each pulser, such as *R2V*, is associated with it not one but two control cams, such as *R2F*, *R2G*. In the case of these sequence switches also, only those pulsers and control cams associated with the highest, next lower, and lowest orders are illustrated in Figs. 5E(2)-5F(2). As in the case of the *RA* and *RB* sequence switches the multiple readout switches *R2*, *R4*, and *R5* are also provided with supplementary control cams such as *R2B*, *R2C* and *R2D* for controlling the timing of miscellaneous switching operations during a readout cycle.

Referring specifically to readout switch 2 an understanding of this readout switch can best be gained by referring to both classification area 317 of drawing group 5 of the circuit drawings (i. e., the top of Figs. 5E(2)-5F(2)) and Fig. 20. The latter is a cam chart which clearly illustrates the relative timing of a pulser such as *R2W*, with

respect to the associated pair of control cams, such as *R2H*, *R2I*. As indicated in these figures, the four upper brushes of *R2H* and *R2I* are connected to contacts *na21*, *na22*, *na24* and *na25* (shown without their relays in G. 14 of drawing group 5) (represented by a legend but not shown in drawing group 5), in such manner that *na21* controls transmission of two unit pulses ($2 \times 1 = 2$), while *na22* controls the transmission of four unit pulses ($2 \times 2 = 4$, and *na24* controls the transmission of one "V" pulse and three unit pulses $2 \times 4 = V + 3$). It will be noted that *na25* does not control any pulses from the *R2W* pulser since 2×5 gives 0 in the units place. The "5" contact is next lower denomination, i. e., *na25* does, however, control transmission of one unit pulse since $2 \times 5 = 1$. Thus it will be seen that of the total number of pulses capable of being produced by pulser *R2V* only those ones are rendered effective which will represent the units component of twice each of the code elements stored in the same order storage set plus the tens component of twice each of the code elements stored in the next lower order storage set.

The principles of operation of the quadrupling readout switch *R4* are essentially like those of *R2* above described. A detailed understanding of the exact timing of the *R4* readout can best be gained by studying the cam chart of Fig. 21 in conjunction with the circuit drawings of drawing group 5, especially area G18 (i. e., especially the central portions of Figs. 5B(2)-5C(2)). As indicated in the circuit diagrams of drawing group 5, the five significant brushes of any control cam pair (e. g.,

R4G+, *R4G+*, *R4F+*, *R4F+*, *R4F+*) are connected to contacts *na1 1*, *na1 2*, *na1 4*, *na2 4*, *na2 5*, respectively. By reference to the cam timing chart of Fig. 21 it will readily be observed that the connections just mentioned enable *na1 1*, *na1 2* and *na1 4* to control the pulser *R4V* during time intervals corresponding to four unit pulses, one *V* pulse with three unit pulses, and one *V* pulse with one unit pulse, respectively. Thus, if we assume that the *V* pulses have a value of 5 (which will be demonstrated in connection with the description of the accumulators) it will be seen that contacts *na1 1*, *na1 2* and *na1 4* control such ones of the pulses generated by pulser *R4V* as to represent the values 4, 8 and 6, respectively (corresponding to the units component of 4×1 , 4×2 , and 4×4 , respectively). It will be noted that contact *na1 5* does not control any of the pulses generated by pulser *R4V* since the unit component of 4×5 is 0.

In the same way it can be seen that contacts *na2 4* and *na2 5* (which represent the codes "4" and "5" in the next lower order storage set *NA2*) control such ones of *R4V*'s pulses as to represent the values 1 and 2 respectively (corresponding to the tens component of 4×4 and 4×5). Thus, it will be seen that of the total number of pulses capable of being produced by pulser *R4V* only those ones are rendered effective which will represent the units component of four times each of the code elements stored in the same order storage set plus the tens component of four times each of the code elements stored in the next lower order storage set. It will be noted that the rule just above quoted is essentially the same as the rule previously quoted for the doubling readout *R2* except that the expression "four times" has been substituted for the word "twice."

The quintupling readout switch R5 is very similar to the other two multiplying readouts. A detailed understanding thereof can best be gained by studying the cam chart of Fig. 22 in conjunction with the circuit drawings of drawing group 5, especially area G19 (i. e., especially the lower portions of Figs. 5B(2)-5C(2)). As indicated in the circuit diagrams of drawing group 5, the five significant brushes of any control cam pair (e. g.,

R5G+, R5F+, R5G+, R5F+, R5F+)

are connected to contacts na1 1, na1 5, na2 2, na2 4, na2 5. By reference to the cam timing chart of Fig. 22 it will be seen that the connections just mentioned enable na1 1, na1 5 to control the pulser R5V during time intervals corresponding to one V pulse each. Thus the pulses controlled by contacts na1 1 and na1 5 represent the value 5 in each case since the units component of 5×1 is 5 and the units component of 1×1 is also 5. It will be noted that the V pulses transmitted under the control of these two contacts na1 1 and na1 5 occur successively so that, if necessary, both such V pulses can be transmitted in case both the code elements "5" and "1" are simultaneously stored in the Na1 storage set. It will be noted that contacts na1 2 and na1 4 do not control any of the pulses generated by pulser R5V since the unit component of 5×2 or of 5×4 is 0.

In the same way it can be seen that contacts na2 2, na2 4 and na2 5 (which represent the codes "2," "4" and "5" in the next lower order storage set Na2) control such ones of R5V's pulses as to represent the values 1, 2 and 2 respectively (corresponding to the tens component of 4×2 , 4×4 and 4×5). Thus it will be seen that of the total number of pulses capable of being produced by pulser R5V only those ones are rendered effective which will represent the units component of five times each of the code elements stored in the same order storage set plus the tens component of five times each of the code elements stored in the next lower order storage set.

The rule just above set forth corresponds exactly to that previously set forth for readouts R2 and R4 except for the substitution of the expression "five times" in place of the expressions "twice" or "four times." The rule may be generalized as follows: Of all of the possible pulses produced by a pulser of any given order in any one of the multiple readout devices only such ones are actually transmitted which will represent the units components of n times each of the code elements stored in the same order storage set plus the tens components of n times each of the code elements stored in the next lower order storage set where " n " is the characteristic numeral of the readout device. It should not be hastily assumed that the value of pulses transmitted from a pulser of any given order will always correspond to the units component of n times the whole digit stored in the same order storage set plus the tens component of n times the whole digit stored in the next lower order set. In some cases such a relationship will hold and in other cases it will not. Referring, for example, to the R4 readout device if the digit stored in the same order storage set is 2 and the digit stored in the next lower order set is 4 then the total pulses transferred over readout wire 401 will exactly correspond to the units component of 4×2 plus the tens component of 4×4 i. e. 9. If, however, the number stored in the same order storage set is 8 and that stored in the next lower order

set is 3, then the total pulses transmitted over the readout wire 401 will be different from the unit component of 4×8 (namely 2) plus the tens component of 4×3 (namely 1) which would give a total of 9. The reason for this is that the 5 is not considered as a whole but is considered as consisting of its components 5, 2, and 1. Therefore, the pulses actually transmitted over readout wire 401 will be such as to represent the unit 10 component of 4×5 (namely 0) plus the unit component of 4×2 (namely 8) plus the units component of 4×1 (namely 4) plus the tens component of 4×2 (namely 0) plus the tens component of 4×1 (namely 0). It will be noted that 15 this gives a total value of 12 units delivered over readout wire 401, these values of 12 units being transmitted in the form of one V pulse and several unit pulses, as will be seen by referring to Fig. 21 and assuming that only those pulses controlled by contacts na1 5, na1 2, na1 1, na2 2, na2 1 are effective.

It will be noted when comparing the A cam of switch R4 with the A cams of the other switches R2 and R5 that R4A has only one normal position whereas R2A and R5A each have two normal positions. The result is that the R4 readout makes a complete revolution per cycle while the R2 and R5 readouts make only a half revolution per cycle. The reason for this is apparent upon 25 comparing Figs. 20, 21 and 22 from which it will readily be seen that the cycle of Fig. 21 is too long to be crowded into a half revolution.

It will be seen that each of the readout sequence switches RA, RB, R2, R4, R5, send out impulses 35 through their pulses along nine lines numbered 400, 401, 402 . . . 408. Each of the readout switches has eight sets of cams and pulses which may deliver pulses into any eight denominational orders of the two accumulators through lines 40 401-408, as well as into an additional (higher) order through line 400 (such additional order being considered as an overflow order of the accumulators). The delivery of pulses from the right orders of the readout RA, RB, R2, R4, R5 45 into any group of orders of the two sixteen-order accumulators is determined by several column shift mechanisms subsequently described.

In the immediately following discussion relating to multiplying operations all of the readout 50 switches, each having eight groups of denominational readout cams and pulsers, may be assumed to be connected to the nine highest orders of the accumulators, wire 401 leading from the highest order group of cams to the second highest accumulator order, and wire 408 leading to the ninth accumulator order.

Attention should be called to the fact that pulsers R2DD, R4DD, R5DD in the lowest cam group of the switches are not connected directly 60 to the corresponding readout wire 408 which leads to the lowest accumulator order now in use, but rather are connected to this wire 408 through control cams R2E, R4E, R5E, respectively. The purpose of this connection is to enable the pulsers R2DD, R4DD, R5DD to be also used for transmitting the necessary pulses to lead 400, which is a readout wire leading to the highest order accumulator now in use, i. e. to the overflow order.

This lead 400 must be supplied with pulses corresponding to the ten's component of the partial product derived from digit stored in NA1 (i. e. the highest order multiplicand digit). Thus, if the number stored in NA1 be assumed to be 6, and the doubling switch R2 be assumed to be in use, the units component of the partial product, name-

ly, 2, should be transmitted to the readout wire 481, but the corresponding ten's component, namely, 1, should be transmitted to the overflow readout wire 480.

Instead of providing a ninth pulser to the left of the eight pulsers R2V-R2DD for producing the pulses required for lead 480, the present invention makes use of pulser R2DD for this purpose, a special control cam R2E being arranged to switch over the pulser R2DD from its normal function of delivering pulses to the readout wire 480 to its auxiliary function of delivering pulses to the overflow readout wire 480. It is for this reason that the pulser R2DD is not connected directly to readout wire 480 but is connected thereto through control cam R2E, during the rotation from position 18 $\frac{1}{2}$ to position 7 $\frac{1}{4}$ (corresponding to the coded legend 1/7) and is thereafter connected to readout wire 480 during rotation from position 7 $\frac{1}{2}$ /7 $\frac{1}{4}$. In addition to these two functions pulses R2DD also provides the pulses hereafter referred to as the "carryover" pulse and the "self-setting" pulse, these pulses being extended, respectively, to wires TK and EK via control cam R2D for a purpose hereafter described. The relationship of pulser R2DD to its regular associated control cams R2T and R2U, as well as to the special control cams R2E and R2D, are clearly shown in Fig. 20, in which the comparison between this lowest order cam set (i. e. R2DD, R2T, R2V) and the other regular cam sets, R2V, R2F, R2G (or R2W, R2H, R2I) can be clearly seen.

The lowest order cam sets of sequence switches R4 and R5 are also modified in the same manner as the lowest order cam set of sequence switch R2 above described. Thus, pulsers R4DD and R5DD, like pulser R2DD, in addition to generating regular readout pulses for the readout wire 480, also serve to generate the pulses for the overflow readout wire 480 as well as the carryover and self-setting pulses for leads TK and EK. The special cam relationships for accomplishing this are clearly shown in Figs. 20 and 21.

For insuring the correct sequence of operations in a multiplication operation a further sequence switch RM is provided see Figs. 5D(2), 5E(1). The cams RMB, RMC . . . RML are arranged to successively make connection with the 32 contacts of the eight storage sets NB8, NB7 . . . NB1, so that the 32 partial multipliers represented by these 32 contacts may be successively used for multiplying the multiplicand stored in storage sets NA1-Na8.

Another sequence switch RC Figs. 5D(2), 5E(1) is provided for combining the accumulations of the two accumulators. For this purpose RC translates those components of the solution registered in the V pulse accumulator means into unit pulses which may be transferred to and accumulated in the unit accumulator switches. Such translation need not ordinarily be effected after each addition or subtraction in the case of a summation problem or after each accumulation of a partial product in the case of a multiplication problem. Ordinarily, therefore, the re-coding or translating sequence switch RC is actuated only once at the end of a multiplication or summation problem in order to transfer the solution wholly to the unit accumulating switches before such solution is read out and sent back to the operator's subset to be printed.

Recapitulating, therefore, very briefly, the several sequence switches shown in drawing group 5 have the following functions:

RA: To additively or subtractively transfer a number from the A storage (principally used in summation problems but also used for reading out a multiplicand times multiplier of unity in multiplication problems).

RB: To additively or subtractively transfer a number from the B storage (principally used in summation problems).

R2, R4, R5: To transfer additively the double, 10 quadruple or quintuple multiples of the number (multiplicand) stored in the A storage.

RM: To regulate the successive steps of a multiplication computation (including the successive testing of the 32 contacts of the B storage group 15 representing the multiplier).

RC: To translate or re-code the solution component stored in the V pulse accumulating chains into unit pulses which can be accumulated on the unit accumulator switches.

20 GENERAL DESCRIPTION OF THE MAIN AND AUXILIARY ACCUMULATOR CIRCUITS

As previously pointed out the accumulator structure of this machine consists of two different accumulators, a main accumulator for accumulating pulses which represent units, and an auxiliary accumulator for accumulating pulses each of which represents the value 5 (referred to as V pulses throughout the description). The 25 main accumulator serves as the final result accumulator, the accumulations in the auxiliary or V pulse accumulator being transferred to the units accumulator in the course of the computation and/or at the end thereof.

The main accumulator principally comprises sixteen stepping switches SM1, SM2 . . . SM16, Figs. 7A(1)-7B(2) which are of the 11-point type previously described. The V pulse accumulator comprises sixteen abbreviated counting chains of three relays such as F₁, F₂, F₃ each such chain being associated with a corresponding stepping switch of the result accumulator for the purpose of receiving and accumulating the V pulses. Each such counting chain is arranged to have its 40 F₁ and F₂ relays energized in response to the receipt of a single V pulse and then if a further V pulse is received the counting chain is arranged to deliver a single unit pulse to the unit accumulator switch of next higher denomination and then re-set itself to normal. Thus every two V 45 pulses produce one step of the next higher unit switch. Functionally, therefore, each counting chain F₁, F₂, F₃ is equivalent to a small accumulator switch having only two contacts and two 50 steps in its complete cycle, so that one step takes it off normal and the next one brings it back home.

Each stepping switch of the main accumulator 55 comprises five brush and contact-arc assemblies such as smal, smbl Fig. 7A(1), smcl, smfl, Fig. 7C(1). The brush arms are all mounted on a common shaft as illustrated in Figs. 7A(1) and 7C(1), the corresponding shafts being unillustrated in all other orders of the accumulator. The function of arcs such as smal is to clear the stepping switch (i. e., bring it to the first or "0" position) at the end of a computation. The function of arcs such as smbl is to control carryovers into higher orders. The function of arcs such as smcl is to check the positions of the switches of calculator I against the positions of the corresponding switches of calculation II. As 60 illustrated in Fig. 7C(1) the contact arc smfl is wired to a similar arc smf'. This latter arc smf' forms part of a second result accumulator 65 70

which is controlled by duplicate calculator equipment as already mentioned and hereinafter referred to. The arcs such as *smcl* Fig. 7C(1) are used for reading out the result of the computation to a printer at an operator's set. The corresponding arcs of the second calculating machine (e. g., *smcl'*) are utilized to terminate printing of the solution.

In addition to the switches SM the result accumulator is also provided with sixteen carry-over marking relays T₁/1-T₁/16 which are arranged to be energized primarily by the passage of the corresponding unit accumulator switches through their positions X.

In addition to the primary energization path through the X contact of the associated SM switch each carryover marking relay T₁ is also connected to be energized through the ninth contact of its associated switch provided the carryover relay of the next stage to the right is just being energized or is already in the operated state.

The purpose of this auxiliary energization path for each carryover marking relay is to take care of a situation where a carryover condition is produced at the right of a nine or of a plurality of nines. In such case it is well known that the carryover must effect not only the switch immediately to the left of the stage causing the carry-over but also as many other stages as are in the nines condition and finally one more switch to the left of the left hand nine. The auxiliary circuits for the T₁ relays accurately give such result.

Assume for example that during a certain readout cycle switch SM9, starting from position 7, takes five steps as follows: 8, 9, X, 0, 1, and assume that during the same readout cycle switch SM8 is driven from position 7 to position 9 and switch SM7 from position 6 to position 8; then relay T₁/8 would be energized due to the passage of SM9 through position X while relay T₁/8 would be energized due to the stoppage of switch SM8 in position 9 together with the energized condition of relay T₁/9. The function of relays T₁/8 and T₁/9 is two-fold: first, each of these relays controls the transmission of a special pulse hereafter called the "carryover" pulse to advance the SM switch of the next higher stage; and second, each relay controls the transmission of another special pulse hereafter referred to as the "self-setting" pulse to advance its own SM switch. Thus in the case above assumed, relays T₁/8 and T₁/9 would first cause switches SM7 and SM8 each to be given one step from positions 8 and 9, respectively, to positions 9 and X, respectively, and thereafter would cause switches SM8 and SM9 to take one step, thus moving respectively from positions X and 1 to positions 0 and 2.

The reason why a self-setting step is required is that the step-by-step switches take eleven steps per cycle. Such arrangement permits the use of standard "11-point" switches and also permits the elimination of one auxiliary relay per switch.

Other relays constituting part of the accumulator circuit will be considered in connection with the detailed description of a typical computation.

GENERAL DESCRIPTION OF DISTRIBUTOR OR COLUMN SHIFT CIRCUITS

The distributor circuit is principally illustrated in drawing group 6. Such distributor circuit

serves to connect the lead wires 488-488 from sequence switches RA RB R2 R4 R5 RR to nine successive ones of the sixteen "solution feed wires" SFW1, SFW2 . . . SFW16 Fig. 6D(1).

5 6F(2) which lead to the accumulators. As will be pointed out in connection with a specific numerical example the number of digits of any number sent from an operator's set are counted by relay counting chain G22 i. e., La, Lb, Lc Dr1, Cr1, Dr2 . . . Cr4, C1, Figs. 6A(1)-6B(1). This counting chain in turn controls relays Tc1-Tc7 (Figs. 6B(2)-6C(2)). The latter relays Tc1-Tc7 are included in the distributor so as to close only the required ones of the seven channels from leads 482-488 to the appropriate SFW wires. Thus the last seven read-out wires 482-488 extend through enabling chain Tc1-Tc7 which connects up only so many of these seven readout wires as correspond to the digits actually received and counted. Since at least the wire 481 will be needed even if only a single-digit number is involved in the computation, this wire 481 as well as the overflow wire 488 is connected directly through without going through any Tc relay.

10 In addition to connecting-up only the desired ones of the readout wires 482-488 the Tc relays also provide a variable connection from a further lead -481 to that one of the wires 481-488 which corresponds to the last significant digit in the computation. This connection serves for fugitive-one entry as hereinafter more fully described. Thus, if only three digits are received and counted only relays Tc1 and Tc2 will be operated since the first counting chain relay does not operate any of the Tc relays and only readout wires 488, 481, 482 and 483 will be connected-up the other remaining open. Also, by virtue of the fact that the Tc2 relay would then be the last one operated the lead -481 would be connected to the wire 483, i. e. to the last wire in use.

15 Beyond the enabling chain Tc1-Tc7 and the rotary shifting arrangement RDJ-RDDD, the connections from W6, W7-W8 extend the contacts of a selected pair of relays S₁. Nine such pairs of S₁ relays S₁/1-S₁/16 (Figs. 6D(1)-6F(2)) are provided, each pair being capable of connecting the nine wires W6-W8 to nine successive ones of the sixteen feed wires SFW1-SFW16.

20 For most purposes the solution feed wires SFW1-SFW16 should extend directly through to the sixteen accumulator switches of the result accumulator. Such connection is normally made by energization of relay Mc and its helping relays Mr1, Mr2, Mr3, Mr4 (Figs. 6E(1) and 6E(2)). For the initial V pulse, however, the feed wires SFW1-SFW16 should be connected through to the V pulse accumulator rather than to the result accumulator, this being done by energization of relay Fc and its helping relays Nr1, Nr2, Nr3 and Nr4 (Figs. 6E(2)-6F(2)).

SUBSET AND ACCESS EQUIPMENTS AND SOLUTION CHECKING AND SENDING EQUIPMENT

25 The subset equipment is shown in drawing group 2 and has already been briefly described in the introductory description of the types of apparatus used in the invention. The mechanical details of the keyboard of the subset are not shown and it is thought the operation thereof will be understood readily from the schematic diagram which shows the circuits operated by the respective keys.

The access equipment which gives any one of seven subset equipments access to the calculating equipment of drawing groups 4, 5, 6, 7 and 8 is clearly shown in Figs. 3(1) and 3(2). This access equipment essentially comprises a sequence switch RL having a pair of cams associated with each of the wires 101, 102, 103, 104 . . . 113, and having these pairs of cams so cut as to connect each of said wires 101-113 to any set of seven corresponding sets of wires (e. g. wires 1-13 of subset 1, wires 1-13 of subset 2 . . . wires 1-13 of subset 7). Seven Co relays and seven St relays are also provided, one for each of the subsets, although for simplicity only one of each of these relays as well as only one set of line wires 1-17 are shown. In addition the access equipment also includes relays Rs, Cs, for controlling the proper operation of the switch RL, and further includes relays Tm and Bd and a stepping switch TTM which serve to gauge the activity of use of the calculator and to cause a breakdown of the connection and the transfer of the calculator to another subset whenever the subset associated with the calculator exhibits less than a predetermined rate of activity.

The circuits shown in drawing group 8 serve principally for checking the accuracy of a solution and transmitting such solution to the subset for printing as well as for determining the position of the decimal point, if any, in a solution. The principle of checking employed according to the present invention is based on the provision of two complete sets of computing circuits. Thus all the equipment shown in drawing groups 5, 6 and 7 should be understood to be duplicated, and accordingly it will be noted that all leads extending to these circuits from other circuits such as those shown in drawing groups 4 and 8 are provided in duplicate. The solution checking circuits shown in drawing group 8 and referred to above are arranged to establish checking circuits which extend serially through the result accumulator of computation equipment #I, and through the corresponding result accumulator of computation equipment #II, order by order in series. Then, after testing the continuity of such connection in order to ascertain the exact agreement of the two solution circuits the answer checking and sending equipment of drawing group 8 is adapted to cause the result to be read out and transmitted digit by digit to the subset. Such transmission is effected by relays Og, Tw, Fp, Fq, Of, Tp (Fig. 8A1).

DESCRIPTION OF A TYPICAL SUMMATION CALCULATION

In order to make the operation of the present invention more clear it will be convenient first to trace the operation of the machine in response to a representative problem in subtraction. The problem chosen for illustration is as follows:

$$760.15 - 26.05 = 734.1$$

It will be assumed that the subset over which such problem is transmitted to the calculator is subset I since this is the only subset shown in drawing group 2.

The time charts of Figs. 12A, 13A, 14A, 15A, 16A, 17A, 12B, 13B, 14B, 15B, 16B, 17B, 14C, 15C, 16C, 17C, 13D, 14D, 15D, 14E, 15E, 16E, 17E, 15F, 16F, 17F, represent in detail all the steps of the operation about to be traced. Fig. 18 shows the manner in which these time charts should be assembled to form a complete time chart of all operations involved in the computation above set 75

forth. Since such time charts do not represent the circuit paths involved in the various operations, a detailed verbal tracing of all circuits is desirable to supplement the showing of the time charts and circuit drawings. In view of the fact that a large number of such circuit paths require tracing and that the tracing of each one is comparatively long, the tracing of all circuits is set forth in a supplemental chapter at the end of the specification, all such circuit paths being identified by numbers between 1000 and 2000. In the following description of a typical summation calculation the circuit paths are referred to by these numbers so as to avoid interrupting continuity of description. In those cases where the reader requires assistance in tracing the circuit paths involved, the numerical reference will enable the pertinent circuit to be readily found in the supplemental chapter.

20 SEIZURE OF CALCULATOR EQUIPMENT BY SUBSET

NORMAL CASE WHERE EQUIPMENT IS IDLE

Referring to Figs. 2(1)-3(2) it will be seen that the operator at subset I closes start key KS prior to sending a problem. Key KS is of the locking type and stays locked until normally restored at the end of the calculation. This energizes a start relay Str via ground at key KS, wire 16, Str battery and ground. Common start relay Cs is energized from ground Cor back str 1 front, Cor, battery, ground.

Cs energizes sequence switch RLM over cs2, rs4 back thus causing sequence switch RL to start 35 rotating from whatever position it previously occupied. When this switch reaches position 1 it is stopped by the opening of the circuit for RLM at Rs4 back due to the operation of relay Rs which takes place as follows. When RLM reaches 40 position 1 the individual cut-off relay Cor operates in series with the common holding relay Rs via ground, Cor, str 2 front, RLDD in position 1, bd1 1 back, Rs. The operation of Cor opens the 45 Cs circuit (circuit 1002) from ground at Cor 1 back, thus releasing Cs. Cor at cor2 and cor3 front connects line wires 14 and 15 to leads 114 and 115 respectively, and also connects the individual service meter SM to contact arc ttmb of timing switch TTM which is rotated by means not shown. With RLM stopped in position 1 as 50 described, wires 3 to 11 are respectively connected via cams RLF to RLW of RLM which are not shown, to wire 103, to 111, Fig. 3(2). The operation of Rs also grounds lead 116 to start the calculator as hereafter described.

55 SPECIAL CASE WHERE EQUIPMENT IS ALREADY IN USE

The above description assumes that the equipment was all idle when the operator at subset I pressed the start key KS. If, however, another subset e. g. subset VII was already using the equipment, Rs would already be operated (in much the same manner as above traced) in series with the cutoff relay CorV of subset VII (circuit 1005). In such a case start key KS of subset I would still operate Str and Cs (circuits 1001 and 1002) but would not start sequence switch RL because the circuit for RLM would be open at rs4 (circuit 1003). In such a case the timing equipment TTM, Tm, Bd1 would come into use to ascertain whether line 1 was actively using the calculator.

Ordinarily there is battery on lead 117 from the calculator (circuit 1006). When Cs is operated by an attempted call from subset I, such battery

will operate T_m each time the t_{TMC} wiper of timer TTM passes its 11th contact (circuit 1007). If the battery on 117 remains uninterrupted T_m will hold via its own number 2 contact and $rs4$ front (circuit 1008). Upon the next rotation of TTM, $Bd1$ will operate when wiper t_{TMC} passes its 10th contact (circuit 1009). This will release Rs (circuit 1005) thus removing ground from 116 to clear the calculator in a manner which will appear hereafter and allowing RL to start rotation to connect to the new calling line (circuit 1003). This will only occur if battery remains on 117 during substantially a whole revolution of the TTM timing switch. Such battery is applied to lead 117 via $dr3$ back, $sr1$ back, $el5$ back (circuit 1006). As will be apparent from the description of calculator operation given hereafter, at least one of the relays Dr , Sr or El will be operated at frequent intervals if the calculator is in active use. Therefore the above described disconnection of subset VII in favour of subset I can only occur if subset VII is not actively using the calculator. The rate of rotation of TTM determines the interval during which the machine may remain under control of a subset without being in active use.

PREPARATION OF EQUIPMENT AND TRANSMISSION OF READY SIGNAL

When Rs operates as above described in response to a call from subset I, contacts $rs3$ apply ground to lead 116 to operate Gg drawing group 4 (circuit 1012) which in turn operates two relays Gn and Gn' (one being in drawing group 7 and the other not shown) and two relays Gr and Gr' (drawing group 5 and not shown respectively) (circuit 1013) as well as one relay Gh drawing group 4, and one relay Ag drawing group 8 (circuit 1014). These seven relays Gg , Gn , GN' , Gr , Gr' , Gh , Ag are the "general ground relays" which supply a large part of the operating grounds for the various circuits of the calculator equipment. Relays gn' and gr' belong to duplicate equipment not illustrated but corresponding to the equipment containing relays gn and gr . All seven of these relays remain continuously operated until the end of the calculation except in cases where an error is made or where a cancel key is actuated.

In response to the closure of contacts $gr2$, $gr4$, $gh3$, $gg2$, relays Cj , Aj in drawing group 6 and Ra , Rc , Ba , in drawing group 4 respectively operate (circuits 1015, 1016, 1017, 1093 respectively). Since Cj and Aj are in drawing group 6 it will, of course, be understood that similar relays Cj' and Aj' are operated in the duplicate equipment (not shown) over circuits corresponding to those traced for Cj and Aj . The operation of relay Ra energizes relay Sj via $ca2$ back (circuit 1020) and also relays $C49$, $C50$, $C99$, $C100$, circuits 1021, 1022. Relay Sj in turn, together with the operated condition of relays Bc , Ba cause the energization of relay $C33$ (circuit 1023). It may be useful to mention that of these eleven relays Cj , Aj , Ra , Sj , $C99$, $C100$, $C49$, $C50$, Bc , Ba and $C33$ all but the last named three remain energized until the end of the calculation except for brief moments of deenergization.

The operation of the general ground relay Gh has meanwhile energized magnet IRM via $gh1$ (circuit 1024), thus causing sequence switch IR to commence rotation. This sequence switch is also part of the "general" equipment which remains actuated throughout the computation.

The first function of this switch is to cause the transmission of three decimal points to the subset by actuating decimal point printing relay Po three times. Relays Sw and Sy control this action, Sw serving to prevent the action from starting in the middle of a cycle and relay Sy serving to indicate that the action has been completed. Although contact 4 of general ground relay Gh applies battery to relay Sw through a resistance (circuit 1025) the latter relay cannot operate so long as direct ground is applied to it from the upper right brush of cam IRB (circuit 1026). Thus the operation of Sw is delayed until the beginning of a new three-dot cycle, as clearly shown in Fig. 12A. When relay Sw operates, contact $sw3$ connects the upper left brush of sequence switch cam IRB (hereafter written

$IRB+$)

20 to Po to energize the latter between positions $3\frac{1}{2}$ and $4\frac{3}{4}$, as clearly shown in Fig. 12A (circuit 1027). Contacts 2, 3, 4, and 5 of Po energize relays Og , Tw , Fp , Fq in drawing group 8 (circuits 1028-1031) and these relays in turn apply energy over lines 112, 111, 110, 109 and 12, 11, 10, 9 to operate selector magnets $CM1$, $CM2$, $CM3$, $CM4$ in the printer unit at the subset (circuits 1032-1035). When these selector magnets $CM1$ - $CM4$ have finally completely operated, their associated contacts apply ground back over line 15, 115 and through $Po6$ (circuit 1036) to operate sign printing relay Ps whose contacts $ps2$ thereupon apply battery to 113, 13 for operating printer magnet PM (circuit 1037).

This process is repeated three times under control of the three pulses generated by

$IRB+$

40 in positions $3\frac{1}{2}$ to $4\frac{3}{4}$, positions $5\frac{3}{4}$ to 7 and positions 8 to $9\frac{3}{4}$ (denoted by the legend "3 $\frac{3}{4}$ -4 $\frac{1}{4}$ -6/6 $\frac{3}{4}$ -8 $\frac{3}{4}$ /9"). These three dots constitute a "ready" signal. After all three dots have been thus printed

45 $IRB+$

energizes Sy (circuit 1038) which locks (circuit 1039) and at $Sy3$ breaks the circuit just used for operating Po (circuit 1027). Hereafter relays Sw and Sy both remain continuously operated until the end of the computation (circuits 1025 and 1039).

FIRST NUMBER

FIRST DIGIT

The operator now proceeds to send the first number 760.15. Upon depression of key 1 relays $A2$, $A4$ operate in series with digit relay Dr via $gg3$ front (circuits 1042, 1044). Contacts $a22$, $a42$ operate relays $C2$ and $C4$ (circuits 1045, 1046) to store the digit 7 in "1, 2, 4, 5" code. (Since relays $C1$ - $C4$ represent the values "1," "2," "4," and "5" respectively the operation of $C2$ and $C4$ signifies 2+5, that is 7.) Meanwhile the Dr relay causes actuation of five different digit counting chains and two digit counting switches.

More particularly, $dr2$ operates $F1$ of the counting chain in area $G6$ (i. e. counting chain $F1$, $S1$, $T1$ $D1$ - $F4$) (circuit 1047) and $dr1$ applies ground over lead 816 to operate Jda and Jsp in areas $G32$, $G31$ in drawing group 8 (circuit 1048). Contacts $jda2$ and $jda3$ energize the La and La' relays (circuit 1049) and these La relays in turn energize the $Dr1$ relays of the two La , Lb , Lc ,

D_{r1}-C_{r4} counting chains in the two calculator units (circuit 1050) (one such L_a-C_{r4} chain is shown in area G22 of drawing group 6 and the other is assumed to be in the duplicate equipment not illustrated). Meanwhile contact J_{da1} actuates digit counting switch BDM (circuit 1051). Note that this switch BDM and both counting chains L_a-C_{r4} are arranged to count all the digits, at least of the first number. At the same time contacts J_{sp1}, J_{sp2} operate the V_a and V_{a'} relays (one in area G23 and one not shown) (circuit 1052) and these relays in turn energize the B_{r1} and B_{r1'} relays of the two counting chains V_a-V_{r4} and V_{a'}-V_{r4'} (only one of which is shown in area G23 of drawing group 6) (circuit 1053) while J_{sp3} operates digit counting switch PDM (circuit 1054). Note that this switch PDM and both counting chains V_a-V_{r4} and V_{a'}-V_{r4'} are arranged to count only the non-decimal digits, as hereafter explained.

The release of key 7 releases the A₂, A₄ and D_r relays (circuits 1042 and 1044) and the release of the latter causes the two digit counting switches and the five counting chains to complete their counting operation. More specifically the opening of d_{r1} releases J_{da} and J_{sp} (circuits 1048) thus causing switches BDM and PDM to become deenergized and so advance their wipers (circuits 1051 and 1054) and also causing the L_b and V_b relays of the counting chains in areas G22, G23 of drawing group 6 to operate in series with the previously actuated relays L_a, V_a, (circuits 1055, 1056). Meanwhile the opening of d_{r2} causes relay S₄ of the counting chain in area G8 of drawing group 4 to operate in series with F₁ (circuit 1057). Contact S₂ operates D₁ (circuit 1058).

The operation of D₁ energizes C₃₄, C₃₅ (circuit 1059) in place of C₃₃ (circuit 1023) thus routing the next received digit to NA2 while also preparing the printing of the digit stored in NA1. Simultaneously contact d₁₁ operates relay T_d of the disagreement pair T_d, T_h (circuit 1060). The resulting disagreement between the contacts t_{d1} and t_{d2} energizes digit preparing relay D_p (circuit 1061) which makes contacts c₂₁ and c₄₁ effective to operate T_w and F_q (circuits 1062, 1063). These in turn cause the energization of selector magnets CM2 and CM4 (circuits 1033, 1036). When these selector magnets finally operate, the ground applied by their contacts to lead 15 passes through d_{p1} to operate P_d (circuit 1064). Thereupon p_{d1} energizes PM (circuit 1065) which now starts to operate for printing digit 7 at the subset. While PM is operating p_{d2} prepares to terminate the printing condition by operating T_h (circuit 1066) so as to bring the T_d, T_h pair into agreement. This agreement causes the release of D_p (circuit 1061) which in turn releases T_w, F_q (circuits 1062, 1063) thus terminating the energization of selector magnets CM2, CM4 (circuits 1032, 1035). P_d remains energized over p_{d2} and the back contact of the PM magnet (circuit 1067) until the latter magnet finally becomes fully operated and releases P_d.

SECOND DIGIT

For the second digit the operator depresses key 8 and this digit is received stored and printed essentially like the first digit, except that receiving magnets A₁ and A₄ take the place of A₂ and A₄, and similarly, O_g, F_q and CM1, CM4 replace T_w and F_q and CM2, CM4, respectively. Relays C₅ and C₈ of storage set NA2 operate to store

this digit in "1245" code, the relay C₅ representing the value "1" and relay C₈ representing the value "5."

In response to receipt of this second digit all the counting means advance one step further, so that relays F₁, C_{r1} and V_{r1}, are operated in response to receipt of this second digit, whereas switches PDM and BDM are advanced to position 2. It should also be noticed that the disagreement between T_d and T_h, which is used to cause the printing of this second digit, is produced by releasing T_d upon the operation of F₁, and that this disagreement is ended by releasing T_h on the operation of P_d.

THIRD DIGIT (ZERO DIAUR)

For the third digit the operator presses the 0 key. This digit is received essentially like the other two except that the receiving relay O_g instead of a combination of relays A₁-A₄ is operated in series with the digit relay D_r (circuit 1068). Contact o_{g3} operates O_h (circuit 1069) whose contact o_{h1} grounds d_{p2} (circuit 1070). This is necessary to insure the operation of P_d because the ground ordinarily arriving over lead 118 and through d_{p1} (compare previously traced circuit 1064) is absent in the case of a 0 digit.

The 0 digit is counted like any other digit, so that in response to the receipt thereof all the counting arrangements take a third step. Thus relays D₂, D_{r2}, B_{r2}, in areas G6, G22, G23, are actuated and switches BDM and PDM are shifted to positions 3. None of the relays C₉-C₁₂ of NA3 are operated to store this digit (since zero is represented by no operated relays).

It should be noted that the circuit through O_g for receiving a 0 digit passes through d_{d1} (circuit 1068). D_d is arranged to be energized only on response to a non-zero digit or a decimal point (circuit 1071). Therefore, it is clear that a zero digit cannot be received unless preceded by a non-zero digit or a decimal point.

DECIMAL POINT

The operator now presses the decimal point key, thus causing the operation of relays B₂ and B₃ in series with the sign relay S_r (circuits 1073, 1074). B₂ and B₃ operate S_s, S_p and S_h (circuits 1076, 1077). These relays S_s, S_p, S_h, lock (circuits 1079, 1080). Upon the release of the key, B_d, B₃ and S_r release. The closure of back contact s_{r2} closes the circuit for decimal point sign printing relay P_o (circuit 1081). The latter causes the decimal point to be printed in much the same manner as when it was operated from cam IRB on the first seizure of the calculating apparatus. This time, however, the release of P_o is produced as a result of the printing operation as follows: When sign printing relay P_s operates in the course of the printing operations, its contact p_{s4} actuates D_b (circuit 1082) which unlocks S_s, S_p, S_h, (circuits 1079, 1080) thus in turn causing the release of P_o (circuit 1081).

It should also be noted that the operation of P_o applies ground through p_{o1} to J_{pr} (drawing group 8), (circuit 1083) which locks (circuit 1084) to mark the fact that a decimal point has been received.

FOURTH DIGIT (FOLLOWING DECIMAL POINT)

For the fourth digit the operator presses the key 1 and the digit 1 is received, stored in storage set NA4, counted, and sent back to the printer mechanism of the sub-set in generally the same manner as the digits previously transmitted. It

will be noted, however, that because of the operated condition of relay J_{Pr} , relay J_{Sp} no longer operates together with relay J_{Dc} (circuit 1048) so that counting chains V_a-V_{r4} and switch PDM do not respond. Thus, the fourth digit is counted only by the main distributor counting chain F_4-F_4 and by counting chains L_a-C_{r4} , as well as by switch BDM.

FIFTH DIGIT

For the fifth digit the operator presses the fifth key, thus completing the number 760.15. This digit is stored, counted and printed like the preceding one. Thus, at the end of this fifth digit, counting chain F_4-F_4 has relays F_4 , S_4 , D_4 , F_4 , D_2 , F_2 and D_3 operated to represent a count of five, while each counting chain L_a-C_{r4} , has relays S_a , L_b , D_{r1} , C_{r1} , D_{r2} , C_{r2} , D_{r3} , also operated to represent a count of five, and switch BDM is in position 5. Each of the counting chains V_a-V_r , however, has only relays V_a , V_b , B_{r1} , V_{r1} , B_{r2} , operated to represent a count of three, while switch PDM is in position 3. The first five storage sets $N_{A1}-N_{A5}$ contain the digits 7, 6, 0, 1, 5, in regular "1, 2, 4, 5" code.

Thus a complete first number has been transmitted, stored and counted. It will be noted, however, that the calculating equipment has as yet received no indication that the number is complete.

FIRST OPERATION SIGN

The operator now presses the "minus" key (K_{-}) thus energizing relay B_2 in series with sign receiving relay S_r (circuit 1073). Of the de-coding relays only S_s operates (circuit 1076) and thus upon release of B_2 , S_r , a circuit is closed via s_{r2} to energize the subtraction sign printing relay S_u in series with an auxiliary relay D_o which characterizes the receipt of any operation sign (circuit 1085). In response to the actuation of relays S_u and D_o a very large number of functions are concurrently performed. It will, therefore, be most convenient to separate these into groups and discuss them separately.

PRINTING OF MINUS SIGN (-)

Relay S_u causes the minus (-) sign to be printed in a manner somewhat similar to the printing of the decimal sign previously discussed. Contacts s_{u2} , s_{u3} operate relays T_w , F_p (circuits 1086, 1087) to cause energization of CM_2 , CM_3 (circuits 1033, 1034) while contact d_{o1} extends the ground from the contacts of magnets CM_2 , CM_3 to operate P_s (circuit 1088). The operation of P_s then energizes PM (circuit 1037) and also operates D_b to release the de-coding relay S_s (circuit 1078) which in turn releases S_u and D_o (circuit 1085).

COUNTING OF OPERATION SIGN

Since operations signs (e. g. +, -, $\times$) are the only signals used to separate two numbers according to the present invention, the equipment is arranged, in accordance with a feature of the invention, to count such signs in order to facilitate transferring the successive numbers alternately to two different storage groups, as well as to aid in other necessary control operations. Since the minus (-) sign now under consideration is an operation sign, the relay D_o responds together with the relay S_u (circuit 1085) as already mentioned. Contact d_{o2} operates F_o (circuit 1089) which, upon the release of D_o , locks up in series with the left winding of S_o (circuit 1088). If another operation sign were subse-

quently received after the second number, the operation of D_o in response thereto would energize T_o and the right winding of S_o via s_{o2} for (circuit 1091) thus breaking the above mentioned locking circuit of F_o and S_o at t_{o1} back (circuit 1088). F_o would release but S_o would be held by its right winding. Then at the end of such second operation sign, the release of D_o would release S_o and T_o leaving counting mechanism F_o , S_o , T_o in normal condition. Contact s_{o2} determines whether relay B_c , B_g shall be energized (circuit 1092) for rendering the "A" storage groups effective or whether, on the contrary, relays A_c , A_g shall be energized (circuit 1093) to render the "B" storage sets effective.

STORAGE OF MINUS SIGN

The relay S_u is only temporarily actuated in response to receipt of a minus sign to control the printing operation. To store or register the general nature of the computation to be performed as indicated by the received sign the relays A_i , A_{it} , are operated (circuit 1084) and locked (circuit 1085). Relays A_i , A_{it} indicate merely that the problem is to involve "summation" i. e. either addition or subtraction. These relays A_i , A_{it} operate and "permanently" lock in response to either a plus or a minus sign, the word "permanently" here being used to mean "for the duration of a complete computation". In addition to A_i , A_{it} which generally and "permanently" indicate summation, some polarity registering relay should be semi-permanently operated to store the negative quality of the minus sign, at least until after the second number has been completely received. This polarity storage is necessary since the minus sign which is received between the first and second numbers is mathematically intended to apply only to the second number to indicate that this second number must be subtracted rather than added.

To effect such semi-permanent polarity storage two negative storage relays A_n and B_n are provided. Relay A_n stores the minus polarity for the number in the "A" storage group and relay B_n stores such polarity for the number in the "B" storage group. Thus, if B_n is actuated it indicates the number in the "B" storage group is to be transferred negatively (i. e. as a ten's complement) when such number is received and is ready to be transferred. No relays are required to register positive polarity since the fact of nonoperation of A_n or B_n is an indication that the corresponding A or B number is to be transferred in positive manner.

The minus sign now under consideration which is assumed to have been transmitted immediately following the first or "A" number, is mathematically applicable to the "B" number subsequently to be received, and therefore, should be registered on the B_n relay. The operation of B_n is effected through s_{u2} and h_{p2} back (circuit 1088) when S_u operates upon receipt of the minus sign, as above described and B_r is then locked via r_{a2} (circuit 1087).

RESETTING OF RECEIVER EQUIPMENT BY OPERATION SIGN

When the D_o relay is operated in response to the receipt of an operation sign there is a small interval before the sign printing relay P_s becomes operated to print such sign. During this interval d_{o2} back releases R_a (circuit 1017) and in turn r_{a2} releases S_f (circuit 1028) thus restoring to normal the whole counting chain F_4-F_4 (of area

G6) as well as relays Fd, Dd, and the disagreement pair Td, Th. Thus, the receiving, storing and counting equipment is all ready to receive the second number except for counting chains La-Cr4 and Va-Vr4 (of areas G22, G23). These last two counting chains are re-set during the very beginning of the transfer of the "A" number described immediately hereafter.

INITIATION OF READOUT OPERATION

Since the minus sign under consideration is the first indication that the number stored in the "A" storage sets is complete, this sign is used to initiate the readout of such "A" number. It will be noted that the "A" number should be additively transferred regardless of whether the operation sign is a plus sign or is a minus sign, as assumed in the problem now under consideration. The reason for this is that there is a mathematically implied plus sign preceding the first number. The manner in which the readout is initiated by the operation sign is as follows:

Contact su5 extends ground through an1 and an2 back to leads 382 thus actuating relays Ad1, Ad1 and Ad2, Ad2' in each of the duplicate readout circuits (of which only one is shown in drawing group 5) (circuit 1088). Note that if An had been operated by a previous operation sign the ground would have extended over leads 383 to operate relays Su1, Su2 in each of these duplicate readout circuits (circuit 1089). At about the same time su1 operates As (circuit 1100). Since So is at this time released, so1 back, an1, an2 front apply ground to leads 384 to operate Sa and Sa' in the duplicate computing circuits (drawing group 5 and not shown respectively) (circuit 1101).

PREPARING REQUIRED READOUT ("PLUS" READOUT FROM "A" STORAGE)

As has already been described, relays Sa and Ad1, Ad2 (in area G20 of drawing group 5 and in the duplicate computing equipment not shown) are actuated briefly by the receiving equipment (drawing group 4) in response to the receipt of the minus sign following the first number 760.15. In response to such brief operation of Sa, Ad1, Ad2, the two computing portions of the equipment independently readout the stored number from the "A" storage group to their respective solution accumulators. For convenience the following description will be given as if only one computing equipment instead of two were provided. Referring first to area G20 of drawing group 5, Sa when operated locks itself (circuit 1102) and operates Sc via sa1 (circuit 1103) and also operates Fa1, Fa2 via sa3 (circuit 1104). The following substantially concurrent operations result:

Contact sc2 applies ground through a resistance to lead 428, to operate S/11, S/12 in area G25 of drawing group under control of the counting chain in area G23 (circuit 1105). These S/ relays immediately lock up in series with Od which is thereby operated (circuit 1106). The opening of back contact od1 causes the release of relay Aj (circuit 1016) which in turn restores counting chain Va-Vr4.

Simultaneously sc3 grounds lead 421 to operate Ty in area G24 of drawing group 6 (circuit 1017) for locking relays Tc1, Tc2, Tc3, Tc4 independent of counting chain La-Cr4. The opening of back contacts t11 causes the release of relay Cj (circuit 1015) which in turn restores counting chain La-Cr4.

Meanwhile ja31 operates Ip (circuit 1108).

Also, ja16 operates Ld (drawing group 7) (circuit 1109). Simultaneously, ja28 operates Fc in area G26 of drawing group 6 (circuit 1110) which in turn operates relays Nr1, Nr2, Nr3, Nr4, (circuits 1111, 1112) to prepare the readout wires for a V pulse.

Last, but not least, ja11 energizes RAM (circuit 1113) to start sequence switch RA.

It may be well at this stage to note that all the above concurrent operations resulted from energization of relay Sa which operated relays Sc, Fa1 and Fa2. If relay Sb had been energized instead of Sa essentially the same operations would have resulted except that relays Fb1 and Fb2 circuit 1114 would have replaced relays Fa1 and Fa2 and thus the sequence switch RB circuit 1115 rather than RA would have been started.

The factor which determined the operation of relay Sa rather than Sb in the specific example hereinabove traced was contact so1 in area G9 of drawing group 4 which was in deenergized condition at the time of operation of relay As. Since counting chain Fo, So, To counts operation signs which separate successive numbers contact so1 will be in actuated condition the next time As is operated at the end of the second number. If more than two numbers were transmitted in a problem (which is not the case in the particular problem chosen for illustration) so1 would be in unoperated position at the time Dc operates in response to a plus or minus sign immediately following the first number, then would be in operated position at the time Dc operates in response to a plus or minus sign immediately following the second number, then would be in unoperated position at the time Dc operates in response to a plus or minus or equals sign immediately following the third number, etc. Thus RA would be started to readout the first number, then RB to readout the third number, then RA to readout the third number, etc.

Consideration may also be given to relays Ad1 and Ad2 (drawing group 5) which were actuated as above described over lead 382 in response to the closure of su5. It should be noted that two factors determined the operation of relays Ad1 and Ad2 circuit 1098 rather than relays Su1 and Su2. These factors were (I) the position of contacts hp1 and hp4 which rendered the An relay contacts effective rather than the Bn relay contacts, and, (II) the position of contacts an2 and an3 themselves.

Operation sign counting chain Fo, So, To controls the position of Hp in such manner that Hp is released throughout the receipt of the first number and during the subsequent energization of a plus or minus printing relay (Ad or Su), then becomes energized upon the release of such sign printing relay and remains energized throughout the receipt of the second number and during the subsequent energization of a plus or minus printing relay (Ad or Su), then becomes deenergized upon the release of such sign printing relay and remains deenergized throughout the receipt of the third number, etc. The position of contacts hp1 and hp4 determines which of the minus sign storing relays An or Bn should be rendered effective to determine the polarity of the next readout. Thus, in response to the operation of a sign printing relay following the first number contacts hp4, being deenergized, will extend ground from su5 or ad3 to the contacts of An. In response to a similar energization of a sign printing relay following the second number, however, ground

through s_{u5} or $ad5$ will be extended via $hp1$ to the contacts of B_n .

The operated or released position of relay A_n should always be determined by the energization or non-energization of relay S_u at the time of the last received even numbered operation sign, i. e. at the time of the receipt of the second operation sign or fourth operation sign, etc. whichever was the latest. This is attained by virtue of the fact that A_n 's operating lead extends through $hp2$ front to s_{u6} circuit 1116. Similarly the operated or released position of relay B_n should always be determined by the energization or non-energization of relay S_u at the time of the last received odd numbered operation sign. This is attained by virtue of the fact that B_n 's operating lead extends through $hp2$ back to s_{u6} circuit 1096.

Applying the above general principles to the particular problem under consideration, it will be seen that the factors determining the operation of relays $Ad1$ and $Ad2$ in area G15 of drawing group 5 instead of $Su1$ and $Su2$ were (I) that hp caused A_n rather than B_n to be effective for polarity control since the transfer operation about to be effected involved an A number, e. g. the first number received; and, (II) that A_n was de-energized at the time since S_u had not theretofore been operated in connection with an even numbered operation sign.

READOUT OF "A" NUMBER TO ACCUMULATORS

Continuing now with the description of operation of the particular computation taken for illustration, the rotation of sequence switch RA serves to readout to accumulator sections 6, 7, 8, 9 and 10 the digits stored in storage sets $Na1-Na5$, and then to deliver "carryover" and "self-setting" pulses to the accumulator for the general purpose of facilitating carryover and related self-setting operations. In this particular stage of the computation these carryover and self-setting operations are unnecessary, but these operations are generally performed after every transfer to the accumulators. The selection of the particular accumulator stages 6 to 10 for receiving the readout is determined by column shift relay $S/11$ and $S/12$ in area G25 of drawing group 14. These particular relays were operated as above described under the control of counting chain V_a-V_r4 in G23 which counted only the pre-decimal digits of the number. The sixteen sections of the accumulator, drawing group 7, have a fixed decimal point arbitrarily assigned between sections 1-8 and sections 9-16, this assignment of a decimal point being physically embodied in the connection joining the ninth terminal of arc $1dmb$, drawing group 8, with the relay Pu . The exact manner in which such connection produces transmission of a decimal point between sections 1-8 and sections 9-16 will be more fully described hereafter. It may be noted, however, that the selection of sections 6-10 for receiving the five digits stored in the A storage sets provides just three digits to the left of the decimal point which properly corresponds to the three digits to the left of the decimal point in the received number 760.15.

The principle by which the digital values are read out from storage groups $Na1-Na5$ by rotation of sequence switch RA has been explained above under the subheading "Details of RA and

RB readouts"; and the detailed application of these principles to the specific number 760.15 can best be seen by inspection of both Fig. 14C and drawing group 5. The time chart of Fig. 14C shows especially clearly how the relays $Ar1-Ar5$ are energized during just such intervals as to render effective the desired ones of the five pulses generated by pulses RAV-RAZ. It should be noted that the operated condition of relay 10 $Ad1$ and $Ad2$ grounds the front contacts of these Ar relays so that the operated condition of any one of the Ar relays will render the pulses of the corresponding pulses effective and the de-energized condition of the Ar relays will render such pulses ineffective. If relays $Su1-Su2$ had been operated instead the reverse would be true so that only the pulses generated during de-energized intervals of the A_n relays would be effective.

20 The first of the five pulses generated by pulse RAV-RAZ will pass to the V pulse accumulator in area G27 rather than to main accumulator in area G28 since $Nr1$, $Nr2$, $Nr3$, $Nr4$ have been energized as previously set forth. Also it should be noted that the eight control paths over which the eight "5 code" contacts of the $Na1-8$ storage set control the actuation or non-actuation of the eight relays $Ar1-Ar8$ (for rendering this first or V pulse effective or ineffective on the corresponding ones of the eight readout wires 401-408) extend over the eight contacts $fa1$ 2, $fa1$ 3, $fa1$ 4, $fa1$ 5, $fa2$ 2, $fa2$ 3, $fa2$ 4, $fa2$ 5 instead of extending through brushes of the eight control cams RAE-RAL. The reason for using these contacts is that the control paths for the "1 code," "2 code" and "4 code" contacts occupy all brushes of these cams RAE-RAL (one brush for each code plus one brush for completing the connection to the corresponding Ar relay).

40 After the first or V pulse is finished, therefore the $Fa1$, $Fa2$ relays should be released, so that the "5 code" contacts will cease controlling the Ar relays, and also the routes should be altered to direct succeeding pulses to the main accumulator. This is performed as follows: Relays Q Eq , are operated by cam $RAC+$ and relay N is operated by cam $RAC+$ when sequence switch RA arrives at position $1\frac{1}{2}$ (circuits 1111, 1118). Contact $q1$ unlocks Sc whose transient energization from relay As (circuit 1101) has already ceased; and $sa1$, $sa3$ in turn permit the release of Sc (circuit 1103) and $Fa1$, $Fa2$ (circuit 1104) the latter being followed by the release of L and Fc (circuits 1108 and 1110). Fc in turn releases $Nr1$, $Nr2$, $Nr3$, $Nr4$ (circuits 1111, 1112). Meanwhile cam $RAC+$ operates Mc (circuit 1119) which in turn operates $Mr1-Mr4$ (circuits 1120, 1121). By the release of $Na1-4$ and the operation of $Mr1-4$ the route has now been changed over to the main accumulator, and by the release of $Fa1$, $Fa2$ the control of relays $Ar1-8$ has been taken away from the "5 code" contacts of $Na1-8$ so that the "1 code," "2 code" and "4 code" contacts of $Na1-8$ are now ready to assume said control via cams RAE-RAL. The release of $Fa1$ has incidentally opened the original circuit of L (circuit 1109) but this L relay has been prevented from releasing by a substitute circuit closed at position $1\frac{1}{4}$ through the lower right brush of cam RAC at about the time of release of relay $Fa1$ (circuit 1122).

50 The operation of relay Q just mentioned also holds $S/11$, $S/12$ (circuit 1123) shorts down relay Os (circuit 1124) to cause the reoperation of Af

ircuit 1016) and at O_1 front re-energizes C_f circuit 1128. Also at the same time that the upper brushes of RAC are operating Q , E_Q and N as just described, $RAB+$ applies ground to lead LM , thus operating relay L_f in Fig. 7B(2) circuit 1128.

The readout cycle then continues with suitable ones of the four unit pulses (which are generated by pulsers RAM'-RAT in area G14 of drawing group 5) being applied by the respective relays to the readout wires 481-488 (which pass beyond the bottom of drawing group 5 to drawing group 6) and thence through the T_c , T_f and M_f relays to denominational orders 6-18 of the main or "I pulse" accumulator in G28 of drawing group 7.

After the readout is completed the carryover and self-setting steps are produced. For producing the carryover and self-setting impulses, impulsive cam RAM' is connected to lead TK between positions 5 and 6 (written $5\frac{1}{4}/5\frac{3}{4}$) and to lead EK between positions 6 and $7\frac{1}{4}$ (written $\frac{1}{4}/7$) via the upper left and upper right brushes of RAD respectively. These connections extend through t_2 back but such contacts have no effect with respect to the circuits now being raced since the I_p relay is released by the release of Fa_1 , Fa_2 , substantially earlier than position 5.

These carryover and self-setting pulses pass over leads TK and EK to relays Ta_1 , Ta_2 , Tb_1 , Tb_2 , and relays Eh_1 , Eh_2 , Eh_3 , respectively (circuits 1127, 1128) thus operating the first the former and then the latter group of relays. The contacts of these relays in turn apply, first, a short pulse of ground to the No. 1 contacts of all T_f relays, and next a short pulse of ground to the No. 4 contacts of all T_f relays. If any T_f relay, say $T_f/8$ were operated, the first of these pulses would pass through t_8 to $SM7$, while the second or "self-setting" pulse would pass through t_8 to $SM8$. Thus, under control of these pulses first the carryover step and then the self-setting step would be performed for the accumulator switches requiring such steps.

In order to prevent the movement of the switches in response to carryover and/or self-setting steps from causing operation of further T_f relays, the "operating" ground supplied from L_f in Fig. 7B(2) to the tenth contacts of all smb arcs (or via a No. 2 contact of an operated T_f relay in any given order to the ninth contacts of the smb arc in the next higher order for causing operation of T_f relays is interrupted by releasing relay L_f under control of RAC+ prior to the completion of the carryover pulse (circuit 1122). Any of the relays $T_f/1-16$ which were already operated would be held over their No. 3 contacts from the separate holding grounds provided at t_1 and t_2 . Finally, after both the carryover and self-setting steps have been fully completed the L_f relay is also released under control of $RAB+$ (circuit 1128) causing all T_f relays to release.

The relative timing of the operations of the L_f and L_f relays with respect to the carryover and self-setting pulses is best shown in Figs. 14C and 14E. In Fig. 14C $RAC+$ and $RAB+$ are the cams which control the "operating ground" relay L_f and the "holding ground" relay L_f , respectively, while the last two closures of cam RAM' determine the timing of the carryover and self-setting pulses, respectively. The routing of these carryover and self-setting pulses to their 75 1083,

respectively separate leads TK and EK is effected by cams

$RAD+$

and

$RAD+$

respectively.

In Fig. 16E the actual movements of the "operating ground" relay L_f and of the "holding ground" relay L_f themselves can be seen and compared with the movements of the relay group Ta_1 , Ta_2 , Tb_1 , Tb_2 , which controls the carryover pulse, and relay group Eh_1 , Eh_2 , Eh_3 , which controls the self-setting pulse.

SECOND NUMBER

The operator may now transmit the second number. Actually such transmission of the second number will generally be commenced by the operator before the readout of the first number into the accumulators has been completed, as shown in the time charts of Figs. 14A, 14B, 14C, 14E. For convenience in description, however, it will be assumed that the second number is not transmitted until the apparatus has come to rest. Upon receipt of the various digits of the second number the receiving, counting, and storage equipment responds in essentially the same manner as above outlined for the first number with the exception that certain of the counting means do not respond to the digits.

Counting chain F_4-F_4 serves, as already stated, for controlling the input distributor relays $C83-C48$ or $C83-C98$. Therefore this counting chain must respond to every received digit of all numbers. The counting chain L_a-C_74 is used to control the channel closing chain of T_c relays in area G24 of drawing group 6 to determine which of the eight possible readout wires 401-408 shall actually be connected up. This counting chain L_a-C_74 therefore responds to every digit of all numbers. Counting chain V_a-V_r4 is used to select the required column shift relay pair such as $S/11$, $S/12$ for summation problems, i. e. addition or subtraction problems. In multiplication such counting of the digits by this counting chain is not necessary but nevertheless this counting chain is arranged to count the pre-decimal digits of all numbers regardless of the type of computation. Counting switches BDM, PDM are used only in multiplication. Therefore, the A_1 relay (drawing group 8), which with A_1 was operated and locked up to "permanently" register the receipt of a summation sign as earlier described, has its contacts a_11 , a_12 arranged to disable PDM and BDM (circuits 1051, 1054). Thus, in the particular example under consideration, neither of these switches follows the digits of the second number.

Aside from the fact that certain counting means no longer respond to the received digits, the receiving, storing and printing of the second number is essentially similar to the receiving, storing and printing of the first number. The four digits of the second number however are stored in the first four "B" storage sets NB_1-NB_4 rather than in the "A" storage sets. This is because A_c and A_e rather than B_c and B_e are now energized under the control of operation sign counting chain F_0 , S_0 , T_0 (cf. circuits 1082, 1083).

COMPLETION OF PROBLEM

RECEIPT OF EQUALS SIGN

The operator next pushes the equals key $\text{K} =$, and the equals sign is received and stored in substantially the same manner as the minus sign previously described, relays B_1 and B_3 being energized in series with S_7 (circuits 1072, 1074) instead of relays B_2 and B_4 (circuits 1073, 1074) and thus operating de-coding relays S_1 , S_2 , S_3 (circuits 1075, 1077) instead of S_5 , S_6 , S_8 (circuits 1078, 1077) so as to result in energization of "equals sending" relay E_g (circuit 1129) rather than "subtraction sending" relay S_u (circuit 1088). In view of the operated condition of A_1 and A_2 which indicate that a plus or minus sign has been previously received, auxiliary relay E_g operates in shunt with relay E_g via $a3$ (circuit 1130). Thus, the right hand contact of E_g performs the function previously performed by S_u , namely, operating relay A_3 (circuit 1131) while the left hand contact of E_g performs the function previously performed by S_u , namely, initiating the operation of A_1 , A_2 , or S_1 , S_2 under the joint control of h_2 and either a_2 , a_3 or b_2 , b_3 , this being effected in the following manner:

In the instant case since H_p is operated to cause B_n to take control and since B_n is also operated to indicate the need for negative read-out, relays S_1 and S_2 will be the ones operated (circuit 1132; contrast this with circuit 1088). Also, in the instant case the relay operated following the operation of A_3 is S_2 (circuit 1133) instead of S_1 (circuit 1101) since s_1 is in actuated condition.

In addition to the two contacts of E_g which perform some of the same functions as an addition or subtraction sign as just explained contacts 2, 3, 4 and 8 of E_g also perform functions similar to those previously described the only difference being that contacts e_2 , e_3 , e_4 , operate relays T_2 , F_p , F_q (circuits 1134-1136) (instead of merely F_p and F_q). Thus, three selector magnets CM_1 , CM_3 , CM_4 are energized (circuits 1032-1035) to select the character. The contact e_8 being directly in parallel with contact d_1 front performs the same function previously performed by d_1 , namely, establishing the circuit over which the contacts of the selector magnets can operate sign printing relay P_s (cf. circuit 1088). It should be noted that relay D_0 is not operated in series with relay E_g (contrast circuit 1129 with 1088) and therefore counting chain P_0 , S_0 , T_0 in area G_0 is not advanced. This is because the equals sign is not an operation sign, being in this respect more like the decimal point sign than like the minus sign.

The most significant departure from the course of operations previously described (in connection with the response to the minus sign) occurs as a result of the closure of the contact e_1 . Contact e_1 operates E_1 (circuit 1137) which locks (circuit 1137 1/2) and, via e_1 front, operates the "no more" relay N_m to prevent the reception of any further digits (circuit 1138) and which via e_3 and e_4 applies ground to the right hand holding contacts of relays E_g and E_g' of the two duplicate computing equipments (only one being shown in drawing group 5) (circuit 1139).

READOUT OF SECOND NUMBER—
(SUBTRACTIVE READOUT)

As a result of the operation of S_2 and S_1 , S_2 which operations were caused by e_1 , as

above described, the number stored in the B storage sets is now read out with the aid of sequence switch R_B in a manner exactly similar to that previously described for the reading out of the first number in the A storage sets, except that the nine's complement of each digit rather than the digit itself is read out because of the grounding of the back contacts of A_1 - A_2 by relays S_1 , S_2 Fig. 5C (2). Since only two pre-decimal digits were counted by counting chain V_a - V_4 the column shift relay pair energized will be S_1 , S_2 , (circuit 1105) and therefore the four digits of the number which are read out over readout wires 481-484 will be routed to accumulator sets 7-10, as most clearly shown in Fig. 15E.

At the same time nine pulses are delivered to each of the accumulator stages of higher order than the one currently associated with readout wire 481. This latter function is performed as follows: Contact s_2 supplies battery to the seventh wire of the SO multiple whence it passes through relays X_{h1} , X_{h2} . . . X_{h6} in series to ground (circuit 1140). These six X_h relays therefore operate and their No. 8 contacts apply the pulses from cams RAM', RAN, RAO, RAF, RAQ, RAR, to wires 1-4 of the M/2 multiple whence they pass through contacts of the M_r relays to unit accumulator switches 1-8. These pulses are transmitted simultaneously with the transmission of the four unit pulses (or selected ones thereof) to switches SM_1 - SM_{10} . Thus these impulses are arranged to begin after the transmission of the V pulses has been completed.

It is interesting to note that in the problem chosen for illustration the V pulse delivered to the V counting chain F_{s1} , F_{f1} , F_{p1} finds this counting chain already conditioned by a previous V pulse therefore restores this counting chain to normal and causes one step to be given to switch SM_6 just before the time that the nine impulses above mentioned are delivered to such switch.

It should also be noted that an additional pulse (serving to supply the fugitive one value) is transmitted over the last readout wire in active use to the unit accumulating switch SM_{10} immediately after the transmission of the four unit pulses has been completed. This extra impulse serves to convert the nine's complement produced by the readout device to the true ten's complement of the number stored in the B storage sets. This extra impulse is extended by special impulsive cam RAU and passes over lead -401 and through back contacts of the T_c relays to the last readout wire in active use, over which it passes to SM_{10} (circuit 1141).

CARRYOVER AND SELF-SETTING OPERATIONS

As a result of the readout of the second number superimposed upon the first one, unit accumulator switch SM_6 passes beyond position X to position 1 while all the preceding switches SM_1 - SM_5 come to rest in position 9. See the time chart especially Fig. 15E. Relay $T/8$ (not shown) is energized through contact X of smb_6 (circuit 1142) while relays $T/1$ - $T/8$ are energized through contacts 8 of smb_1 - smb_5 (circuit 1143). In response to the carryover pulses delivered by relays T_{a1} , T_{a2} , T_{b1} , T_{b2} , switches SM_1 - SM_6 step to position X. Next, in response to the self-setting pulse delivered by relays Eh_1 , Eh_2 , Eh_3 , switches SM_1 - SM_6 step from position X to position 0 while switch SM_6 steps from position 1 to position 2.

It should be noted that if the auxiliary pulse

over lead -481 should happen to shift its accumulator switch to position X, there is a possibility that this switch might be so shifted too late to operate its T_f relay (i.e. the switch might shift at practically the same instant that the "operating ground" relay L_t became released). In such case, however, the switch would remain in position X and at the next cycle the necessary carryover would be performed.

TRANSLATION OR RECODING OF SOLUTION

At the end of the readout cycle the operating

two pulses act as in the previously traced cases and produce any necessary carryovers and self-setting actions.

In order to facilitate a clear understanding of the exact manner in which the above computation $760.15 - 26.05 = 734.1$ was performed by two readouts and one translation (or recoding readout) together with three carryover operations and three self setting operations, a condensed synopsis of the essential steps and the condition of the accumulator equipments after each such step may be set forth in tabular form as follows:

Signal received from operator's control unit	General nature of arithmetic operation performed in response thereto	Analysis of operation into separate (successive or simultaneous) sub-operations	Condition of all switches and relays of accumulator circuit after each operation	
760.15	No operation		00000000.00000000	Accumulator switch (SM) V counting chain (F ₂ F ₁ F ₀) Carryover marking relay (T _f)

circuits of relays N, Q, Eq are broken as before (circuits 1118, 1117) but Eq holds over the holding ground on its right hand contact which was prepared by e13 and e14 as above traced (circuit 1138). Accordingly, "re-coding" sequence switch 60 RC is started via q3, eq1.

RCB+

(circuit 1144). As can be seen from the legends applied to the cams of this RC switch, or as 65 more clearly shown in Fig. 15E, cams RCF-RCU, of this switch in rotating from position 1 to position 7 generate five pulses which are transmitted via the No. 1 contacts of the F₂ relays of all off normal V pulse counting chains to step the corresponding switches of the main accumulator five steps. Thereafter a carryover pulse and a self-setting pulse are generated by impulsive cam RCV and are distributed to leads TK and EK by control cam RCR (circuits 1127, 1128). These 75

The above tabular synopsis relates only to the operations performed upon the accumulator and does not attempt to show the action of the receiving and storing circuits, nor indeed any other circuits which do not directly act upon the accumulator. Such tabular synopsis is especially useful to show how the self-setting pulses of the present invention compensate for the use of 11-point switches and obviate the undesirable practice of providing intermediate or "passing" contacts between two steps of a 10-stop switch or the alternative practice of providing an extra relay associated with each carryover marking relay.

CHECKING OF SOLUTION AND TRANSMISSION THEREOF TO SUBSET

The unit accumulator switches are now in a 75 position representing the complete answer to

the problem. To initiate the checking and sending out of this answer by the solution checking and sending circuits of drawing group 8, cam

RCD+

applies ground to lead 314 when the RC sequence switch finally comes to rest in position 7 (circuit 1147). This ground upon the 314 lead of the first computing equipment operates Ec (drawing group 8). The similar ground from the 314 lead of the duplicate computing equipment (not shown) passes via ec3 front via checking arcs of the two accumulator circuits to operate Vs (circuit 1148).

Ground is now connected via ec4 front, (circuit 1148) to operate Ls. The IRE pulser (drawing group 8) of the sequence switch IR, (drawing group 4) now applies ground via ls1 front to operate switch LD under control of Ls, ldmb, multiple MLA (circuit 1150). This multiple MLA extends to the solution circuit (drawing group 7) and there has those wires grounded which correspond to accumulator switches in normal position. LD hunts over this multiple from wire 18 backwards the ground on the several wires of the MLA multiple serving to hold Ls during such hunting (circuit 1151); and therefore LD stops on the last ungrounded wire (wire 9 associated with SM8). Ls releases.

Relay Fu also operates via vs3 front (circuit 1152) and causes FDM to be stepped by cam IRF (circuit 1153). FD hunts over the MLA multiple from wire 1 forward the grounds on the several wires of this multiple serving to hold Fa during such hunting (circuit 1154) and stops on the first ungrounded wire (wire 6 associated with SM6). Fa releases.

Id was energized via id1, (circuit 1155) and locks (circuit 1156). When Fa releases and cam IRG is open, Ic energizes via id1 front, jd4 back (circuit 1157). Switch FD is standing on wire 6 corresponding to accumulator switch SM6; and ground via ic2, jdmc, multiple MLB, wiper smc6, wire 1 of multiple MLC (since SM6 is in position 7) is connected to the appropriate ones of the transmitting relays Og, Tw, Fp, Fq, Of, Tp. In consequence the proper combination of these relays (in this case only relay Tp) operates (circuit 1158) corresponding to the digit value 7 recorded on the said switch SM6; and the corresponding wires to the operator's printer selecting magnets (i. e. wires 882 and 884 to CM2, CM4) are grounded to select the corresponding digit 7 (circuits 1033, 1035).

Impulses are now sent under the control of cam IRG via is1, leads to printer magnet PM (circuit 1159) and via is2 front, pu2 back, to FDM (circuit 1160). The reasons for shifting from cam IRF to cam IRG at this time is to permit use of a fast cam, i. e. IRF for rapid hunting over the nonuseful zeros while permitting the use of a slow cam i. e. IRG for actually controlling the transmission of significant digits.

In consequence the digit recorded on the selecting magnets is printed and switch FD stepped onto wire 7. Another combination of transmitting relays (in this case relays Tw and Og) is now operated (circuit 1161; contrast this with circuit 1158) and another digit value 3 is selected by CM1 and CM2 (circuits 1032, 1033) and is printed by PM on the next impulse from Is (circuit 1160). Thus the digits 734 recorded on the accumulator switches SM6-SM8 are printed in turn.

After S8 comes the decimal point, since there 75

is to be at least one further digit. In position 9 of FD, ground via jdmb, operates Pv (circuit 1162). This is because of the wire connected arbitrarily to contact 9 of the jdmb arc to fix the decimal point between SM8 and SM9 for all summation problems, as heretofore mentioned in connection with the wiring from the Vd-B74 counting chains to the Sf relays. Ground via pu1, and pu4, energizes Og, Tw, Fp, Fq to send the decimal point signal to the operator's set (circuits 1163, 1164). One or more of these four relays (or one of the other relays Of, Tp) may already be energized over the MLC multiple from SM8. In the instant case Og is so energized preparatory to sending the digit 1. But the decimal-point sign blankets any other code, since it consists of ground on all four leads 881-884 (circuits 1032-1035). Contacts pu2 disconnect contacts is2 from FDM and connect them via pl1 to Pn.

In consequence of the operation of Pv on the next pulse from cam IRG, the decimal point is printed, FD is not stepped, but instead, Pn is energized (circuit 1165) and locked in series with Pl (circuit 1166). Contacts pl2, pl3, disconnect pu1, pu2 from the transmitting relays Og, Tw, Fp, Fq (circuits 1163, 1164) while contacts is2 are connected via pu2 front, pl1 front, pu2 back, to FDM (circuit 1167) to permit this switch to resume its advance. In consequence the digit "1" stored in SM8, is now transferred to transmitting relay Og and printed (circuit 1168). Further digits, if there were any, would be transferred and printed in the same manner.

After leaving the last non-zero accumulator (i. e. SM8) jdmb reaches wire 10 of the multiple on which jdmc is standing. In consequence ground is connected via lead 218 to operate relay R4 (circuit 1169) which releases the general ground relays Gg, Gh, Gr, Gn and Ag. All relays except R4 in the receiving-and-storing circuit of drawing group 4 and most of the relays of other circuits release (except the Om relays of the solution accumulators and a few other relays hereafter mentioned). RLM is held by relay R4 to keep sequence switch RL rotating (circuit 1170).

Relay R4 is provided with locking circuit from

RCD+

(circuit 1170) and with a further locking path (circuit 1172) which is connected to each of the following: relay Ls (used for homing LDM) (circuit 1173) relay Fu (used for homing FDM) (circuit 1174) relay Pv (used for homing PDM) (circuit 1175) relay Bh (used for homing BDM) (circuit 1176) as well as a locking circuit from relay Ho which is operated whenever any of the solution switches are off-normal as more fully explained below (circuit 1177). Thus relay R4 is retained in operated condition until all switches have restored to normal. Ground via gr4 back.

RCB+

drives RC from position 7 to home position 1 (circuit 1178). During this rotation cams RCF . . . RCU produce ten impulses each upon the wires 1V, 2V, 3V . . . 10V.

The release of Gn operates Ho in series with the F's relays of any off-normal accumulator switches via (1) the No. 1 front contacts of any off-normal relays Om1-8 in parallel (circuit 1179) and/or (2) the a wipers of switches SM9-SM16 if off-normal SM switches operate and con-

let the impulses produced upon wires IV, 7 . . . 18V to the corresponding magnets (circuit 1181). When each accumulator switch aches home, its F₂ relay releases (circuits 1179, 58) and no more impulses reach the magnet, thus every off-normal accumulator switch SM homed from whatever position it occupied. During this process cam

RCD+

and also relay R₆ provide holding ground for relay R₄, as already indicated (circuits 1171, 1177).

The release of V₈ (drawing group 8) applies round via v₈ back and off-normal wiper fdma to operate L₈ (circuit 1182) so that impulsive am IRE homes LD (circuit 1183). Similarly, round via ag₁ back, fdma in any position beyond 8 operates F₂ (circuit 1184) which closes homing circuit for F_d from cam IRF. Similarly back contacts ag₁, 4 connect ground via spars pdma, bdma, to Ph, Bh, which home switches PDM, BDM by aid of cams IRH, IRI (circuits 1185, 1186). During this process relays s, F₂, Ph, Bh also supply holding ground for R₄, as already indicated (circuits 1172-1176).

Finally when all the switches are home, R₄ releases and IR stops (circuit 1170).

Contacts r₄2 back connect G_g via 118, 18 to be start key of the operators set which is still closed. Operation of G_g causes transmission of points to the operators set in exactly the same manner as when it was originally operated on seizure of the calculator. The broken away portion of the time charts Fig. 17A, 17B, 17C, 17E, 17F represents such transmission of 3 points.

On seeing the three points indicating that the complete result has been received and the equipment is ready to perform another calculation the operator may send another problem which will be dealt with as required. It will be assumed, however, that he releases his start key KS. The release of key KS releases S₁ followed by Contact R₅. Contact r₅ releases G_g which releases R_r, G_n, G_h and A_g. The equipment then all releases in substantially the same way as when G_g was released by operation of R₄ (except that now no switches require homing and also there is now no ground on lead 118 to reoperate relay G_g).

DRAFT 0

It has been explained above that the dd1 contacts of relay D_d prevent the zero digit from being received except after a decimal point or a non-zero digit. The attempted transmission of zeros under other circumstances is of no effect.

With respect to the transmission of valid initial zeros, i. e. zeros preceded by a decimal point but not preceded by any non-zero digits, it should be noted that these valid initial zeros are generally treated just like ordinary digits and are stored (by leaving all relays of the appropriate storage group unoperated) and counted just like ordinary digits.

MULTIPLICATION

The operation of the system for performing a multiplication problem begins in just the same way as for a summation problem. It will be convenient therefore, to assume as illustrative of multiplication, a problem whose multiplicand is the same as the first number assumed to be transmitted in the summation problem: 760.15. Accordingly, the problem "760.15 $\times$ 26=" has been

chosen for illustrating the operation of the equipment in multiplication.

In response to the operation of start key KS at the operator's station, the access equipment of Fig. 3(1), Fig. 3(2) connects this operator's station to the calculator as before and applies ground over lead 118. In response to this ground the calculator places itself in condition for operation and causes three dots to be printed at the operator's station for a ready signal just as before.

The first number is received as before and stored on NAI-8, Fig. 4B.

The multiplication signal on leads 6, 7 resulting from depressing key KY operates relays B₁, B₂, (circuits 1072, 1073) Fig. 4C(2), followed by S_f, S_s, (circuits 1075, 1076) which lock via d_{b2}, g_{g4} (circuits 1078, 1079). Relays D₀, M₂ in series now operate via s_f front, s_f front, (circuit 1181). Relays M₁ and M₂ operate (circuit 1188) and lock via m₁, d_{b3} (circuit 1189). Ground via e₁, m₁ and 6, is connected via leads 301 to the calculator circuits, to operate the relays M₁ Fig. 5D(1) and M₂ (not shown) (circuit 1190) (to indicate multiplication).

From this point onward the operations of the duplicate equipment will be disregarded and the description will, for convenience, be confined to the equipment shown in drawing groups 5, 6 and 7, it being understood, however, that similar actions occur in the duplicate computing equipment. Relay M_c locks via m₁, g_{r3} (circuit 1181). One significant difference between the operations in the instant case and those in the summation example is that no transfer of the A number is initiated at this time (cf. circuits 1098, 1101). Moreover, to prevent clearing the A storage set right after the second number, relays C₄₉, C₅₀ are locked by M₂ (circuit 1182).

In multiplication, the S_f relays of the distributor are not to be controlled by either number directly and therefore immediately the multiplication sign is received relays V_r, B_r of the distributor must be restored to normal, and prevented from responding to receipt of the "B" number. For this purpose A_j is released by removing the ground from 427 at m₁4 back (circuit 1016).

The second number is received on NB1-8, after which the equals sign is sent so that as before E_g operates (circuit 1129) followed by E₁ (circuit 1137) which locks to g_{h3} front (circuit 1137 1/2). Contacts e₃ and e₄ ground leads 213 to operate relay M_e via m₁ front (circuit 1183). Contacts m₃ front energize magnet RMM of sequence switch RM (circuit 1194). Ground via m₁ front operates A_{d1}, A_{d2} (circuit 1194 1/2). Further ground via m₄ front operates A_j (circuit 1185).

Sequence switch RM rotates and as it passes through positions 1 1/2 the test relay M_{t1} is connected to contacts nb₈ 1, i. e., contacts which represent the code element (1) in the lowest order storage set of the B number storage equipment e. g., multiplier storage equipment (circuit 1188). Since in the specific problem assumed the multiplier is a two digit number 26 and since such multiplier is stored in two highest order storage set NB1-NB8, the only relays which will be operated are those representing the codes 5 and 1 in the next to highest storage set NB2 (e. g., nb₂ 5 and nb₂ 1) and the one representing code 2 in the highest order set (i. e., nb₁ 2). M_{t1} will therefore not operate when contacts nb₈ 1 are tested (circuit 1186) and therefore sequence switch RA will continue to rotate. In intervals 2 1/3, 3 1/4 and 4 1/5 the test relay M_{t1} is con-

ected to contacts $nb8$ 2, $nb8$ 4 and $nb8$ 5, respectively (circuits 1197-1199), thus completing the sensing of the lowest order multiplier digit, which in the case assumed was 0.

Having checked the condition of $NB8$ RM moves to positions in which the contacts of $NB7$ are tested. Cam RMN in positions $5\frac{1}{4}/6$, before the contacts 1 of $NB7$ are tested, connects a passing ground to advance the counting chain $Va-Ar4$ in area G23 of drawing group 6. More specifically this passing ground is applied via wire 411, $vb1$ back, Fig. 6A, to operate Va (circuit 1200). Upon termination of this ground, Va locks in series with Vb (circuit 1201). Ground via $Va1$ energizes $Br1$ (circuit 1202).

The contacts 1, 2, 4, 5 of $NB7$ are tested by RM and $Mf1$ in the same way as $NB8$ was tested, the brushes lower left RMD, upper left RMD, upper right RMD, and lower right RMD making the successive four connections during intervals $6/6\frac{1}{2}$, $7\frac{1}{4}/7\frac{1}{2}$, $8\frac{1}{4}/8\frac{1}{2}$ and $9\frac{1}{2}/10$, respectively. After such testing of $NB7$ is completed a passing ground is again connected to advance the counting chain $Va-Vr4$ in area G23 in drawing group 6 one more step. More particularly the ground is applied via lead 411 to energize relay Vc in parallel with the left winding of Vb (circuit 1203). The operation of Vc immediately releases Va (circuit 1201). Then upon the termination of the passing ground, relay Vc and Vb release simultaneously. The release of Va just mentioned breaks the original operating circuit of $Br1$ (circuit 1202), thus causing this relay to lock up in series with $Vr1$, operating the latter (circuit 1204). Connection is then made in turn to the successive contacts of $NB6$ under control of the lower left, upper left, upper right, and lower right brushes of RME, respectively. A third passing ground pulse is now applied via lead 411 to advance the $Va-Vr4$ counting chain of area G23 into its third position. More specifically, the start of this ground impulse operates Va (circuit 1205) and the end of it operates Vb (circuit 1201) much as before (cf. circuit 1205 with 1200). This time, however, Va operates $Br2$ (circuit 1206) instead of $Br1$ (circuit 1202).

For the complete test of the thirty-two contacts of $NB8-1$, it is necessary to provide three sets of RM cams RMB-E, RMF-I, RMJ-L, which are connected up in turn during three successive revolutions of RM by relays $F7$, Or . At the end of the first revolution of RM, Frm operates via cam RMW in position $17\frac{3}{4}/18$ (circuit 1207) and locks via $me2$ front (circuit 1208). Now during the second revolution of RM the next higher storage set $NB8$ has its contacts tested by relay $Mf1$ under the control of brushes upper left RMG, upper right RMG, upper left RMF and upper right RMF respectively. Then a fourth counting pulse over lead 411 (circuit 1208) operates Vc to cause the release of Va (circuit 1201) whereby $Vr2$ becomes actuated in series with $Br2$ (circuit 1210). Then storage set $NB4$ is sensed under the control of the lower left, upper left, upper right, and lower right brushes of RMH respectively, this being followed by a fifth passing ground pulse which operates Va (circuit 1211), thus actuating $Br3$ (circuit 1212) and finally (at the end of the ground pulse) causing the operation of Vb (circuit 1201). The condition of the counting chain now may be called "position 5." During the last third of this second revolution of RM the storage set $NB8$ has its contacts sensed under the control of the lower left, upper left, upper right, and lower right brushes of RMJ,

respectively. Finally a sixth passing ground pulse is delivered over lead 411 to operate V (circuit 1213) thus releasing Va (circuit 1201) to thereby cause the actuation of $Vr3$ (circuit 1214). Then upon termination of the ground pulse Vb and Vc release leaving the counting chain in what may be called "position 6." At the end of the second revolution, Or operates via $fr1$ front, cam RMW in positions $16\frac{3}{4}/17$ (circuit 1215) and locks to $me2$ front (circuit 1216).

During the third revolution only two orders of the multiplier require to be sensed. During the first third of this third revolution contacts $nb2$ 1, $nb2$ 2, $nb2$ 4, $nb2$ 5 are sensed in order under the control of brush upper left RME, brush upper right RMK, brush upper left RM, brush upper right RMJ, respectively (circuits 1217-1220). Since the digit 6 is represented by code elements "1" and "5," test relay $Mf1$ will be operated as soon as it is connected to contact $nb2$ 1 (circuit 1217). Such actuation of $Mf1$ stops the RM sequence switch in position 2 (circuit 1194) and actuates relay Mf (circuit 1221). Mf locks itself (circuit 1222) and puts into operation the appropriate readout device (as determined by the position of switch RN at the moment). In the case under consideration relays $Fa1$, $Fa2$ are operated (circuit 1223) to energize RAM (circuit 1118) which then starts switch RA rotating. The number stored in $NA1$ $NA8$ (e. g., the multiplicand) is now transferred to the accumulator in substantially the same manner as in a summation problem. Since relays $Ad1$, $Ad2$ were operated by Me (circuit 1194½) the true number rather than its ten complement is read out. Moreover the column shift relays ($S/1-S/8$ in area G25 drawing group 6) are controlled somewhat differently in the present instance. When relay Mf is actuated it controls the starting of the RA readout switch. $Mf/4$ front operates column shift relays $S/8$ and $S/6$ (circuit 1225) under control of the $Va-Vr3$ counting chain of area G23 which has been advanced one step for each multiplier storage set sensed (as above described in detail) and therefore now in "position 6" with relays $B1$ and $Vr3$ operated (circuit 1214). When relay N is operated near the commencement of the readout cycle (circuit 1118) $n4$ front locks the relays $S/8$ and $S/6$ (circuit 1226). Because of the operation of column shift relays $S/8$, $S/6$ the eight multiplicand digits are transferred to auxiliary accumulator relay chains $Fs3$, $F/3$, $Fs3-Fs10$, $F/10$, $Fv10$ or to main accumulator switch $SM3-SM10$ respectively as can readily be seen by tracing the course of readout wires 401-408. Readout wire 401 for instance, extends through $s/8$ 2 front, $mr1$ 3 front, to $SM3$ (circuit 1227) or to $Fs3$, $F/3$, $Fv3$ (circuit 1227½), while readout wire 408 extends through $s/8$ 5 front and $mr3$ 2 front to $SM10$ (circuit 1228) or to $Fs1$, $F/10$, $Fv10$ (circuit 1228½) depending upon whether $Nr1-4$ or $Nr1-4$ are operated (as explained hereafter).

While the readout RA is still performing its cycle the sensing switch RM commences its search for another closed contact in the multiplier storage equipment, this switch being started as follows: The operation of relay N in the early portion of the RA readout cycle (circuit 1118) energizes RMM (circuit 1229). As soon as the RM switch rotates beyond position $2\frac{1}{4}$ $Mf1$ is released (circuit 1217) thus releasing Mf (circuit 1222).

As RM rotates between positions $2\frac{1}{2}$ and $3\frac{1}{4}$ (written $2\frac{1}{2}/3$) and then later between positions $3\frac{1}{2}$ and $4\frac{1}{4}$ (written $3\frac{1}{2}/4$), test relay M_{t1} is connected to the "2 code" contacts of NB2 (i. e., $nb2\ 2$) and then to the "4 code" contact thereof (i. e., $nb2\ 4$) (circuits 1230, 1231) but since these contacts are open M_{t1} makes no response.

Finally when RM arrives in position $4\frac{1}{2}$ the test relay M_{t1} is operated from the "5 code" contact of NB2 (i. e. $nb2\ 5$) (circuit 1232). Assuming that relay N is still held by the rotating readout RA (circuit 1118) the readout starting relay M_f is prevented from operating at $n2$ back (circuit 1221).

When RA has substantially completed its cycle relay N is released (circuit 1118) thus causing the release of $S/8$, $S/8$ (circuit 1228). The relay M_f is thereby operated (circuit 1221). As before M_f operates relays $S/8$ and $S/8$ (circuit 1228) and also starts a readout device into operation, but this time since the RM switch is in position 5 magnet RM5 will be the one which is energized (circuit 1233).

As explained in detail in the description of the readout devices above sequence switch R5 has its pulsers and control cams arranged to readout five times the multiplicand. According to the rule previously enunciated the pulses delivered over any given readout wire (e. g. over 401 associated with the highest order multiplicand storage set NA1) are equal to the units component of five times each of the code elements stored in the same order storage set (e. g. the units component of five times 2 which is 0 plus the units component of five times 5 which is 5, making a total of 5) plus the ten's component of five times each of the code elements stored in the next lower order storage set (e. g. the ten's component of five times 1 which is 0 plus the ten's component of five times 5 which is 2, making a total of 2). Thus the pulses transmitted over readout wire 401 for example should, in accordance with the above rule, represent the value 7. By referring to the cam chart of Fig. 22, while bearing in mind the fact that the only contacts closed in NA1 are $na1\ 1$ and $na1\ 5$ and that the only contacts closed in NA2 are $na2\ 1$ and $na2\ 5$, it will be seen that the second one of the two possible V pulses shown shaded in Fig. 22 is rendered effective via brush upper left R5F under the control $na1\ 5$ while the last two of the four possible unit pulses shown black in Fig. 22 are rendered effective via brush lower right R5F under the control of $na2\ 5$. Thus the pulses delivered over readout wire 401 consist of one V pulse and two unit pulses representing the value 7. In similar fashion readout wires 402, 403, 404, and 405 carry pulses representing the values 10, 0, 7 and 5 respectively, while the overflow wire 400 carries pulses representing the value 3; thus the number transferred to the accumulator readout R5 represents five times the multiplicand (i. e., 3800.75) but is actually transmitted in the form 3, 7, 10, 0, 7, 5.

As before the sensing switch RM moves on while readout R5 is performing its cycle. This is effected as follows: relay N is actuated by R5 early in its cycle and is held till the cycle is substantially complete (circuit 1234). As before switch RM is thereby started (circuit 1229) thus releasing M_{t1} (circuit 1217) and then M_f (circuit 1222). As before the operation of N locks $S/8$, $S/8$ (circuit 1228) to prevent these from being released by the release of M_f (circuit 1225).

Now a seventh passing ground pulse over 411

operates V_a (circuit 1200) which in turn operates Br_4 (circuit 1235) and on the termination of such passing ground pulse V_b is operated (circuit 1201) thus leaving the counting chain in "position 7."

5 During the second third of the third revolution contacts $nb1\ 1$, $nb1\ 2$, $nb1\ 4$, $nb1\ 5$ are sensed in order under the control of the lower left, upper left, upper right, and lower right brushes of RML, respectively (circuits 1236—1239). Since the digit 10 2 is represented by the single code element "2," test relay M_{t1} will be operated as soon as it is connected to contact $nb1\ 2$ (circuit 1237). Assuming that R5 has not yet finished its cycle, the actuation of M_{t1} cannot now operate relay M_f (circuit 1221) because $n2$ back is open.

When at last readout switch R5 finishes its cycle and releases relay N (circuit 1234) relays $S/8$, $S/8$ are released (circuit 1228) and relay M_f is operated (circuit 1221). M_f locks itself (circuit 1222), starts the appropriate readout device (in this case switch R2) circuit 1240, and operates the appropriate columnshift relays as determined by counting chain $V_a—Vr_4$ in "position 7": namely 20 $S/3$, $S/4$ (circuit 1041). These relays $S/3$ and $S/4$ lock via $n4$ front (circuit 1242) when relay N is operated (circuit 1243) near the commencement of the readout cycle of switch R2.

Readout switch R2 now delivers over readout wires 401—409 (and overflow wire 400) pulses representing twice the multiplicand. In conformity with the rule set forth in the description of the readout devices, the pulses delivered over any given readout wire are such as to represent the units component of twice each of the code elements stored in the same order storage set plus the tens component of twice each of the code elements stored in the next lower order storage set. Thus, the pulses delivered over readout wire 402 associated with the second highest order storage set NA2, should represent the value which would be derived by taking the units component of 12 (i. e., 2×6) plus the tens component of 0 (i. e., 2×0), or, in other words, the total value of 2. Referring to the cam chart of Fig. 20, it will be seen that the transmission of this required value 2 over readout wire 402 is effected by transmitting the first two of the seven possible units pulses (shown black in Fig. 20). The transmission of these two pulses is controlled by brush 45 upper right R2I under control of contacts $na2\ 1$.

The pulses over the other readout wires 400, 401, 402, 403, 404, 405 are determined in similar manner, so that the pulses transmitted over these wires respectively represent the values 1, 5, 2, 0, 5.3, 0 which properly represent twice the multiplicand.

60 The readout wires 401—408 and overflow wire 400 are associated with auxiliary accumulator orders $Fs2$, $Ff2$, $Fv2—Fs3$, $Ff3$, $Fv3$ and $Fs1$, $Ff1$, $Fv1$, or main accumulator orders $SM2—SM9$ and $SM1$, respectively, via the contacts of column shift relay $S/3$ and $S/4$ depending upon whether $Nr1—Nr4$ or $Mr1—Mr4$ are operated.

65 The carryover and self-setting steps which have not been described in connection with the three readout cycles above outlined, will be understood to have taken place in exactly the same manner as in a summation problem. Likewise, the transmission of ground over leads LT_1 and LT_2 for operating and holding the T_f relays in conjunction with the carryover, is performed as before. The application of ground to LF in the early portion of each cycle and over lead LM in the later portion of each cycle for operating relays Fc , $70 Nr1$, $Nr2$, $Nr3$, $Nr4$ near the beginning of the

cycle, and for operating relays M_1 , M_2 , M_3 , M_4 near the end of the cycle will likewise be understood to have taken place as in summation.

More specifically, pulsers R2DD, R4DD and R5DD are supplied with ground from cams R2U, R4U, R5U to enable these pulsers to generate the carryover and self-setting pulses for the respective switches R2, R4 and R5. The carryover pulses so generated are then applied via wire TK to relays T_{a1} , T_{a2} , T_{b1} , T_{b2} , by cams R2D and R2E of switch R2, cams R4D and R4E of switch R4, or cams R5D and R5E of switch R5, respectively (circuits 1248-1248). Similarly, the self-setting pulses generated by these pulsers are then applied by a wire EK to relays E_{h1} , E_{h2} , E_{h3} by the same cams above mentioned (circuits 1249-1251). The properly timed ground potentials via leads L_{T1} and L_{T2} for operating relays L_f , L_t , to control the grounds which actuate and hold relays T_{f1} - T_{f6} are produced under the control of brush upper left R2B and brush lower right R2C (circuits 1252, 1253), in the case of readout switch R2 or under the control of brush upper left R4B and brush lower right R4C (circuits 1254, 1255), in the case of readout switch R4, or under the control of brush upper left R5B and brush lower right R5C (circuits 1256, 1257) in the case of readout switch R5 respectively. Likewise, the properly timed ground potentials for operating relay F_c in the earlier portion of the cycle and for operating relay M_c in the later portion of the cycle are produced under the control of brushes upper right R2B and lower left R2C (circuits 1258, 1259) in the case of switch R2, or under the control of brushes upper right R4B and lower left R4C (circuits 1260, 1261) in the case of switch R4, or under the control of brushes upper right R5B and lower left R5C (circuits 1262, 1263) in the case of switch R5.

As before, sensing switch RM continues onward while readout R2 is still continuing its cycle, this switch being started as follows: relay N is operated from rotating readout R2 (circuit 1243), thus starting switch RM (circuit 1229) which shortly releases M_{t1} (circuit 1237), thus releasing M_f (circuit 1222), but leaving column shift relays S_{f3} , S_{f4} held over n_4 front (circuit 1242). After finishing the sensing of N_{b1} (without effect, since contacts n_{b1} 4 and n_{b1} 5 are open) the switch RM delivers an eighth passing ground pulse via wire 411 to operate V_c , thus releasing V_a and later V_b (circuits 1283, 1281, 1288). Again, near the very end of the third revolution of RM, a ninth passing ground pulse is transmitted. These eighth and ninth pulses serve no purpose but are not detrimental.

At the end of the third revolution, M_t operates (circuit 1266). M_t operates M_f as usual (circuit 1221). Earth via m_1 front, cam RMO in position 16, operates sequence switch magnet RCM (circuit 1267). As previously described, RC rotates and converts all stored "five" impulses into groups of five unit pulses which are transmitted to the corresponding switches SM1-SM16 (drawing group 7), after which the result is ready for transmission to the operator's set. In position 7 of cam RCD of the first calculator circuit ground via back, wire 814 operates relay E_c (circuit 1288) so that the similar ground from the other calculator circuit operates V_s (circuit 1289). The result is now sent and printed on the operator's set as described for addition and subtraction except in regard to the decimal point.

For each result digit sent FD makes one step (circuits 1153, 1160). As the number of steps made by FD before the decimal point is reached is equal to the number of steps previously made by PD, therefore the position of the decimal point is determined when wipers $fdmb$ and $pdmb$ are in line and complete a circuit for relay P_u via mu front.

In the case actually assumed for illustration (1760.15 $\times$ 26 = 19763.90) switch PD will have taken five steps (i. e. three steps for the three integral digits of 1760.15 and two more steps for the integral digits of 26) while switch BD will have taken seven steps (i. e. five steps for the five digits of 1760.15 and two more steps for the digits of 26). Thus when the result sensing switch FD reaches position 6 (i. e. after transmitting the first five result digits 19763) relay P_u will be operated via the multiple MLL, which is wired to arcs $fdmb$ and $pdmb$ in an offset manner so that wire 1 from contact 1 of $fdmb$ extends to contact 0 of $pdmb$, etc. (circuit 1270). The operation of this relay P_u is essentially similar to the operation of the same relay which was previously described in the case of a summation problem, excepting that in the summation case the path from $fdmb$ wiper to relay P_u invariably extended through the ninth contact of arc $fdmb$ and mul back, while in multiplication the corresponding path may extend through any of the contacts 1-16 of $fdmb$ depending upon the position of $pdmb$. The manner in which relay P_u causes the printing of a decimal point and temporarily suppresses the advance of sensing switch FD until such decimal point has been printed is exactly the same as in the summation problem previously described.

The manner in which the transmission of solution digits is terminated is also slightly different in the case of multiplication, being determined by the relationship between switches FD and BD rather than by the relationship between FD and LD. In the case of multiplication, relay L_s is never operated to start switch LD since a_1 front is not closed (circuit 1149). On the other hand switch BD is operated as previously described to count the aggregate number of digits in both the multiplier and multiplicand. Therefore, instead of operating relay R_f via arcs of switches LD and FD as in the case of summation (circuit 1169) the corresponding operation of relay R_f in the case of multiplication is effected through arcs of switches FD and BD (circuit 1273). Thereafter the release of all the equipment and the restoration to normal of all the switches takes place just as in the case of summation.

In the case assumed for illustration aggregate number of digits in the multiplier and multiplicand is 7 and therefore 7 result digits are printed prior to release of equipment by operation of relay R_f , thus giving the result in the form 19763.90. This is desirable since it is usually customary to show as many decimal digits in the solution as there are in the two factors together.

For the sake of completeness, consideration may be given to a case in which both factors were wholly integral so that PD, BD are in the same position, and wherein therefore the result is a whole number. In such case when FD reaches the position corresponding to PD (which would tend to initiate sending of a decimal point) R_f , Fig. 4, operates; ground, $fdmb$, multiple to $bdmb$, mul front, wire 818 R_f . Relay R_f causes immediate release as previously described, no decimal point being sent.

RECAPITULATION

OPERATOR'S STATIONS AND THEIR CONTROL OF
CALCULATING EQUIPMENT

As explained at the beginning, the present calculating equipment is intended to be operated from a plurality of operator's stations, such as illustrated in drawing group 2, and comprises two duplicate calculators (drawing groups 5, 6, and 7) which perform duplicate computations concurrently and produce independent results. After a result is computed by each structure the two results are checked against each other and are transmitted to a printer at the operator's station which controlled the calculating equipment.

Each operator's station may seize, or take control of, the calculating equipment by operating a start key KS which, through a seizure device of drawing-group 3, will connect the particular station to the calculating equipment. As described in detail above, if the calculating equipment is in use under control of one operator station, when key KS is operated at another operator's station, the second operator's station will not seize the calculating equipment until the first operator's station completes the use thereof by releasing its key KS. Furthermore, a disconnection device is provided to automatically disconnect the calculation equipment from a given operator's station if no activity takes place for a predetermined length of time providing some other operator's station has called for the equipment by operating its key KS. Thus, if an operator of a station forgets to release his start key after having used the machine, another operator's station will be enabled to seize the equipment for use. When the calculating equipment is seized by an operator's station, it sends a three dot signal to the latter to indicate that the equipment is ready to receive a problem (relays Sw and Sy, Po, and cam IRB, Figs. 4E(1) and 4E(2)).

The transmission of digits 1-9 from an operator's station is effected by a four-wire code, the code chosen being "1, 2, 4, 5." A further wire for transmission of zeros is provided. Arithmetical signs and a cancel symbol are transmitted to the calculating equipment on three wires. For printing all digits and signs at the operator's station under the control of the calculating equipment seven wires interconnect each station with the calculating equipment.

In the calculating equipment it is to be remembered that drawing groups 4 and 8 show structures common to two duplicate calculators whereas drawing groups 5, 6, and 7 (except for the structure shown below, the dot-dash line in Fig. group 7) show a single calculator a duplicate of which is understood to be provided in the complete machine.

The amount is transmitted from any operator's station by selectively depressing ten numeral keys beginning with the digit of highest order, with proper operation of the decimal point key if one is required, and may be received by one of two storage sets NA1 . . . NA8 or NB1 . . . NB8 which storage sets comprise a group of four relays for each digit to be entered. When the first number is entered with the equipment cleared, the number will be invariably entered in storage set NA1-8 with the first digit always routed to the highest order of this storage set. Storage entry distributor structure (drawing group 4) directs the entries beginning with the

highest order to successive lower orders of the storage set as successive numeral keys are operated. Following the completion of each digital entry due to depression of a numeral key, and upon release of said key, the digit entered is printed at the operator's station; and upon completion of said printing the key for the next digit or sign may be depressed. When the entire number to be entered has been transmitted, a sign control key may be depressed. The depression of any of the following sign keys +, -, ×, = signifies completion of the entry of a number, and any of the first three mentioned signs also initiate operation of alternator relays Fo, So, To, which will cause the entry of the next number to be routed to the second storage set NB . . . NB8. In cases of repeated addition or subtraction operations, where it may be desired to sum up a plurality of successive numbers, the alternator will alternately condition storage sets NA1-8 and NB1-8 to receive the alternate numbers. In cases of multiplication no more than two numbers may be entered in the calculating equipment for any one problem, therefore the multiplicand (always being the first one to be entered) is invariably set up in the NA1-8 storage set while the multiplier is invariably set up in the NB1-8 storage set.

30

As stated above, the first number is entered in the equipment in the same manner no matter what operation is performed; it is set up and stored in 1, 2, 4, 5 code in storage set NA1-8. As the digits of the number are being entered one by one they are counted by two counting chains (drawing group 6) the first of which counts the total number of digits in the item entered, while the second counts only the number of integral digits (before the decimal point). In either addition or subtraction the first amount entered is invariably transmitted to two accumulating devices positively by a readout structure RA (drawing group 5). The initiation of a readout operation is effected by depression of either a + or - sign key. The sign key determines the type of entry (positive or negative) of the second number about to be set up, but as far as the first number is concerned it signifies completion of entry by the operator and causes its transmission to the accumulators.

Since the first number is set up in the A storage set invariably beginning with the highest order of this set, when the number is transmitted through readout RA it must be routed to its proper denominational position in the accumulators. For this purpose, a distributor structure (drawing group 6) is provided. For purposes of addition and subtraction a fixed decimal point has been arbitrarily established between the eighth and ninth orders of the accumulators, (having a total of 16 denominational orders each) and the integral digit counting chain (Br1-Vr4 drawing group 6) which has counted all integral digits during entry, will now control the distributor to enter all integral digits of the number to the left of the decimal point in the accumulators. The total digit counting chain (Dr1-Cr4 drawing group 6) in case of addition is used to enable only the transmission lines to those orders which will receive digits. In the orders where no significant digits have been set up the transmission lines between the readout RA and the accumulators are left open.

ADDITION

The accumulating structure (drawing group 7) of each calculator consists of two accumulators, one of which accumulates units pulses (stepping switches SM1-18) and the second of which accumulates "five" or "V" pulses (relay groups "F₁, F₂, F₃, F₄" 1 to 18). In the course of entries in said accumulators, every second entry in a given order of the "V" pulse accumulator (making a total entry of ten units in said order) is transferred as one unit to the next higher order of the units accumulator.

After depression of the plus sign key signifying that the second number to be entered by the operator is to be added to the first number, the operator transmits the second number to storage set NB1-8. Following the entry of the second number, if a third number is to be added, the plus key is depressed again. This will signify completion of the entry of the second number and said second number will be read out from storage set NB1-8 and transmitted to the accumulators by readout device RB. The readout devices RA and RB are in all respects similar; each consists of a sequence switch having properly "designed" "cams" (commutator sets) which readout the coded representations in storage sets NA1-8 and NB1-8, respectively, and transmit them in the form of "units" and "fives" pulses to the respective accumulators (units and V).

The third number is now set up by the operator and is stored in NA1-8; and assuming that no further numbers are to be added, the = key is depressed. The depression of the = key signifies completion of entry of the third number, as well as completion of the problem, and causes transmission thereof to the accumulators by readout RA. Upon completion of entry of the third number into the accumulators, the values in the V pulse accumulator (5 or 0 in each order) are transferred to the units accumulator by readout RC.

The additions of the three numbers described above have proceeded concurrently in the two calculators and the sum thereof will now be present in the units (I) accumulator of each calculator. Next checking of the sums obtained is effected by comparing said sums over a comparison circuit (drawing group 7) and if the sums correspond, printing is initiated by check relays Vs (drawing group 8).

Since it is not desired to print meaningless zeros before and after the result, stepping switch FDM and LDM are caused to hunt down from the highest and up from the lowest accumulator orders to locate the highest and lowest significant digits respectively. When switch FDM arrives at the highest significant digit, it commences to readout the successive digits of the sum and causes printing thereof. Relays Og Tw Fp Fq O/ and Tp (drawing group 8) serve to transmit the codes for energizing the required selection magnets in the printer of the operator's set. If the answer contains decimal digits, a decimal point is transmitted to the printer in its proper denominational position.

SUBTRACTION

Subtraction is effected by complementary addition. After the first number is set up and stored in storage set NA1-8, a minus key is depressed to signify the completion of the first number entry and to prepare the calculating equipment for subtracting the second number to be entered. The first number is transferred positively to the ac-

cumulator as is the case of addition described above. The second number is then entered by the operator and is stored in storage set NB1-8. If no further numbers are to be added or subtracted, the "equals" key is now depressed. Again this key signifies completion of the entry of the second number as well as completion of the problem.

Since the minus key had energized Bn (drawing group 4) the transfer of the second number from storage set NB1-8 through readout RB is modified by energization of subtraction relays Su1-Su2 (drawing group 5). The energization of these relays causes RB (which in the addition example readout the true number stored) to readout into the accumulators the nine's complement of the number stored. Further devices are provided to enter nines in all accumulator orders to the left of the highest digit and a fugitive one means is provided to enter a fugitive one into the lowest digit of the complement entered in the accumulator. Following the complimentary entry, the reading of the V pulse accumulator is transferred to the I pulse accumulator in the same manner as in the case of addition described above. The checking of the difference and the printing thereof is effected in the same manner as in the case of addition supra.

It is to be understood that any number of successive items may be added and/or subtracted in succession each number being transmitted from one of the storage sets to the accumulators according to the sign preceding it, and the result may be obtained by depressing the equal key at the end of the series of entries. The present machine is incapable of printing a true negative total. If a negative total is accumulated, it will be printed as a complement.

MULTIPLICATION

In multiplication only two numbers may be multiplied at one time. The first number is entered in the NA1-8 storage set, and after depression of the multiplication key, the second number is set up and entered in the NB1-8 storage set. Depression of the $\times$ key Ky (unlike the depression of the plus and minus keys) only signifies completion of entry of the first number but does not cause transfer thereof to the accumulators. As the first number is entered, the total number of digits and number of integral digits are again counted by the counting chains Dr1-Cr4 and Br1-Vr4 which also functioned in addition and subtraction computations. In multiplication, however, the integral digit counting chain Br1-Vr4 has no useful function at this point, and it is therefore released upon receipt of the $\times$ sign and is prevented from counting the digits of the second number (multiplier). In order to locate the decimal point in the product to be computed, stepping switches BDM and PDM (drawing group 8) also count the total digits and integral digits respectively as the first number is set up. (These switches counted also in the cases of addition and subtraction but, performed no function in these operations).

The operator now enters the second number in storage set NB1-8, and as this number is entered, stepping switches BDM and PDM are further advanced in accordance with the total and integral digits of the multiplier, respectively, but neither counting chain Dr1-A4 nor counting chain Br2-Vr4 is affected by the entry of the multiplier.

With the multiplicand now stored in the A storage set NAI-8 and the multiplier stored in the B set NB1-8, the multiplication may be initiated by depressing the equals key. In order to effect multiplication in this machine, special readouts R2, R4, R5, (drawing group 5) are provided which readout twice the multiplicand, four times the multiplicand, and five times the multiplicand, respectively. These are used in connection with the multiplicand times one readout RA. It is to be remembered that both the multiplicand and the multiplier are stored in the "1, 2, 4, 5" code in the A and B storage sets NAI-8 and NB1-8, respectively. In carrying out a multiplication, the successive digits of the multiplier are read beginning with the lowest order under control of cycle controller RM, and the readouts corresponding to the code components of each multiplier digit are rendered effective to readout into the accumulators the proper multiples of the multiplicand.

For example, assume that multiplier digit 7 is read in the lowest order. This digit will be represented by the energized condition of a "5" relay and a "2" relay, e. g. C82 and C86 in NR8. In the first multiplying cycle (for the lowest order multiplier digit) readout devices R2 and R5 will be operated in succession. At the beginning of the multiplication relays S/17 and S/18 of the column shift mechanism are energized to route the lines from the readout devices RA, R2, R4 and R5 to the lowermost orders of the accumulators. With this routing, when R2 functions, twice the multiplicand standing on storage set NAI-8 is entered in the accumulator. Following this entry R5 functions to enter five times the multiplicand thus completing multiplication by seven.

Following the multiplication by the lowest digit, cycle controller RM advances the counting chain Br1-Vr4 so as to energize relays S/15 and 16; thereby shifting to the next higher group of orders. Thereafter cycle controller RM causes reading of the code components of the next higher multiplier digit and renders the readouts corresponding to the components of said digit effective as before. The foregoing operations repeat themselves until the highest order of the multiplier storage set is read and after the last multiple is entered under control of the cycle controller RM, a transfer operation from the V accumulator to the I accumulator is performed (by readout RC).

The cycle controller RM consists of a sequence switch which makes three complete revolutions for a complete multiplying operation (i. e. reading eight possible multiplier digits, controlling seven column shifts, rendering effective the multiplicand multiple readouts, and controlling total transfer from the V accumulator to the I accumulator). The cycle controller reads the multiplier digits and stops once for each code component present to permit a corresponding entry to be made in the product accumulators. In the absence of code component representations (zeros for some of the multiplier digits) the cycle controller continues its advance. Therefore, the length of time required in multiplication will depend on the values of the digits of the multiplier, as well as on the number of zeros present therein.

When both calculators complete their multiplications, a comparing circuit is established as in the case of addition. When agreement is

found, switches FDM and PDM hunt for the highest and lowest digit of the result, respectively, and printing is initiated and carried forward same as in addition, except as to the decimal point. The decimal point is now printed under control of stepping switch PDM which has been stepped in accordance with the integral digits in the two factors as above described.

When printing of the product is completed, 10 relay R4 is picked up and the machine is cleared by releasing all ground relays.

DETAILED TRACING OF CIRCUIT PATHS INVOLVED IN THE TYPICAL OPERATIONS DESCRIBED

- 15 Circuit 1001—ground via key KS (Fig. 2(1), over Fig. 2(2) and terminal 18, through winding of relay Str to battery.
- 20 Circuit 1002—ground via cor 1 back Fig. 3(1) st1 1 front, winding of relay Cs Fig. 3(2) to battery in Fig. 3(1).
- 25 Circuit 1003—ground cs2 front Fig. 3(2) rs4 back through winding of RLM to battery.
- 30 Circuit 1004—ground via winding of Cor Fig. 3(1), st1 2 front, brush lower left RLDD in position 1 Fig. 3(2), brush lower right RLDD, bdl 1 back, winding of Rs to battery.
- 35 Circuit 1005—ground through winding Covi Fig. 3(1) stvn2 front brush upper right RLCC in position 14 Fig. 3(2), brush lower right RLDD, bdl 1 back winding of Rs to battery.
- 40 Circuit 1006—battery via dr3 back Fig. 4A(2), srl back (Fig. 4C(3) across Fig. 4E(2), el5 back Fig. 4E(1), upward across Fig. 4C(1) to Fig. 4A(1) (lead 117) thence to lead 117 Fig. 3(2).
- 45 Circuit 1007—battery on lead 117 as traced in circuit 1006, through winding of Tm (Fig. 3(2) eleventh contact and wiper tm2 Fig. 3(1), cs3 front Fig. 3(2).
- 50 Circuit 1008—battery on lead 117 as traced in circuit 1006 winding of Tm Fig. 3(2), tm2 front rs4 front cs2 front to ground.
- 55 Circuit 1009—ground via cs3 front (Fig. 2(2) tm2 wiper and tenth contact Fig. 3(1) tm1 front Fig. 3(2), winding of Bd1 to battery.
- 60 Circuit 1012—ground rs3 front Fig. 3(2) lead 116 to Fig. 4A(1) ri2 back, winding of Og to battery.
- 65 Circuit 1013—ground via gg5 and gg6 Fig. 4A(1), across Figs. 4C(1) 4C(2) 4C(3) 4D(1) 4F(1) 4F(2) (designated as leads 306), thence to lead 306 Fig. 5G(1) and a similar lead in the duplicate equipment not shown; from lead 306 Fig. 5G(1) the circuit branches extending on one hand through the winding of Gr to battery and on the other hand to a terminal GL which is understood to connect to a corresponding terminal GL in Fig. 7B(2) and thence through the winding of Gn to battery.
- 70 Circuit 1014—ground via gg2 front Fig. 4A(1), over Figs. 4C(1), 4E(1) to Fig. 4E(2), thence branching the circuit extends on one hand via Gh to battery and on the other hand via lead 808 to Fig. 8A(2), thence through winding of Ag to battery.
- 75 Circuit 1015—ground via sc3 back Fig. 5G(1) gr2 front, over Fig. 5G(2) via lead 428 to Fig. 6A(2), through winding of Cj to battery.
- Circuit 1016—ground via gr4 front Fig. 5G(1) od1 back mi4 back Fig. 5D(1) thence down across Fig. 5G(1) to 5G(2) thence via lead 427 to Fig. 6A(2), through winding of Aj to battery.

- Circuit 1017—ground via *gh3* Fig. 4E(2), *do2* back Fig. 4C(1), up across the corner of Fig. 4A(1), through the winding of *Ra* Fig. 4A(2) to battery.
- Circuit 1020—ground via *ra3* front Fig. 4A(2), *do2* back Fig. 4C(1), up across the corner of Fig. 4A(1), through the winding of *S* to battery.
- Circuit 1021—ground via *ra1* front Fig. 4A(2), across Fig. 4B(1), thence dividing through the windings *C48* and *C59* to battery.
- Circuit 1022—ground *ra2* front, down across Figs. 4C(3) 4D(1), thence dividing through windings *C89* and *C100* to battery.
- Circuit 1023—ground via *sj2* Fig. 4A(2), *fr2* back, *d4* 3 back, *fr3* 3 back, *fr2* 2 back, *d2* 3 back, *fr1* 2 back, *d1* 3 back, *bc1* 1 front through winding of *C33* Fig. 4B(1) to battery.
- Circuit 1024—ground via *gh1* Fig. 4E(2), across Fig. 4E(1) Fig. 4C(1), through magnet *IRM* Fig. 4A(1) to battery.
- Circuit 1025—battery via a resistance adjacent *relay Gh*, Fig. 4E(2), via *gh4* front, through winding of *Sw* to ground.
- Circuit 1026—ground via brush lower left *IRB* in any position except 10 $\frac{1}{4}$ to 11 inclusive or 18 $\frac{3}{4}$ to 2 inclusive Fig. 4E(2), thence out over brush upper right *IRB* *sw1* back, to the upper side of the winding *Sw*.
- Circuit 1027—ground via brush lower left *IRB* in positions 3 $\frac{1}{4}$ to 4 $\frac{3}{4}$ inclusive (written 3 1/2/4 1/4) Fig. 4E(1), thence out over brush upper left *IRB*, *sw3* front Fig. 4E(2), *sy3* back, through the lower edge of Fig. 4C(2) through the winding of *relay Po* Fig. 4A(2) to battery.
- Circuit 1028—ground via *po2* front Fig. 4E(2), across Figs. 4C(2) 4C(3) 4D(1) 4F(1), via lead *819* to Fig. 8B(1), thence across Fig. 8A(2) through the left winding of *Og* Fig. 8A(1) to battery.
- Circuit 1029—ground via *po3* front Fig. 4E(2), across Figs. 4C(2) 4C(3) 4D(1) 4F(1), via *820* to Fig. 8B(1) thence across Fig. 8A(2) through the right winding of *Tw* Fig. 8A(1) to battery.
- Circuit 1030—ground via *po4* front Fig. 4E(2) across Figs. 4C(2) 4C(3) 4D(1) 4F(1), via lead *821* to Fig. 8B(1), thence across Fig. 8A(2) through the left winding of *Fp* Fig. 8A(1) to battery.
- Circuit 1031—ground via *po5* front Fig. 4E(2), across Figs. 4C(2) 4C(3) 4D(1) 4F(1), via lead *822* to Fig. 8B(1), thence across Fig. 8A(2) through the right winding of *Fq* Fig. 8A(1) to battery.
- Circuit 1032—battery via *og1* front (or *o2* front in some cases) Fig. 8A(1), via lead *821* to Fig. 4E(1), thence across Fig. 4C(1) to Fig. 4A(1), via lead *112* to Fig. 3(2) via brush lower right *RLY* in position 1 out through brush lower left *RLY* across Fig. 3(1) via lead *12* to Fig. 2(2) through magnet *CM1* to ground.
- Circuit 1033—battery via *tw1* front (or *tp1* front in some cases) Fig. 8A(1), via lead *822* to Fig. 4E(1) thence across Fig. 4C(1) to Fig. 4A(1), via lead *111* to Fig. 3(2), via brush lower right of *RLW* (not shown) in position 1, via lead *11* Fig. 3(1) to Fig. 2(2) through magnet *CM2* to ground.
- Circuit 1034—battery via *fp1* front Fig. 8A(1) via lead *823* to Fig. 4E(1), thence across Fig. 4C(1) to Fig. 4A(1), via lead *110* to Fig. 3(2) via brush lower right of *RLU* (not shown) in position 1 via lead *10* Fig. 3(1) to Fig. 2(2) through magnet *CM3* to ground.
- Circuit 1035—battery via *fq1* front (or *o1* front or *tp2* front in some cases) Fig. 8A(1) lead *824* to Fig. 4E(1), thence across Fig. 4C(1) to Fig. 75
- 4A(1), via lead *108* to Fig. 3(2), via brush lower right of *RLS* (not shown) in position 1, via lead *9* Fig. 3(1) of Fig. 2(1) through magnet *CM4* to ground.
- Circuit 1036—ground via any one of the front contacts of magnets *CM1*-*CM4* Figs. 2(1) and 2(2), via lead *15* to Fig. 3(1), via *co2* front over Fig. 3(2), via lead *115* to Fig. 4A(1), down across Fig. 4C(1) Fig. 4E(1), via *po6* front Fig. 4E(2) over Fig. 4C(2) through winding of *Ps* Fig. 4C(1) to battery.
- Circuit 1037—battery via *ps2* front Fig. 4C(1) up across Fig. 4A(1) via lead *113* to Fig. 3(2), brush lower right *RLBB* in position 1, brush lower left *RLBB* across Fig. 3(1) via lead *13* to Fig. 2(2) through magnet *PM* to ground.
- Circuit 1038—ground via brush lower left *IRB* in position 9 $\frac{1}{4}$ Fig. 4E(1), brush lower right *IRB* *sw2* front Fig. 4E(2) through winding of *Sy* to battery.
- Circuit 1039—ground via *sy1* front Fig. 4E(2), *sw2* front through winding *Sy* to battery.
- Circuit 1041—ground via front contact of digit key *K1*, *K3*, *K8*, or *K9* Fig. 2(1), or 2(2), via lead *1* to Fig. 3(1), via brush lower left *RLC* in position 1 Fig. 3(2), via brush lower right *RLC* via lead *101* to Fig. 4A(1) through the winding of *A1* Fig. 4A(2), *gg3* front Fig. 4A(1) *nm2* back, through the winding of *Dr* to battery, Fig. 4A(2).
- Circuit 1042—ground via front contact of digit key *K2*, *K3*, *K7* or *K8* Fig. 2(1), or 2(2), via lead *2* to Fig. 3(1), brush lower left *RLE* in position 1 Fig. 3(2), brush lower right *RLE* via lead *102* to Fig. 4A(1) through winding of *relay A2* Fig. 4A(2), via *gg3* front Fig. 4A(1), *nm2* back, through the winding of *Dr* to battery, Fig. 4A(2).
- Circuit 1043—ground via front contact of digit key 4 or 9 Fig. 2(2), via lead *3* Fig. 3(1), via brush lower left *RLG* in position 1 (not shown), via brush lower right *RLG* via lead *102* Fig. 3(2) to Fig. 4A(1) through winding of *relay A3* via *gg3* front, via *nm2* back, through the winding of *Dr* to battery.
- Circuit 1044—ground via front contact of digit key 5, 6, 7, 8, or 9 Fig. 2(2), via lead *4* to Fig. 3(1), via brush lower left *RLI* (not shown) via brush lower right *RLI*, via lead *104* Fig. 3(2) to Fig. 4A(1), through winding of *relay A4* via *gg3* front via *nm2* back, through the winding of *Dr* to battery.
- Circuit 1045—ground via *a2* 2 Fig. 4A(2), *c33* 3 Fig. 4B(1), through the winding of *C2* Fig. 4B(2) to battery.
- Circuit 1046—ground via *a4* 2 Fig. 4A(1), across Fig. 4A(2), via *c33* 1 front Fig. 4B(1) through winding of *C4* Fig. 4B(2) to battery.
- Circuit 1047—ground via *dr2* front Fig. 4A(2), *st1* back, through winding of *P1* to battery.
- Circuit 1048—ground via *dr1* front Fig. 4A(2), across Figs. 4A(1) 4C(1) 4E(1) 4E(2) 4F(1) via lead *816* to Fig. 8B(1) thence dividing through winding of *relay Jd1* to battery, on one hand and on the other hand, via *fp1* back Fig. 8A(2), through the winding of *Jsp* to battery.
- Circuit 1049—ground via *jda2* and *jda3* Fig. 8B(1), via leads *815* and *817* to Fig. 4F(1), across Fig. 4F(2) via leads *812* to the duplicate computing equipment (not shown), on the one hand, and to Fig. 5C(1) on the other hand, via lead *412* to Fig. 6A(1) via *lb1* back through the winding of *L2* to battery.
- Circuit 1050—ground via *la1* front Fig. 6A(1), cr 1 2 back through winding of *Dr1* to battery.

- Circuit 1051—ground via *jd1* front Fig. 8B(1), *at1* Fig. 8A(2) through magnet BDM Fig. 8B(1) to battery.
- Circuit 1052—ground via *jsp1* front and *jsp2* front Fig. 8A(2), via leads *810* and *811* to Fig. 4E(2) across Figs. 4F(1) 4F(2) via leads *811* to the duplicate equipment (not shown) on one hand, and on the other hand to Fig. 5G(1) via leads *411* to Fig. 6A(1) via *vbl* back through winding of *Va* to battery.
- Circuit 1053—ground via *val* front Fig. 6A(1), *vrl* back through the winding of *Brl* to battery.
- Circuit 1054—ground via *jsp3* front Fig. 8A(2), *at1* back through magnet PDM to battery.
- Circuit 1055—ground via *cl1* front Fig. 6A(2), *lc1* back Fig. 6A(1) via the right winding of *Lb* *la2* front, the winding of *La* to battery.
- Circuit 1056—ground via *aj2* front Fig. 6A(2), *vc1* back Fig. 6A(1), right winding of *Vb*, *va2* front, winding of *Va* to battery.
- Circuit 1057—ground via *s15* front Fig. 4A(2), *tl1* back, right winding of *S1* *tl2* front, winding of *F1* to battery.
- Circuit 1058—ground via *si2* front Fig. 4A(2), *fl1* 3 back winding of *D1* to battery.
- Circuit 1059—ground via *si2* front Fig. 4A(2), *f4* 2 back, *d4* 3 back, *f3* 2 back, *d3* 3 back, *f2* 2 back, *d2* 3 back, *f1* 2 back, *d1* 3 front, *bs2* front, through the windings of *C34* and *C35* parallel Fig. 4B(1) to battery.
- Circuit 1060—ground via *fl1* 1 back Fig. 4A(2), *dl1* front, down across Fig. 4C(3) winding of *Td* Fig. 4E(2) to battery.
- Circuit 1061—ground via *dr1* back Fig. 4A(2), across Figs. 4A(1) 4C(1) *td1* front Fig. 4E(2), *th2* back, through the winding *Dp* to battery.
- Circuit 1062—ground via *c2* 1 front Fig. 4B(2), *c35* 2 front Fig. 4B(1), down across Fig. 4D(1) Fig. 4F(1) via *dp4* front Fig. 4E(2), through a corner of Fig. 4C(3) in a corner of Fig. 4D(1) across Fig. 4F(1) via lead *820* to Fig. 8B(1) across Fig. 8A(2) through the right winding of *Tw* Fig. 8A(1) to battery.
- Circuit 1063—ground via *c4* front Fig. 4B(2), *c35* 4 front Fig. 4B(1) across Figs. 4D(1) 4F(1) via *dp2* front Fig. 4E(2), across corners of Fig. 4C(3) and Fig. 4D(1) down across Fig. 4F(1), via lead *822* to Fig. 8B(1) across Fig. 8A(2) through the right winding of *Fq* Fig. 8A(1) to battery.
- Circuit 1064—ground via any one of the front contacts of magnets CM1—CM4 Figs. 2(1) and 2(2) via lead *15* to Fig. 3(1), via *co2* front over Fig. 3(2) via lead *115* to Fig. 4A(1) down across Fig. 4C(1) Fig. 4E(1) via *dpl* front Fig. 4E(1) through the winding of *Pd* to battery.
- Circuit 1065—battery via *pd3* front Fig. 4E(2) across Figs. 4E(1) 4C(1) 4A(1) via lead *113* to Fig. 3(2), brush lower right RLBB in position 1 brush lower left RLBB across Fig. 3(1) via lead *13* to Fig. 2(2) through magnet PM to ground.
- Circuit 1066—ground via *td2* front Fig. 4E(2) *pd1* front winding of *Th* to battery.
- Circuit 1067—ground via back contact PM magnet Fig. 2(2) via lead *14* to Fig. 3(1) via *co2* front across Fig. 3(2) via lead *114* to Fig. 4A(1) Fig. 4C(1) *pd2* front Fig. 4E(2) winding of *Pd* to battery.
- Circuit 1068—ground via key KO Fig. 2(1), across Fig. 2(2), via lead *5* to Fig. 3(1), via brush lower left of *rlk* in position 1 (not shown) via lead *105* Fig. 3(2) Fig. 4A(1) *dd1* front through winding of *Os* Fig. 4C(1), via *75* *nm2* back Fig. 4A(1) through the winding of relay *Dr* to battery.
- Circuit 1069—ground via back contact of magnet PM Fig. 2(2), via lead *14* to Fig. 3(1) *co2* front Fig. 3(1) across Fig. 3(2), via lead *114* to Fig. 4A(1) via *os3* front Fig. 4C(1) through winding of *Oh* to battery.
- Circuit 1070—ground via *oh1* front Fig. 4C(1) across Figs. 4C(2) 4C(3) to *dp6* front Fig. 4E(2); upon the energization of *Dp* this ground is extended via *dp6* front through the winding of relay *Pd* to battery.
- Circuit 1071—either ground via *nm1* back Fig. 4A(1) *sj6* front Fig. 4A(2) *fl1* front (*fi* being operated by the counting of a non-zero digit as heretofore explained); or ground via *sy2* front Fig. 4E(2) *pol* front lead *812* to Fig. 8A(2) via *jpr2* front (*Jpr* being energized by the ground potential just traced) via lead *814* to Fig. 4E(2) across Fig. 4C(3) and 4A(2); thence joining both branches of the circuit extending through the winding of *Dd* Fig. 4A(2) to battery.
- Circuit 1072—ground via front contacts of sign keys *K* plus, *K* times, or *K* equals, Figs. 2(1) and Figs. 2(2), via lead *8* to Fig. 3(1) via brush lower left RLM in position 1 (not shown) brush lower right RLM (not shown) via lead *106* from Fig. 3(1) to Fig. 4A(1) down across Fig. 4C(1), through winding of *B1* Fig. 4C(2) across Fig. 4C(1), via *gg1* front Fig. 4A(1) across Fig. 4C(1) and 4C(2), through winding of *Sr* Fig. 4C(3), to battery.
- Circuit 1073—ground via front contacts of sign keys *K*—, *K*+, or *K*(.), Figs. 2(1) and 2(2) via lead *7* to Fig. 3(1) via brush lower left RLO in position 1 (not shown) brush lower right RLO (not shown) via lead *107* from Fig. 3(1) to Fig. 4A(1) down across to Fig. 4C(1) through winding of *B2* and Fig. 4C(2) across Fig. 4C(1) via *gg1* front Fig. 4A(1) across Fig. 4C(1) and 4C(2) through winding of *Sr* Fig. 4S(3) to battery.
- Circuit 1074—ground via front contacts of sign keys *K*= or *K*(.), Fig. 2(2) via lead *8* to Fig. 3(1) via brush lower left RLQ in position 1 (not shown) brush lower right RLQ (not shown) via lead *108* from Fig. 3(1) to Fig. 4A(1) down across to Fig. 4C(1) through winding of *B3* and Fig. 4C(2) across Fig. 4C(1) via *gg1* front Fig. 4A(1) across Fig. 4C(1) and 4C(2) through winding of *Sr* Fig. 4C(3) to battery.
- Circuit 1075—ground via *bl1* Fig. 4C(2), through winding of *Sf* to battery.
- Circuit 1076—ground via *bl2* Fig. 4C(2), through winding *Ss* to battery.
- Circuit 1077—ground via *bs1* Fig. 4C(2), thence branching through the windings of *Sp* and *Sh* in parallel Figs. 4C(2) and 4C(1) to battery.
- Circuit 1078—ground via *gg4* front Fig. 4A(1) across Figs. 4C(1) and 4C(2), via *db2* back, *sf2* front, winding of *Sf* to battery.
- Circuit 1079—ground via *gg4* front Fig. 4A(1) across Figs. 4C(1) and 4C(2), via *db2* back, *ss3* front, winding of *Ss* to battery.
- Circuit 1080—ground via *gg4* front Fig. 4A(1) across Figs. 4C(1) and 4C(2), via *db1* back, *sp3* front, thence branching through the windings of *Sp* and *Sh* Figs. 4C(2) and 4C(1) to battery.
- Circuit 1081—ground via *db3* back Fig. 4C(3), *sr2* back, *sl1* back Fig. 4C(2), *ss2* front, *sp2* front, across Fig. 4C(2) through the winding of *Po* Fig. 4E(2) to battery.

- Circuit 1082—ground via ps_4 front Fig. 4C(1) across Fig. 4C(2) through the winding of D_6 Fig. 4C(3) to battery.
- Circuit 1083—ground via sy_2 front Fig. 4E(2), ps_1 front, via lead 812 to Fig. 8A(2) through the winding of Jpr to battery.
- Circuit 1084—ground via nm_1 back Fig. 4A(1), sj_6 front Fig. 4A(2), dd_2 front Fig. 4A(1) (note that if D_d were not already operated, it would be operated at the instant of operation of Jpr via circuit 1071), over Figs. 4A(2) 4C(3) 4E(2), via lead 814 to Fig. 8A(2), via jpr_2 front, through the winding of Jpr to battery.
- Circuit 1085—ground via db_3 back Fig. 4C(3), sr_2 back, s_1 back Fig. 4C(2), ss_2 front, sp_2 back, winding of Su , winding of D_0 Fig. 4C(1) to battery.
- Circuit 1086—ground via su_2 front Fig. 4C(2), across Figs. 4C(3) 4D(1) 4F(1), via lead 820 to Fig. 8B(1), across Fig. 8A(2) through right winding of T_w Fig. 8A(1), to battery.
- Circuit 1087—ground via su_3 front Fig. 4C(2), across Figs. 4C(3), 4D(1), 4F(1), via lead 821 to Fig. 8B(1) across Fig. 8A(2) through left winding of F_p Fig. 8A(1), to battery.
- Circuit 1088—ground via any one of the front contact of magnets CM_1 — CM_4 Figs. 2(1) and 2(2), via lead 15 to Fig. 3(1), via Co_2 front over Fig. 3(2), via lead 115 to Fig. 4A(1), via do_1 front Fig. 4C(1), through winding of Ps , to battery.
- Circuit 1089—ground via gh_3 front Fig. 4E(2), across Fig. 4E(1), via do_2 front Fig. 4C(1), so_2 back, through winding of F_0 to battery.
- Circuit 1090—ground via gh_3 front Fig. 4E(2), across Fig. 4E(1), via to_1 back, left winding of S_0 , fo_1 front, winding of F_0 to battery.
- Circuit 1091—ground via gh_3 front Fig. 4E(2), across Fig. 4E(1), via do_2 front Fig. 4C(1), so_2 front thence branching through the right winding of S_0 on the one hand and through the winding of To on the other hand, to battery.
- Circuit 1092—ground via gg_3 front Fig. 4A(1), fo_2 back Fig. 4C(1), across Fig. 4A(1), through the windings of B_c and B_a in parallel Fig. 4A(2), to battery.
- Circuit 1093—ground via gg_3 front Fig. 4A(1), fo_2 front Fig. 4C(1), across Fig. 4A(1), through windings of A_c and A_e in parallel Fig. 4A(2), to battery.
- Circuit 1094—ground via su_4 front Fig. 4C(2) then branching on the one hand through winding of A_1 to battery and on the other hand down across Figs. 4C(1) 4E(2), via lead 813 to Fig. 8A(2), through winding of A_{11} to battery.
- Circuit 1095—ground via ag_4 front Fig. 8A(2), ai_2 front thence branching on the one hand through A_{11} to battery, on the other hand via lead 813 to Fig. 4E(2), across Fig. 4E(1) 4C(1) through the winding of A_1 Fig. 4C(2) to battery.
- Circuit 1096—ground via su_6 front Fig. 4C(2), hp_2 back Fig. 4C(1) right winding of B_n Fig. 6E(1) to battery.
- Circuit 1097—ground via ra_2 front Fig. 4A(2) down across Figs. 4C(2) 4C(1), via bn_1 front Fig. 4E(1) left winding of B_n to battery.
- Circuit 1098—ground via su_5 front Fig. 4C(2), hp_4 back Fig. 4C(1) thence dividing over an_2 back and an_3 back Fig. 4E(1) across Figs. 4C(1) 4C(2) 4C(3), 4D(1) 4D(2), via leads 382 one of which extends to the duplicate equipment (not shown) and the other of which ex- 75 tends to Fig. 5D(1) then across Figs. 5D(2) 5E(1) 5E(2) 5F(1) 5F(2) thence branching through windings of Ad_1 , Ad_2 Fig. 5C(2) to battery.
- Circuit 1099—ground via su_5 front Fig. 4C(2), hp_4 back Fig. 4C(1) thence dividing over an_2 front and an_3 front Fig. 4E(1) across Figs. 4C(1) 4C(2) 4C(3) 4D(1) 4D(2), via leads 383 one of which extends to the duplicate equipment (not shown) and the other of which extends to Fig. 5D(1) then across Fig. 5D(2) 5E(1) 5E(2) 5F(1) 5F(2) thence branching through windings of Su_1 and Su_2 Fig. 5C(2) to battery.
- Circuit 1100—ground via su_1 front Fig. 4C(2) down across Figs. 4C(1) 4E(1) 4E(2) 4F(1), through winding of As Fig. 4F(2) to battery.
- Circuit 1101—ground via so_1 back Fig. 4C(1) down across Figs. 4E(1) 4E(2) 4F(1), branching through as_1 and as_2 front over Fig. 4D(2), via leads 304 one of which extends to the duplicate equipment (not shown) and the other of which extends to Fig. 5D(1), through the winding of Sa to battery.
- Circuit 1102—ground via gr_1 front Fig. 5G(1), q_1 back, sa_2 front Fig. 5D(1), through the winding of Sa to battery.
- Circuit 1103—ground via sa_1 front Fig. 5D(1), through winding of Sc Fig. 5G(1) to battery.
- Circuit 1104—ground via sa_3 front Fig. 5D(1), across Figs. 5D(2) 5E(1) 5E(2) 5F(1) 5C(1) then branching through the windings of F_a_1 and F_a_2 in parallel Fig. 5C(2), to battery.
- Circuit 1105—ground via resistor shown to the left of relay Sc Fig. 5G(1), via sc_2 front, across Fig. 5G(2), via lead 429 to Fig. 6B(1), via a_1 front, across Fig. 6A(2), via vr_4 1 back Fig. 6A(1), br_4 2 back, vr_3 1 back Fig. 6A(2) br_3 2 back vr_2 1 back br_2 2 front across Fig. 6D(2) 6E(1) 6E(2) thence branching through windings of $S/13$ and $S/14$ in parallel Fig. 6F(1) to battery.
- Circuit 1106—ground via winding of $0d$ Fig. 5G(1) sc_1 front across Fig. 5G(2) via lead LL to Fig. 6A(2) across Figs. 6D(2) 6E(2) via $s/13$ 3 front Fig. 6F(1) thence branching through windings of $S/13$ and $S/14$ in parallel to battery.
- Circuit 1107—ground via sc_3 front Fig. 5G(1) across Figs. 5G(2) 5H(1) via lead 421 to Fig. 6B(1), through winding to T_j Fig. 6B(2) to battery.
- Circuit 1108—ground via fa_2 1 front Fig. 5C(2) across Figs. 5C(1) 5B(2) 5B(1) 5A(2) through the winding of I_p Fig. 5A(1) to battery.
- Circuit 1109—ground via fa_1 6 front Fig. 5C(2) across Figs. 5C(1) 5B(2) 5E(2) 5H(2) from terminal LT_2 in Fig. 5H(2) to the corresponding terminal in Fig. 7B(1), through winding of L_t Fig. 7B(2) to battery.
- Circuit 1110—ground via fa_2 6 front Fig. 5C(2) across Figs. 5F(2) 5F(1) 5E(2) 5H(2), via lead LF to Figs. 6B(2) 6E(1) through winding F_c Fig. 6E(2) to battery.
- Circuit 1111—ground via fc_1 front Fig. 6E(2) hence branching through windings of Nr_1 and Nr_2 Fig. 6F(1) to battery.
- Circuit 1112—ground via fc_2 front Fig. 6E(2) thence branching through windings of Nr_3 and Nr_4 Figs. 6F(1) and 6F(2) to battery.
- Circuit 1113—ground via fa_1 1 front Fig. 5C(2) through magnet RAM Fig. 5C(1) to battery.
- Circuit 1114—ground via sb_3 front Fig. 5D(1) across Figs. 5D(2) 5E(1) through windings of F_b_1 and F_b_2 in parallel in Fig. 5B(1) to battery.

- Circuit 1116—ground via *sb1* 1 front Fig. 5B(1) magnet RBM to battery.
- Circuit 1116—ground via *su6* front Fig. 4C(2) *hp2* front Fig. 4C(1) right winding of *An* Fig. 4E(1) to battery.
- Circuit 1117—ground via brush lower left RAB Fig. 5B(2) brush upper right RAC in any position between $1\frac{1}{2}$ and $6\frac{1}{2}$ (written $1\frac{3}{4}/6\frac{1}{4}$) across Figs. 5E(2) 5H(2) 5H(1) 5G(2) branching through left winding of *Eq* Fig. 5D(2) and 10 winding of *Q* Fig. 5G(1) to battery.
- Circuit 1118—ground via brush lower left RAB Fig. 5B(2) brush upper left RAC in any position between $1\frac{1}{2}$ and $6\frac{1}{2}$ inclusive (written $1\frac{3}{4}/6\frac{1}{4}$) across Figs. 5E(2) 5E(1) through 15 winding of *N* Fig. 5D(2) to battery.
- Circuit 1119—ground via brush lower left RAB Fig. 5B(2) brush lower left RAC in any position between $1\frac{3}{4}$ and 6 (written $2/5\frac{1}{4}$) across Figs. 5E(2) 5H(2), via lead *LM* to Fig. 6B(2) 20 through the winding of *Mc* Fig. 6E(2) to battery.
- Circuit 1120—ground via *mc1* front Fig. 6E(2) windings of *Mr1* and *Mr2* in parallel Fig. 6E(1) to battery.
- Circuit 1121—ground via *mc2* front Fig. 6E(2) 25 through the windings of *Mr3* and *Mr4* Figs. 6E(1) and 6E(2) in parallel to battery.
- Circuit 1122—ground via brush lower left RAB Fig. 5B(2) brush lower right RAC in any position between $1\frac{3}{4}$ and $5\frac{1}{4}$ (written $2/5 1/2$) down across Figs. 5E(2) 5H(2) from terminal 30 *LT2* Fig. 5H(2) to the corresponding terminal in Fig. 7B(1), through winding of *Lt* Fig. 5B(2) to battery.
- Circuit 1123—ground via *q2* front Fig. 5G(1) across Fig. 5G(2), via lead *LL* to Fig. 6A(2) across Figs. 6D(2) 6E(1) 6E(2), via *sf13* 3 front Fig. 6F(1), through winding of *Sf13* to battery.
- Circuit 1124—ground via *q2* front Fig. 5G(1) *sc1* 40 front through the winding of *Od* to ground.
- Circuit 1125—ground via *gr1* front Fig. 5G(1), *q1* front across Fig. 5G(2), via lead *428* to Fig. 6B(1), through winding of *Cj* to battery.
- Circuit 1126—ground via brush lower left RAB 45 Fig. 5B(2) brush upper left RAB and any position between $1\frac{1}{2}$ and $6\frac{1}{4}$ (written $1\frac{3}{4}/6\frac{1}{2}$) across Figs. 5E(2) 5H(2), from terminal *LT1* Fig. 5H(2) to the corresponding terminal in Fig. 7B(1), through winding of *Lf* to the battery.
- Circuit 1127—ground via pulser RAM' Fig. 5B(2) across Figs. 5B(1) and 5A(2), via *ip2* back Fig. 5A(1), across Figs. 5A(2) 5B(1) brush lower right RAD Fig. 5B(2) brush upper left 55 RAD in position any between 5 and 6 (written $5\frac{1}{4}/5\frac{3}{4}$) down across Figs. 5E(2) 5H(2) from terminal *tk* Fig. 5H(2) to the corresponding terminal in Fig. 7B(1) thence branching through windings of *Ta1* and *Ta2* in parallel 60 in battery on the one hand and across through windings of *Tb1* and *Tb2* Fig. 7A(2) to battery on the other hand.
- Circuit 1128—ground via pulser RAM' Fig. 5B(2) across Figs. 5B(1) and 5A(2), via *ip2* back Fig. 65 5A(1), across Figs. 5A(2) 5B(1), via brush lower right RAD Fig. 5B(2), brush upper right RAD in any position between 6 and $7\frac{1}{4}$ (written $6\frac{1}{4}/7$) down across Figs. 5E(2) 5H(2), from terminal *ek* Fig. 5H(2) to the corresponding terminal in Fig. 7B(1) thence branching through windings of *Eh1* *Eh2* and *Eh3* in parallel Fig. 7A(2) to battery.
- Circuit 1129—ground via *db3* back Fig. 4C(3) *sr2* back, *sf1* front Fig. 4C(2) *ss1* back, *sh2* 75 front Fig. 4C(1) through winding of *Eg* Fig. 4E(1) to battery.
- Circuit 1130—ground via *db3* back Fig. 4C(3) *sr2* back, *sf1* front Fig. 4C(2) *ss1* back, *sh2* front Fig. 4C(1) through winding of *Eg1* around and up via *At3* front Fig. 4C(2) to battery.
- Circuit 1131—ground via right hand contact with relay *Eg1* Fig. 4C(1) across Figs. 4E(1) 4E(2) 4F(1) through winding of *As* Fig. 4F(2) to battery.
- Circuit 1132—ground via left hand contact of *eg1* Fig. 4C(1) *hp1* front thence dividing over *bn2* front and *bn3* front Fig. 4E(1) across Figs. 4C(1) 4C(2) 4C(3) 4D(1) 4D(2) via leads *303* one of which extends to the duplicate equipment (not shown) and the other of which extends to Fig. 5D(1) then across Figs. 5D(2) 5E(1) 5E(2) 5F(1) 5F(2) thence branching through windings of *Su1* *Su2* Fig. 5C(2) to battery.
- Circuit 1133—ground via *so1* front Fig. 4C(1) down across Figs. 4E(1) 4E(2) 4F(1), branching through *as3* and *as4* front over Fig. 4D(2), via leads *305* one of which extends to the duplicate equipment (not shown) and the other of which extends to Fig. 5D(1), through the winding of *Sb* to battery.
- Circuit 1134—ground via *eg2* front Fig. 4E(1) across Figs. 4C(1) 4C(2) 4C(3) 4D(1) 4F(1), via lead *820* to Fig. 8B(1) across Fig. 8A(2), through right winding of *Tw* Fig. 8A(1) to battery.
- Circuit 1135—ground via *eg3* front Fig. 4E(1) across Figs. 4C(1) 4C(2) 4C(3) 4D(1) 4F(1), via lead *821* to Fig. 8B(1) across Fig. 8A(2), through left winding of *Fp* Fig. 8A(1) to battery.
- Circuit 1136—ground via *eg4* front Fig. 4E(1) across Figs. 4C(2) 4C(3) 4D(1) 4F(1), via lead *822* to Fig. 8B(1) across Fig. 8A(2) through right winding of *Fq* Fig. 8A(1) to battery.
- Circuit 1137—ground via *gh3* front Fig. 4E(2) *eg1* front Fig. 4E(1) winding of *El* to battery.
- Circuit 1137½—ground via *gh3* Fig. 4E(2), *el2* front Fig. 4E(1), thru winding of *El* to battery.
- Circuit 1138—ground via *el1* front Fig. 4E(1), across Fig. 4C(1), thru the winding of *Nm* Fig. 4A(1) to battery.
- Circuit 1139—ground via *el3* front and *el4* front Fig. 4E(1), across Figs. 4E(2), 4F(1), 4F(2), 4D(2), via leads *313* one of which extends to the duplicate equipment (not shown) and the other of which extends to Fig. 5D(1), via *mt2* back across Figs. 5G(1), 5G(2), via *eq2* front Fig. 5D(2), through the winding of relay *Eq* to battery.
- Circuit 1140—battery via resistor shown adjacent relay *Su2* Fig. 5C(2), *su2* 6 front across Figs. 5F(2) 5I(2) via lead *LN* to Fig. 6C(2) across Fig. 6F(2) via *sf13* 6 front Fig. 6F(1) across Figs. 6E(2) 6E(1) 6D(2) via the seventh wire of the SO multiple to Fig. 7A(1), across Fig. 7A(2) 7B(1) to a point just to the left of relay *Xh1* in the chain of relays *Xh1*, *Xh2* . . . *Xh8*, thence through the relays of windings of *Xh6* (not shown), *Xh5* (not shown) *Xh4* (not shown) *Xh3* (not shown), *Xh2* Fig. 7C(1).
- Circuit 1141—ground via *su1* 6 front Fig. 5C(2) across Figs. 5C(1) 5B(2) 5B(1), via pulser RAU Fig. 5B(2), down across Figs. 5E(2) 5H(2) 5I(1) 5I(2), via lead *-401* to Fig. 6C(2) via *tc1* 3 back *tc6* 3 back *tc5* 3 back *tc4* 3 back Fig. 6C(1) *tc3* 3 front *sf14* 1 front Fig. 6F(1) across Fig. 6E(2), via *mr3* 2 front Fig. 6E(1) via lead *10* IP to the corresponding lead (not

shown) in drawing group 7 then thru the winding of switch SM10 (not shown) of the main accumulator.

Circuit 1142—since $t/6$ is not shown the corresponding circuit for $t/8$ via contact X of arc $smb8$ can be taken as illustrative: ground via $lt1$ front Fig. 7B(2) across Fig. 7B(1) then downward and to the right in Fig. 7A(2), via contact Xo of arc $smb8$ and its associated wiper Fig. 7B(1), thru the left winding of $T/8$ to 10 battery.

Circuit 1143—since arcs $smb3$ - $smb8$ are not shown the corresponding circuit thru arcs $smb1$ - $smb8$ (instead of thru arcs $smj1$ - $smb8$) may be taken as illustrative: Ground via $lt1$ front Fig. 7B(2) $t/8$ 2 front Fig. 7B(1) contact 8 of arc $smb1$ and its associated wiper Fig. 7A(2) thence branching thru left winding of $t/1$ to battery on the one hand and on the other hand onward to the ninth contact of arc $smb3$ (not shown) etc. . . . finally after passing thru the ninth contacts and wipers of arcs of $smb6$, $smb5$, $smb4$, $smb3$ (not shown) with consequent operation of the associated $T/$ relays, the circuit extends thru the ninth contact and wiper of arc $smb2$ Fig. 7A(1) partly thru the left winding of relay $T/2$ to battery and partly onward thru the ninth contact and wiper of arc $smb1$, thru the left winding of relay $T/1$ to battery. This illustrative circuit above traced will thus operate relays $T/1$ - $T/1$ via the ninth contacts of arcs $smb1$ - $smb1$ assuming that relay $T/8$ were energized. 25

Circuit 1144—ground via $q3$ back Fig. 5G(1) across Fig. 5G(2), via $eq1$ front Fig. 5D(2) 35 brush lower right RCB in position 1 magnet RCM to battery.

Circuit 1145—ground via brush upper left RCD Fig. 5E(1) brush lower right RCD in any position between $6\frac{1}{4}$ and $7\frac{1}{4}$ (written 7) across 40 Figs. 5H(1) 5G(2) 5G(1) via lead 314 to one of the leads 314 in Fig. 8B(2).

Circuit 1146—ground from lead 314 as traced in circuit 1147 via $ec3$ front Fig. 8B(2) across Fig. 8D(2), via lead $CH1$ to Fig. 7C(1) across 45 Figs. 7C(2) 7D(1) via the wiper and a contact $smj16$ Fig. 7D(2), via the corresponding contact and the wiper $smj16'$, via the wiper and contact of arc $smj15'$ via corresponding contact and the wiper $smj15$ thus continuing the series 50 thru wiper-and-arc assemblies $smj14$, $smj14'$, $smj13$, $smj13'$, $smj12$, $smj12'$, $smj11$, $smj11'$, $smj10$, $smj10'$, $smj9$, $smj8$, $smj8'$, $smj7$, $smj7'$, $smj6$, $smj6'$, $smj5$, $smj4$, $smj4'$, $smj3$, $smj3'$, $smj2$, $smj2'$, $smj1$, $smj1'$, only a 55 few of these arcs being shown in Figs. 7D(2) 7D(1) 7C(2) 7C(1) then via lead $CH2$ up across Fig. 8D(2) via $ec2$ front Fig. 8B(2), across Figs. 8B(1) 8A(2), thru winding of Vs Fig. 8A(1). Circuit 1147—ground via $at14$ front Fig. 8A(2), 60 $vs2$ front Fig. 8A(1), 0 contact and wiper of arc $ldmb$ Fig. 8C(1), through winding of Ls Fig. 8A(1), to battery.

Circuit 1148—ground via pulser IRE Fig. 8C(1), $ls1$ front Fig. 8A(1), through magnet LDM , to 65 battery.

Circuit 1149—ground via wiper and 0 contact of $smc16'$ arc Fig. 7B(2), thence through higher order arcs and wipers in 0 position in series up to the order upon which the LD switch is 70 standing at the moment under consideration. Assuming for example that LD has taken two steps to position 2 at the instant under consideration, the corresponding wire of multiple MLA would be wire 15 and thus the above 75

traced ground potential, after passing through wipers and 0 contacts of the two arcs $smc16'$ and $smc15'$ would extend across Figs. 7D(1), 7C(2), 7C(1), via the fifteenth wire of multiple MLA to Fig. 8D(2), thence across Figs. 8B(1), 8A(2), via contact No. 2 and wiper $ldmb$ Fig. 8C(1), through the winding of Ls Fig. 8A(1), to battery.

Circuit 1150—ground via $vs3$ front Fig. 8A(1), 0 contact and wiper of arc $fdma$ Fig. 8C(2), $pu3$ back, across Fig. 8C(1), through the winding of Fa Fig. 8A(1), to battery.

Circuit 1151—ground via pulser IRE Fig. 8C(1), $ja3$ front Fig. 8A(1), through the winding of FDM, to battery.

Circuit 1152—ground via $smc1'$ wiper and 0 contact, thence through the wipers and 0 arc contacts of as many assemblies as necessary to reach the wire upon which switch FD is standing at the moment. If it be assumed that at the moment in question switch FD has taken two steps to position 2, the second wire of the MLA multiple is the one involved, and in such case, the ground potential just above traced after passing through wiper and arc assemblies $smc1'$, $smc2'$ in series extends via wire 2 of multiple MLA, across Figs. 8B(2), 8B(1), 8A(2), via the 2 contact and wiper of arc $fdma$ Fig. 8C(2), $pu3$ back up across Fig. 8C(1), through winding Fa Fig. 8A(1), to battery.

Circuit 1153—ground via $vs4$ front Fig. 8A(1) $ja1$ front thru winding of Id Fig. 8C(1) to battery.

Circuit 1154—ground via $vs4$ front Fig. 8A(1) $id2$ front Fig. 8C(1), thru the winding of Id to battery.

Circuit 1155—battery via resistor shown adjacent relay Fa Fig. 8A(1) $ja4$ back, $id1$ front Fig. 8C(1), thru the winding of Ic to ground.

Circuit 1156—ground via $ic2$ front Fig. 8C(1), wiper and 6 contact of arc $fdmc$ Fig. 8C(2), wire 6 of multiple MLB across Figs. 8C(2) 8D(1) 8D(2) 7C(1) to the wiper and contact 7 of arc $smc6$ (not shown) thence over wire 7 of multiple MLC from Fig. 7A(1) across Figs. 8D(2) 8B(2) 8B(1) 8A(2), thru the right winding of relay Tp Fig. 8A(1) to battery.

Circuit 1157—battery via resistor shown adjacent relay Fa Fig. 8A(1) $ja4$ back, $id1$ front Fig. 8C(1), thru the winding of Ic to ground.

Circuit 1158—ground via $ic2$ front Fig. 8C(1), wiper and 6 contact of arc $fdmc$ Fig. 8C(2), wire 6 of multiple MLB across Figs. 8C(2) 8D(1) 8D(2) 7C(1) to the wiper and contact 7 of arc $smc6$ (not shown) thence over wire 7 of multiple MLC from Fig. 7A(1) across Figs. 8D(2) 8B(2) 8B(1) 8A(2), thru the right winding of relay Tp Fig. 8A(1) to battery.

Circuit 1159—battery via $ts1$ front Fig. 8C(1) across Fig. 8A(1) via lead 805 to Fig. 4E(1), across Figs. 4E(1) 4C(1) 4A(1) via lead 113 to Fig. 3(2), brush lower right RLBB brush lower left RLBB in position 1 across Fig. 3(1) via lead 13 to Fig. 2(2) thru magnet PM to ground.

Circuit 1160—ground via $ts2$ front Fig. 8C(1) $pu2$ back Fig. 8C(2) across Fig. 8A(2) thru magnet FDM Fig. 8A(1) to battery.

Circuit 1161—ground via $ic2$ front Fig. 8C(1) wiper and 1 contact of arc $fdmc$ Fig. 8C(2), wire 7 of multiple MLB across Figs. 8C(2) 8D(1) 8D(2) 7C(1) to the wiper and contact 3 of arc $smc1$ Fig. 7C(2) thence over wire 3 of multiple MLC from Fig. 7C(2) across Figs. 7C(1) 8D(2) 8B(2) 8B(1) 8A(2) thru the right winding of Og and the left winding of Tw Fig. 8A(1) to battery.

Circuit 1162—ground via $fdmb$ wiper contact 9 Fig. 8C(2) $mu2$ back thru the winding of Pu to battery.

Circuit 1163—ground via $pu1$ front Fig. 8C(2) $pl2$ back across Fig. 8A(2) thru left winding of Tw and right winding of Og Fig. 8A(1) to battery.

Circuit 1164—ground via $pu4$ front Fig. 8C(2) $pl3$ back across Fig. 8A(1) thru right winding

- of F_p and left winding of F_q Fig. 8A(1) to battery.
- Circuit 1165—ground via is_2 front Fig. 8C(1) pu_2 front Fig. 8C(2) pl_1 back, thru the winding of P_m to battery.
- Circuit 1166—ground via ag_1 front Fig. 8A(2) thru winding of P_l Fig. 8C(2) pn_1 front thru winding of relay P_n to battery.
- Circuit 1167—ground via is_2 front Fig. 8C(1) pu_2 front Fig. 8C(2) pl_1 front across Fig. 8A(2), thru winding of magnet FDM Fig. 8A(1).
- Circuit 1168—ground via ic_2 front Fig. 8C(1) wiper and 9 contact of arc $fdmc$ Fig. 8C(2), wire 8 of multiple MLB across Figs. 8C(2) 8B(1) 8B(2) 7C(1) 7C(2) to the wiper and 15 contact 1 of arc smc_8 Fig. 7D(1), via the one wire of multiple MLC across Figs. 7C(2) 7C(1) 8D(2) 8B(2) 8B(1) 8A(2) thru the left winding of relay O_g Fig. 8A(1) to battery.
- Circuit 1169—ground via wiper and contact 10 20 of arc $fdmb$ Fig. 8C(2), via wire 10 of multiple MLL, via contact 10 and wiper of arc $ldmc$ Fig. 8C(1) across Fig. 8C(2) 8A(2) 8B(1), via lead 81_8 to Fig. 4F(1) across Figs. 4F(1) 4D(1) 4C(3) 4C(2) 4C(1) thru winding of R_i Fig. 25 4A(1) to battery.
- Circuit 1170—ground via ri_1 front Fig. 4A(1) thru magnet IRM to battery.
- Circuit 1171—ground via brush upper left RCD Fig. 5E(1) brush lower left RCD in any position between $1\frac{3}{4}$ and $18\frac{1}{4}$ (written 2/18) 30 thence to the No. 3 lever of relay R_i Fig. 4A(1), via ri_3 front, through the winding of R_i to battery.
- Circuit 1172—this path may be considered as beginning at lead 807 Fig. 8A(2), and extending then to Fig. 4E(2), through gh_2 back then up over Figs. 4F(1) 4D(1) 4C(3) 4C(2), 4C(1) through winding of R_i Fig. 4A(1) to battery. 35
- Circuit 1173—ground via ls_2 front Fig. 8A(1) thence to lead 807 Fig. 8A(2) and thence over circuit 1172.
- Circuit 1174—ground via fa_2 front Fig. 8A(1) to lead 807 Fig. 8A(2) and thence over circuit 40 1172.
- Circuit 1175—ground via ph_2 front Fig. 8A(2) to lead 807 and thence via circuit 1172.
- Circuit 1176—ground via bh_2 front Fig. 8B(1) to lead 807 Fig. 8A(2) and thence over circuit 45 1172.
- Circuit 1176—ground via bh_2 front Fig. 8B(1) to lead 807 Fig. 8A(2) and thence over circuit 1172.
- Circuit 1177—ground via ho_1 front Fig. 7B(2), 50 thence to No. 3 lever of relay R_i Fig. 4A(1), via ri_3 front, through winding of R_i to battery.
- Circuit 1178—ground via gr_4 back, Fig. 5G(1) over Fig. 5G(2) brush lower left RCB in any 55 position between $1\frac{3}{4}$ and $18\frac{1}{4}$ (written 2/18) through magnet RCM to battery.
- Circuit 1179—ground via gn_2 back Fig. 7B(2) through the winding of H_o , via the left hand one of the two resistors shown below relay H_o via the number 1 front contact of any one of the relays Om_1 – Om_8 (e. g. via om_8 1 front 60 through the right winding of the corresponding one of the relays sf_1 – sf_8) (e. g. through the right winding of s_8 to battery).
- Circuit 1180—ground via gn_2 back Fig. 7B(2) 65 through the winding of H_o , via the right hand one of the two resistors *when* below relay H_o thence via the wiper and any contact except the zero contact and any one of the arcs sma_9 – sma_16 (e. g. via wiper and one contact 70
- of sma_9) through the right-hand winding of the corresponding one of the relays Fs_9 – Fs_{16} (e. g. through the right winding of Fs_9 to battery).
- 5 Circuit 1181—an illustrative circuit would be ground via pulser RCG Fig. 5E(1) thence from lead 2V Fig. 5E(1) to corresponding lead in Fig. 7A(1), via fs_2 1 front through the right winding of Sm_2 to battery.
- 10 Circuit 1182—ground via rs_3 back Fig. 8A(1) wiper and any contact except zero contact of arc $ldma$ Fig. 8C(1) through the winding of L_s Fig. 8A(1) to battery.
- Circuit 1183—ground via pulser IRE Fig. 8C(1) ls_1 front Fig. 8A(1) through magnet LDM to battery.
- Circuit 1184—ground via ag_1 back Fig. 8A(2) across Fig. 8A(1) through any one of contacts 9–21 and the wiper of arc $fdma$ Figs. 8C(1) and 8C(2) via pu_3 back Fig. 8C(2) across Fig. 8C(1), through winding of F_a Fig. 8A(1) to battery.
- Circuit 1185—ground via ag_1 back Fig. 8A(2) via any contact 1–21 and the wiper of arc $pdma$ Fig. 8C(2), through winding of P_h Fig. 8A(2) to battery.
- Circuit 1186—ground via ag_4 back Fig. 8A(2) across Fig. 8B(1) via any contact 1–21 and the wiper of arc $bdma$ Fig. 8D(1), through winding of B_h Fig. 8B(1) to battery.
- Circuit 1187—ground via db_3 back Fig. 4C(3) sr_2 back, sf_1 front Fig. 4C(2), ss_1 front, sp_1 back through the winding of M_u , through the winding of Do Fig. 4C(1) to battery.
- Circuit 1188—ground via mu_1 front Fig. 4C(2) thence on the one hand through the winding M_h to battery and on the other hand across Figs. 4C(3) 4D(1) 4F(1) via lead 824 to Fig. 8B(1) across Fig. 8D(1) through winding of M_u Fig. 8C(2) to battery.
- Circuit 1189—ground via ag_4 front Fig. 8A(2) via mu_3 front Fig. 8C(2) thence on the one hand through the winding of M_u to battery and on the other hand across Figs. 8D(1) 8B(1) via lead 824 to Fig. 4F(1) across Figs. 4D(1) 4C(3) through winding of M_h Fig. 4C(2) to battery.
- Circuit 1190—ground via el_1 back Fig. 4E(1) across Fig. 4C(1), via mu_5 front and mu_6 front Fig. 4C(1) across Figs. 4C(3) 4D(1) 4D(2), via leads 301 on the one hand to the duplicate computing equipment (not shown) and on the other hand to Fig. 5D(1) through winding of M_i to battery.
- Circuit 1191—ground via gr_3 front Fig. 5G(1) ml_1 front Fig. 5D(1), through the winding of M_i to battery.
- Circuit 1192—ground via mh_3 front Fig. 4C(2), across Figs. 4C(3) 4A(2) 4B(1), through the windings of $C49$ and $C50$ Fig. 4B(2) to battery.
- Circuit 1193—ground via el_3 and el_4 front Fig. 4E(1) across Figs. 4E(2) 4F(1) 4F(2) 4D(2) via one of leads 313 to Fig. 5D(1) via ml_2 front, through the winding of M_e to battery.
- Circuit 1194—ground via me_3 front Fig. 5D(1), ml_1 1 back Fig. 5D(2), through magnet RMM to battery.
- Circuit 1194½—ground via me_1 front Fig. 5D(1), across Figs. 5D(2) 5E(1) 5E(2) 5F(1) 5F(2) thence branching through the windings of relays Ad_1 and Ad_2 Fig. 5C(2) to battery.
- Circuit 1195—ground via me_4 front Fig. 5D(1), down across Fig. 5G(2) via lead 427 to Fig. 6B(1), through the winding of A_j to battery.

- Circuit 1186—ground via contacts *nb8* 1 (shown apart from their relay at the top of Fig. 5B(1) or shown fully as unnumbered contacts of relay C79 Fig. 4D(2)) if these contacts are closed, down across Fig. 5B(1) through brush upper left RMC in any position between 1½ and 2½ (written 1¾/2) Fig. 5E(1) via brush lower right RMB, *frm3* back, through winding of *Mt1* Fig. 5D(2) to battery.
- Circuit 1187—ground via contacts *nb8* 2 (shown apart from their relay at the top of Fig. 5B(1) or shown fully as unnumbered contacts of relay C80 Fig. 4D(2)) if these contacts are closed, down across Fig. 5B(1) through brush upper right RMC in any position between 2½ and 3½ (written 2¾/3) Fig. 5E(1) via brush lower right RMB, *frm3* back, through winding of *Mt1* Fig. 5D(2) to battery.
- Circuit 1188—ground via contacts *nb8* 4 (shown apart from their relay at the top of Fig. 5B(1) or shown fully as unnumbered contacts of relay C81 Fig. 4D(2)) if these contacts are closed, down across Fig. 5B(1) through brush upper left RMB in any position between 3½ and 4½ (written 3¾/4) Fig. 5E(1) via brush lower right RMB, *frm3* back, through winding of *Mt1* Fig. 5D(2) to battery.
- Circuit 1189—ground via contacts *nb8* 5 (shown apart from their relay at the top of Fig. 5B(1) or shown fully as unnumbered contacts of relay C82 Fig. 4D(2)) if these contacts are closed, down across Fig. 5B(1) through brush upper right RMB in any position between 4½ and 5½ (written 4¾/5) Fig. 5E(1) via brush lower right RMB, *frm3* back, through winding of *Mt1* Fig. 5D(2) to battery.
- Circuit 1200—ground via brush lower right RMN Fig. 5D(1) brush upper left RMN in any position between 5½ and 6½ (written 5¾/6) across Fig. 5G(1) via lead 411 to Fig. 6A(1) via *vb1* back, through winding of *Va* to battery.
- Circuit 1201—ground via *a/2* front Fig. 6B(1) across Fig. 6A(2), via *vc1* back Fig. 6A(1), through right winding of *Vb*, via *vc2* front, through winding of *Va* to battery.
- Circuit 1202—ground via *vb1* front Fig. 6A(1), *vr1* 2 back Fig. 6A(2) through winding of *Br1* to battery.
- Circuit 1203—ground via brush lower right RMN Fig. 5D(1), brush upper left RMN in any position between 10½ and 11½ (written 10¾/11) across Fig. 5G(1), via lead 411 to Fig. 6A(1), via *vb1* front through left winding of *Vb* and winding *Vc* in parallel to battery.
- Circuit 1204—ground via *a/4* front Fig. 6B(1) through winding of *Vr1* Fig. 6A(2), via *br1* 1 front through winding of *Br1* to battery.
- Circuit 1205—ground via brush lower right RMN Fig. 5D(1) brush lower left RMN in any position between 16¾ and 18¾ (written 17/18) across Fig. 5G(1) via lead 411 to Fig. 6A(1) via *vb1* back, through winding of *Va* to battery.
- Circuit 1206—ground via *vb1* front Fig. 6A(1), *vr1* 2 front Fig. 6A(2) *vr2* 2 back through the winding of *Br2* to battery.
- Circuit 1207—ground via brush lower right RMN Fig. 5D(1) across Fig. 5D(2) (e. g. via a tie bushing) via brush upper right RMW in the interval 17¾/18 Fig. 5E(1) through winding of *Frm* to battery.
- Circuit 1208—ground via *me2* front Fig. 5D(1) across Fig. 5D(2), via *frm2* front Fig. 5E(1) through winding of *Frm* to battery.
- Circuit 1209—ground via brush lower right RMN Fig. 5D(1) brush upper left RMN in any position between 5½ and 6½ (written 5¾/6) across Fig. 5G(1) via lead 411 to Fig. 6A(1), via *vb1* front through left winding of *Vb* and winding *Vc* in parallel to battery.
- Circuit 1210—ground via *a/4* front Fig. 6B(1) through the winding of *Vr2* Fig. 6A(2), via *br2* 1 front, through winding of *Br2* to battery.
- Circuit 1211—ground via brush lower right RMN Fig. 5D(1), brush upper left RMN in any position between 10½ and 11½ (written 10¾/11) across Fig. 5G(1), via lead 411 to Fig. 6A(1) via *vb1* back through winding of *Va* to battery.
- Circuit 1212—ground via *vb1* front Fig. 6A(1), *vr1* 2 front Fig. 6A(2) *vr2* 2 front, *vr3* 2 back, through winding of *Br3* to battery.
- Circuit 1213—ground via brush lower right RMN Fig. 5D(1) brush lower left RMN in any position between 16¾ and 18¾ (written 17/18) across Fig. 5G(1) via lead 411 to Fig. 6A(1), via *vb1* front through left winding of *Vb* and winding *Vc* in parallel to battery.
- Circuit 1214—ground via *a/3* front Fig. 6B(1), through winding of *Vr3* Fig. 6A(2), via *br3* 1 front, through the winding of *Br3* to battery.
- Circuit 1215—ground via brush lower right RMN Fig. 5D(1), across Fig. 5D(2) (e. g. via a tie bushing) via brush lower left RMW in any position between 16¾ and 17¾ (written 16¾/17 Fig. 5E(1)) via *frm1* front, through winding of *Or* to battery.
- Circuit 1216—ground via *me2* front Fig. 5D(1) across Fig. 5D(2), via *or1* front Fig. 5E(1), through winding of *Or* to battery.
- Circuit 1217—ground via *nb2* 1 front if closed Fig. 5A(2), brush upper left RMK in any position between 1½ and 2½ (written 1¾/2) Fig. 5D(2), brush lower right RMJ, via *or2* front Fig. 5E(1), *frm3* front through winding of *Mt1* Fig. 5D(2), to battery.
- Circuit 1218—ground via *nb2* 2 front if closed Fig. 5A(2), brush upper right RMK in any position between 2½ and 3½ (written 2¾/3) Fig. 5D(2), brush lower right RMJ, via *or2* front Fig. 5E(1), *frm3* front through winding of *Mt1* Fig. 5D(2), to battery.
- Circuit 1219—ground via *nb2* 4 front if closed Fig. 5A(2), brush upper left RMJ in any position between 3½ and 4½ (written 3¾/4) Fig. 5D(2), brush lower right RMJ, via *or2* front Fig. 5E(1), *frm3* front, through winding of *Mt1* Fig. 5D(2), to battery.
- Circuit 1220—ground via *nb2* 5 front if closed Fig. 5A(2), brush upper right RMJ in any position between 4½ and 5½ (written 4¾/5) Fig. 5D(2), brush lower right RMJ, via *or2* front Fig. 5E(1), *frm3* front, through winding of *Mt1* Fig. 5D(2), to battery.
- Circuit 1221—ground via *me3* front Fig. 5D(1), *mt1* 1 front Fig. 5D(2), *n2* back, through winding of *Mf1*, to battery.
- Circuit 1222—ground via *me3* front Fig. 5D(1), *mt1* 1 front Fig. 5D(2), *m2* front, through winding of *Mf1*, to battery.
- Circuit 1223—ground via *m3* front Fig. 5D(2), *n1* back (or ground via *mf1* front, *n3* back), via brush lower left RMO Fig. 5E(1), brush upper left RMP in any position between 1¾ and 2½ (written 2), up across Figs. 5E(2), 5F(1), 5C(1), thence branching through windings of *Fu1* and *Fu2* Fig. 5C(2), to battery.
- Circuit 1225—ground via *m4* front Fig. 5D(2), across Fig. 5G(2), via lead 429 to Fig. 6B(1),

- via *a/1* front, *vr4 1* back Fig. 6A(1), *br4 2* back, *vr3 1* front Fig. 6A(2), thence dividing through windings *S/5* and *S/6* Fig. 6D(2), to battery.
- Circuit 1226—ground via *n4* front Fig. 5D(2), across Figs. 5D(1), 5G(2), via lead LL to Fig. 6A(2), via *s/5 3* front Fig. 6D(2), through the windings of *S/5* and *S/6*, to battery.
- Circuit 1227—starting from a point adjacent relay *Ar1* Fig. 5B(2), wire 401 extends down across Figs. 5E(2), 5H(2), then across to Fig. 6B(2), to wire *W1* Fig. 6E(2), thence leftward across Fig. 6E(1), via *s/5 2* front Fig. 6D(2), across Figs. 6E(1), 6E(2), through *nr1 3* front Fig. 6F(1), via wire 3VP to the corresponding wire (not shown in drawing group 7) which is understood to be connected to switch *SM3* (not shown) in the same manner that wires 1IP and 2IP Fig. 7C(2), are connected to switches *SM1* and *SM2* Fig. 7C(1) respectively.
- Circuit 1227½—starting from a point adjacent relay *Ar1* Fig. 5B(2), wire 401 extends down across Figs. 5E(2), 5H(2), then across to Fig. 6B(2), to wire *W1* Fig. 6E(2), thence leftward across Fig. 6E(1), via *s/5 2* front Fig. 6D(2), across Figs. 6E(1), 6E(2), through *nr1 3* front Fig. 6F(1), via wire 3VP to the corresponding wire (not shown in drawing group 7) which is understood to be connected to counting chain *Fs3*, *Fv3*, *Fv2* (not shown) in the same manner as wires 1VP, 2VP Fig. 7B(1) are connected to counting chains *Fs1*, *Fv1*, *Fv1* and *Fs2*, *Fv2*, *Fv2* Fig. 7A(1), respectively.
- Circuit 1228—starting from a point adjacent relay *Ar8*, Fig. 5C(2), wire 408 extends down across Figs. 5F(2), 5I(2), then across Fig. 6C(2), to wire *W8* Fig. 6F(2), thence leftward across Figs. 6F(1), 6E(2), 6E(1), via *s/6 5* front Fig. 6D(2), *mr3 2* front Fig. 6E(1), via wire 10IP, to the corresponding wire (not shown in drawing group 7) which is understood to be connected to switch *SM10* (not shown) in the same manner that wires 1IP, 8IP and 9IP Fig. 7A(2) are connected to switches *SM1* Fig. 7A(2), *SM8* Fig. 7B(1) and *SM9* Fig. 7B(1), respectively.
- Circuit 1228½—starting from a point adjacent relay *Ar8*, Fig. 5C(2), wire 408 extends down across Figs. 5F(2), 5I(2), and then across Fig. 6C(2), to wire *W8* Fig. 6F(2), thence leftward across Figs. 6F(1), 6E(2), 6E(1), via *s/6 5* front Fig. 6D(2), across Figs. 6E(1) and 6E(2), via *nr3 2* front, via wire 10VP corresponding wire (not shown in drawing group 7) which is understood to be connected to counting chain *Fs10*, *Fv10*, *Fv10* (not shown) in the same manner as wires 1VP, 8VP, 9VP Fig. 7B(2) are connected to counting chains *Fs7*, *Fv7*, *Fv7* Fig. 7A(2) and *Fs8*, *Fv8*, *Fv8* and *Fs9*, *Fv9*, *Fv9* Fig. 7B(1).
- Circuit 1229—ground via *m/3* front, Fig. 5D(2), *n1* front, through magnet *RMM*, to battery.
- Circuit 1230—ground via *nb2 2* front if closed Fig. 5A(2), brush upper right *RMK* in any position between $2\frac{1}{2}$ and $3\frac{1}{4}$ (written $2\frac{2}{3}/3$) Fig. 5D(2), brush lower right *RMJ*, *or2* front Fig. 5E(1), *frm3* front, through winding of *M1*, Fig. 5D(2), to battery.
- Circuit 1231—ground via *nb2 4* front if closed Fig. 5A(2), brush upper left *RMJ* in any position between $3\frac{1}{2}$ and $4\frac{1}{4}$ (written $3\frac{3}{4}/4$) brush lower right *RMJ*, *or2* front Fig. 5E(1), *frm3* front, through winding of *M1* Fig. 5D(2), to battery.
- Circuit 1232—ground via *nb2 5* front if closed Fig. 5A(2), brush upper right *RMJ* in any position between $4\frac{1}{2}$ and $5\frac{1}{2}$ (written $4\frac{3}{4}/5$) Fig. 5D(2), brush lower right *RMJ*, *or2* front Fig. 5E(1), *frm3* front, through winding of *M1* Fig. 5D(2), to battery.
- Circuit 1233—ground via *m/3* front Fig. 5D(2), *n1* back (or ground via *m/1* front, *n3* back), via brush lower left *RMO* Fig. 5E(1), brush upper right *RMP* in any position between $4\frac{3}{4}$ and $5\frac{1}{4}$ (written 5), through magnet *RM5* Fig. 5E(2), to battery.
- Circuit 1234—ground via brush lower right *R5B* Fig. 5E(2), brush upper left *R5C* in any position between $1\frac{1}{2}$ and 8 (written $1\frac{3}{4}/7\frac{3}{4}$), across Fig. 5E(1), through winding of *N* Fig. 5D(2), to battery.
- Circuit 1235—ground via *a/3* front Fig. 6B(1), across Fig. 6A(2), through winding *Vr4* Fig. 6A(1), *br4 1* front, through winding of *Br4*, to battery.
- Circuit 1236—ground via contacts *nb1 1* front if closed Fig. 5A(2), brush lower left *RML* in any position between $5\frac{1}{2}$ and $6\frac{3}{4}$ (written $6/6\frac{1}{2}$) Fig. 5D(2), brush lower right *RMJ*, *or2* front Fig. 5E(1), *frm3* front, through winding of *M1* Fig. 5D(2), to battery.
- Circuit 1237—ground via *nb1 2* front if closed Fig. 5A(2), brush upper left *RML* in any position between 7 and $7\frac{3}{4}$ (written $7\frac{1}{4}/7\frac{1}{2}$) Fig. 5D(2), brush lower right *RMJ*, *or2* front Fig. 5E(1), *frm3* front, through winding of *M1* Fig. 5D(2), to battery.
- Circuit 1238—ground via *nb1 4* front if closed Fig. 5A(2), brush upper right *RML* in any position between 8 and $8\frac{3}{4}$ (written $8\frac{1}{4}/8\frac{1}{2}$) Fig. 5D(2), brush lower right *RMJ*, *or2* front Fig. 5E(1), *frm3* front, thru winding of *M1* Fig. 5D(2), to battery.
- Circuit 1239—ground via *nb1 5* front if closed Fig. 5A(2), brush lower right *RML* in any position between $9\frac{1}{4}$ and $10\frac{1}{4}$ (written $9\frac{1}{2}/10$) Fig. 5D(2), brush lower right *RMJ*, *or2* front Fig. 5E(1), *frm3* front, through winding of *M1* Fig. 5D(2), to battery.
- Circuit 1240—ground via *m/3* front Fig. 5D(2), *n1* back (or ground via *m/1* front *n3* back) via brush lower left *RMO* Fig. 5E(1), brush lower left *RMP* in any position between $7\frac{1}{4}$ and $7\frac{3}{4}$ (written $7\frac{1}{2}$) through magnet *RM2* Fig. 5E(2) to battery.
- Circuit 1241—ground via *m/4* front Fig. 5D(2) across Fig. 5G(2) via lead 429 to Fig. 6B(1), via *a/1* front, across Fig. 6A(2) via *vr4 1* back Fig. 6A(1) *br4 2* front thence branching through windings of *S/3* and *S/4* Figs. 6D(1) 6D(2) to battery.
- Circuit 1242—ground via *n4* front Fig. 5D(2), across Figs. 5D(1) 5G(2) via lead LL to Fig. 6A(2), down across Fig. 6D(2), via *s/3 3* front Fig. 6D(1), then branching through the windings of *S/3* Fig. 6D(1) and *S/4* Fig. 6D(2), to battery.
- Circuit 1243—ground via brushes lower left and lower right *R2B* Fig. 5E(2), brush upper left *R2C* in any position between $1\frac{1}{2}$ and $9\frac{1}{2}$ (written $1\frac{3}{4}/9\frac{1}{4}$), across Fig. 5E(1), through the winding of *N* Fig. 5D(2) to battery.
- Circuit 1246—ground via brush lower right *R2U* in any position between 8 and $10\frac{1}{4}$ (written $8\frac{1}{4}/10$) Fig. 5F(2), brushes lower left and lower right *R2T*, pulser *R2DD* across Fig. 5F(1), via brushes lower left and lower right

- R2E Fig. 5H(2), via brushes lower left and upper left R2D in any position between 8 and 9 (written $8\frac{1}{4}/8\frac{3}{4}$) down to terminal TK Fig. 5H(2), thence across to the corresponding terminal Fig. 7B(1) then dividing through the windings of relays Ta1 Fig. 7B(1), Ta2 Fig. 7B(2), Tb1 Fig. 7A(2), Tb2 Fig. 7A(2), to battery.
- Circuit 1247—ground via brush lower right R4U in any position between $10\frac{1}{4}$ and $12\frac{1}{4}$ (written $10\frac{1}{2}/12$) Fig. 5F(2), brush lower left, R4T pulser R4DD, across Fig. 5F(1), brush lower left R4E Fig. 5E(2), brush upper left R4D in any position between $10\frac{1}{4}$ and $11\frac{1}{4}$ (written $10\frac{1}{2}/11$) down to terminal TK Fig. 5H(2), thence across to the corresponding terminal Fig. 7B(1) then dividing through the windings of relays Ta1 Fig. 7B(1), Ta2 Fig. 7B(2), Tb1 Fig. 7A(2) Tb2 Fig. 7A(2) to battery.
- Circuit 1248—ground via brush lower right R5U in any position between $6\frac{1}{2}$ and $8\frac{1}{2}$ (written $6\frac{3}{4}/8\frac{1}{4}$) Fig. 5F(2), brush lower left R5T, pulser R5DD, across Figs. 5I(2) 5I(1) 5H(2), via brush lower left R5E Fig. 5E(2), brushes lower left and upper left R5D in any position between $6\frac{1}{2}$ and $7\frac{1}{2}$ (written $6\frac{3}{4}/7\frac{1}{4}$) down to terminal TK Fig. 5H(2), thence across to the corresponding terminal Fig. 7B(1) then dividing through the windings of relays Ta1 Fig. 7B(1), Ta2 Fig. 7B(2), Tb1 Fig. 7A(2) Tb2 Fig. 7A(2) to battery.
- Circuit 1249—ground via brush lower right R2U in any position between 8 and $10\frac{1}{4}$ (written $8\frac{1}{4}/10$) Fig. 5F(2), brushes lower left and lower right R2T, pulser R2DD across Fig. 5F(1) via brushes lower left and lower right R2E Fig. 5E(2), via brushes lower right and upper right R2D in any position between 9 and $10\frac{1}{4}$ (written $9\frac{1}{4}/10$) down to terminal EK Fig. 5H(2), thence across to the corresponding terminal Fig. 7B(1), then dividing through the windings of Eh1 Eh2 Eh3 Fig. 7A(2) to battery.
- Circuit 1250—ground via brush lower right R4U in any position between $10\frac{1}{4}$ and $12\frac{1}{4}$ (written $10\frac{1}{2}/12$) Fig. 5F(2), brush lower left R4T, pulser R4DD, across Fig. 5F(1) via brush lower left R4E Fig. 5E(2), brush upper right R4D in any position between $11\frac{1}{4}$ and $12\frac{1}{4}$ (written $11\frac{1}{2}/12$) down to terminal EK Fig. 5H(2), thence across to the corresponding terminal Fig. 7B(1), then dividing through the windings of Eh1, Eh2, Eh3 Fig. 7A(2) to battery.
- Circuit 1251—ground via brush lower right R5U in any position between $6\frac{1}{2}$ and $8\frac{1}{2}$ (written $6\frac{3}{4}/8\frac{1}{4}$) Fig. 5F(2) brush lower left R5T, pulser R5DD, across Figs. 5I(2) 5I(1) 5H(2), via brush lower left R5E Fig. 5E(2), brushes lower right and upper right R5D in any position between $7\frac{1}{2}$ and $8\frac{1}{2}$ (written $7\frac{3}{4}/8\frac{1}{4}$) down to terminal EK Fig. 5H(2), thence across to the corresponding terminal Fig. 7B(1), then dividing through the windings of Eh1, Eh2, Eh3 Fig. 7A(2) to battery.
- Circuit 1252—ground via brushes lower left and right R2B, Fig. 5E(2), brush upper left R2B in any position between $1\frac{1}{2}$ and $9\frac{1}{4}$ (written $1\frac{3}{4}/9\frac{1}{2}$) down to terminal LT1 Fig. 5H(2), then across to the corresponding terminal in Fig. 7B(1), through the winding of Lf to battery.
- Circuit 1253—ground via brushes lower left and right R2B Fig. 5E(2), brush lower right R2C in any position between $1\frac{1}{4}$ and $8\frac{1}{4}$ (written $2/8$) down to terminal LT2, Fig. 5H(2), across to the corresponding terminal in Fig. 7B(1), through the winding of Lt to battery.
- Circuit 1254—ground via brushes lower left and right R4B, Fig. 5E(2), brush upper left R4B in any position between $1\frac{1}{2}$ and 12 (written $1\frac{3}{4}/11\frac{3}{4}$) down to terminal LT1, Fig. 5H(2), across to the corresponding terminal in Fig. 7B(1), through the winding of Lf to battery.
- Circuit 1255—ground via brushes lower left and lower right R4B, Fig. 5E(2) brush lower right R4C in any position between $1\frac{1}{4}$ and $10\frac{1}{4}$ (written $2/10\frac{1}{4}$) down to terminal LT2, Fig. 5H(2) across to the corresponding terminal in Fig. 7B(1), through the winding of Lt, Fig. 7B(2) to battery.
- Circuit 1256—ground via brushes lower left and right R5B, Fig. 5E(2) brush upper left R5B at any position between $1\frac{1}{2}$ and $8\frac{1}{4}$ (written $1\frac{3}{4}/8$) down to terminal LT1, Fig. 5H(2) across to the corresponding terminal in Fig. 7B(1) through the winding of Lf to battery.
- Circuit 1257—ground via brushes lower left and right R5B, Fig. 5E(2), brush lower right R5C in any position between $1\frac{1}{4}$ and $6\frac{1}{4}$ (written $2/6\frac{1}{2}$) down to terminal LT2, Fig. 5H(2) across to the corresponding terminal in Fig. 7B(1), through the winding of Lt Fig. 7B(2) to battery.
- Circuit 1258—ground via brushes lower left and right R2B Fig. 5E(2), brush upper right R2B, in any position between $1\frac{1}{2}$ and $2\frac{1}{2}$ (written $1\frac{3}{4}/2\frac{1}{4}$) down across Fig. 5H(2), via lead LF to Fig. 6B(2) down across Fig. 6B(2), through winding of Fc Fig. 6E(2) to battery.
- Circuit 1259—ground via brushes lower left and right R2B Fig. 5E(2), brush lower left R2C in any position between $2\frac{1}{2}$ and 8 (written $2\frac{3}{4}/7\frac{1}{4}$) down across Fig. 5H(2) via lead LM to Fig. 6B(2), through winding of Mc Fig. 6E(2) to battery.
- Circuit 1260—ground via brushes lower left and right R4B Fig. 5E(2), brush upper right R4B in any position between $1\frac{1}{2}$ and 2 (written $1\frac{3}{4}/2\frac{1}{4}$) down across Fig. 5H(2) via lead LF to Fig. 6B(2), through winding of Fc Fig. 6E(2) to battery.
- Circuit 1261—ground via brushes lower left and right R4B Fig. 5E(2), brush lower left R4C in any position between 2 and $10\frac{1}{4}$ (written $2\frac{1}{4}/10$) down across Fig. 5H(2) via lead LM to Fig. 6B(2), through winding of Mc Fig. 6E(2) to battery.
- Circuit 1262—ground via brushes lower left and right R5B Fig. 5E(2) via brush upper right R5B in any position between $1\frac{1}{2}$ and $3\frac{1}{4}$ (written $1\frac{3}{4}/3$) down across Fig. 5H(2), via lead LF to Fig. 6B(2), through winding of Fc Fig. 6E(2) to battery.
- Circuit 1263—ground via brushes lower left and right R5B Fig. 5E(2) via brush lower left R5C in any position between $3\frac{1}{4}$ and $6\frac{1}{2}$ (written $3\frac{1}{2}/6\frac{1}{4}$) down across Fig. 5H(2) via lead LM to Fig. 6B(2), through winding of Mc Fig. 6E(2) to battery.
- Circuit 1264—ground via brush lower right RMN Fig. 5D(1) across Fig. 5D(2) (e. g. via a tie bushing) brush lower right RMW in any position between $15\frac{1}{2}$ and $16\frac{1}{4}$ (written $15\frac{1}{4}/16$) Fig. 5E(1) via or2 front, fm3 front, through winding of Mf1 Fig. 5D(2) to battery.
- Circuit 1265—ground via m1 front Fig. 5D(2), n3 back (or m3 front n1 back) brush lower left RMO Fig. 5E(1) brush upper left RMO

in any position between 15 $\frac{1}{4}$ and 16 $\frac{1}{4}$ (written 16) brush lower right RCB in any position between 18 $\frac{1}{4}$ and 1 $\frac{1}{4}$ (written 1) Fig. 5D(2), through magnet RCM to battery.

Circuit 1268—ground via brush upper left RCD Fig. 5E(1), brush lower right RCD in any position between 6 $\frac{1}{4}$ and 7 $\frac{1}{4}$ (written 7) across Figs. 5H(1) 5G(2) 5G(1), via wire 314, across Fig. 4F(2) to the left hand one of the two leads 314 Fig. 8B(2), through winding of Ec to battery. The similar circuit (not shown) from the duplicate computing equipment is understood to extend in a similar fashion to the left hand one of the two leads shown in Fig. 6B(2) and thence to relay Vs as described in circuit 1268.

Circuit 1269—ground via from the duplicate computing equipment (not shown) extends over a path similar to that described in circuit 1268 to the left hand one of the two leads S14 shown in Fig. 8B(2), and thence through ec3 front down across Fig. 8D(2), via lead CH1 to Fig. 7C(1), across Figs. 7C(2), 7D(1), via the wiper and a contact smf16 Fig. 7D(2), via the corresponding contact and the wiper of smf16, via the wiper and contact of arc emf15, via corresponding contact and the wiper and contact of arc smf15, thus continuing the series through wiper and arc assemblies smf14, smf14', smf13', smf13, smf12, smf12', smf11', smf11, smf10, smf10', smf9', smf9, smf8, smf8', smf7', smf7, smf6, smf6', smf5', smf5, smf4, smf4', smf3', smf3, smf2, smf2', smf1', smf1, (only a few of these arcs being shown in Figs. 7D(2), 7D(1), 7C(2), 7C(1)) then via lead CH2, up across Fig. 8D(2), via ec2 front Fig. 8B(2), across Figs. 8B(1), 8A(2), through winding of Vs Fig. 8A(1).

Circuit 1270—ground via fdmb wiper and contact number 6 Fig. 8C(2), wire 6 of multiple MLL, contact 5 and wiper of pdmb, mul2 front, through winding of Pu to battery.

Circuit 1273—ground via wiper and contact number 7 of fdmb Fig. 8C(2), wire 7 of multiple MLL, contact 6 and wiper of bdmb, Fig. 8D(1), mul1 front Fig. 8C(2), up across Figs. 8A(1), 8A(2) 8B(1), via lead 818 to Fig. 4F(1), across Figs. 4F(1), 4D(1), 4C(3), 4D(2), 4C(1), through winding of R4 Fig. 4A(1), to battery.

We claim:

1. A calculating unit provided with digit storing means having denominational groups of contacts, solution accumulator devices, a plurality of test relays and at least one power-driven sequence switch having impulse-producing cams for producing groups of impulses, circuits controlled by said test relays for interconnecting said impulse-producing cams with the accumulator devices, and other cams for connecting groups of said digit storing contacts to said test relays, whereby the test relays control the number of effective impulses sent by said impulse-producing cams to denominational orders of said accumulator devices simultaneously.

2. A calculator as claimed in claim 1, and in which one solution accumulator device comprises units accumulator means and the other comprises "five" impulse accumulator means, and said calculator further comprising means operative after a completed calculation to transmit five unit pulses to each denominational order of the units accumulator means if the corresponding denominational order of the "five" impulse accumulator means is off-normal, and carry-over

means thereafter operative to effect carry-overs required by such transfer of the stored "five" pulses, whereby the result is obtained in decimal form in the units accumulator means.

5 3. A calculator of the type adapted to be controlled by successively received electrical signals representing digits and signs, which comprises digit receiving and storing means for storing a first number in response to the successive receipt of electrical signals representing successive digits thereof, control means variably responsive to electrical sign signals representing different types of computations received after said first number for determining the type of computation to be performed, computation performing structure of a first type associated with said receiving and storing means, computation performing structure of a second type also associated with said receiving and storing means, means for selectively conditioning either of said structures for operation under control of said variably responsive means, means for thereafter receiving and storing further signals representing digits of a second number, means for thereafter receiving an invariable signal representing the end of the problem, and means responsive to receipt of said further signals for performing with respect to said two numbers the type of computation represented by said sign signals under the sole control of said variably responsive control means.

4. A calculator of the type adapted to be controlled by successively received electrical signals representing digits and signs, which comprises digit receiving and storing means for storing a first number in response to the successive receipt of electrical signals representing the successive digits thereof, control means variably responsive to electrical signals representing either a summation sign or a multiplication sign received after said first number for determining the type of computation to be performed, summation performing structure associated with said receiving and storing means, multiplication performing structure also associated with said same receiving and storing means, means for selectively conditioning either said summation performing structure or said multiplication performing structure for operation under control of said variably responsive means, means for thereafter receiving and storing further signals representing digits of a second number, means for thereafter receiving an invariable signal representing the end of the problem, and means responsive to receipt of said further signals for either performing summation of said first and second numbers or performing multiplication thereof depending solely upon the condition of said variably responsive means.

5. A calculator of the type adapted to be controlled by successively received electrical signals representing digits and signs, which comprises digit receiving and storing means for storing a first number in response to the successive receipt of electrical signals representing the digits thereof, control means variably responsive to electrical signals representing either an addition sign or a multiplication sign received after said first number for determining the type of computation to be performed, addition performing structure associated with said receiving and storing means, multiplication performing structure also associated with said same receiving and storing means, means for selectively conditioning either said addition performing structure or said multi-

plication performing structure for operation under control of said variably responsive means, means for thereafter receiving and storing further signals representing digits of a second number, means for thereafter receiving an invariable signal representing the end of the problem, and means responsive to receipt of said further signals for either performing addition of said first and second numbers or performing multiplication thereof depending solely upon the condition of said variably responsive means.

6. A calculator as claimed in claim 3, wherein said digit receiving and storing means comprise multi-order storage devices and wherein said two computation performing structures include accumulator means serving jointly for both types of computation, and further wherein the variably responsive control means comprises instrumentalities responsive to an electric sign signal representing summation received after a first number has been stored in said first storing means for initiating immediate transfer of such number to said accumulator means and for thereupon conditioning the second storage means for the storage of a second number.

7. A calculator as claimed in claim 3, wherein said digit receiving and storing means comprises two separate multi-order storage devices and wherein said two computation performing structures include accumulator means serving jointly for both types of computation, and further wherein the variably responsive control means comprises instrumentalities responsive to an electric sign signal representing summation received after a first number has been stored in said first storing means for thereupon conditioning the second storage means for the storage of a second number.

8. A calculator as claimed in claim 13 for use with problems in which the number of digits in the numbers may vary, wherein said storage means is adapted to store the digits of the first number prior to determination of the ordinal values thereof, and further comprising means for assigning ordinal values to said stored digits in response to the receipt of said electrical operating-sign signal.

9. A calculator as claimed in claim 13, wherein said calculation sign responsive means comprise calculation sign storage means, means for transferring the calculation sign received by said sign responsive means to said sign storage means for controlling the sign of transfer of the succeeding number received, and means for returning a part of the responsive means to normal in readiness to receive a further calculation sign before the transfer of said succeeding number is completed.

10. A calculator as claimed in claim 3, wherein said variably responsive control means comprise two sign storage relay means, and further means for connecting said two sign storage relay means for alternate operation by successive sign signals, and means for clearing each of said sign storage relay means prior to receipt of the said subsequent sign signal whereby the sign of the first, third, fifth, etc. sign signals is stored upon one of said sign storage relay means, while that of the second, fourth, etc. signals is stored on the other of said sign storage relay means.

11. A calculator as claimed in claim 13, further comprising two calculation sign storage devices, one for each number storage means, alternating number distributing means for distributing successive series of digits representing successive numbers alternately to said first mentioned num-

ber storage means and to said second number storage means, sign distributing means for connecting said sign responsive means alternately to said two sign storage devices, and means for controlling the transfer of numbers from said first mentioned number storage means under control of one of said sign storage devices and for controlling the transfer of numbers from said second number storage means under control of the other of said sign storage devices.

12. An electric calculating machine for performing addition or multiplication of two numbers, comprising accumulating means, manipulative means for transmitting electric signals representing successive digits of numbers to be added or multiplied and operation-sign signals, storage means controlled by signals from said manipulative means for storing digits of the first number, means for receiving operation-sign signals representing addition, multiplication or equal, means responsive to the addition signal receiving means when an addition signal is entered therein following entry of a number in said storage device to cause transfer of the stored number to the accumulating means, a second storage means for storing digits of a second number, means effective upon entry of an addition signal into the operation-sign receiving means for placing the manipulative means in control of said second storage means, whereby the second number entered by the manipulative means is transmitted to the second storage device digit by digit, further transfer means effective upon transmission of an equal signal following entry into the second storage means for causing transfer of the number therein to the accumulating means, means responsive to the multiplication signal receiving means upon entry of a signal therein following entry of a number in the first storage means for preventing transfer of said number to the accumulating means and for preconditioning multiplication control means, and multiplying means controlled by the equal sign signal receiving means and said preconditioned multiplication control means, and effective upon entry of a number in the second storage device followed by entry of an equal sign signal, for causing multiplication of the factors stored in the two storage devices and entry of intermediate products of multiplication in the accumulating means.

13. An electrically controllable calculator for performing addition or subtraction between a first number and a second number, comprising means for successively entering signals representing successive digits of said first number, operation signs, and said second number, number storage means for storing digits of said first number, number storage means for storing digits of said second number, calculation sign responsive means for responding to an operation-sign signal representing addition or subtraction after the first number is entered in its storage means, accumulator means on which addition or subtraction is to take place, means for transmitting numbers from said storage devices to the accumulating means, means for in all cases controlling said transmitting means for transmitting the first number from said first storage device to said accumulator means as an addition following the entry of a plus or minus sign, and means for controlling said transmitting means for variably transmitting the second number to said accumulator means as an addition or subtraction, said last means being controlled by the calculation

sign responsive means in accordance with the sign preceding the said second number.

14. An electrically controllable calculator for performing addition or subtraction between a first number and a second number, comprising means for successively entering signals representing successive digits of said first number, operation signs, and said second number, number storage means for storing digits of said first number, number storage means for storing digits of said second number, calculation sign responsive means for responding to an operation-sign signal representing addition or subtraction after the first number is entered in its storage means, accumulator means on which addition or subtraction is to take place, means for transmitting

numbers from said storage devices to the accumulating means, means for in all cases controlling said transmitting means for transmitting the first number from said first storage device to said accumulator means as an addition following the entry of a plus or minus sign, and means for controlling said transmitting means for variably transmitting the second number to said accumulator means as an addition or subtraction, said last means being responsive to a further addition or subtraction sign following the second number and controlled by the calculation sign responsive means in accordance with the sign preceding the said second number.
